ELEVATOR SYSTEM

Edward L. Dunn, East Orange, N. J., assignor to
 Otis Elevator Company, New York, N. Y., a corporation of New Jersey

Application September 28, 1927, Serial No. 222,480

89 Claims. (Cl. 187—29)

This invention relates to electric elevator systems, particularly systems of the automatic push button type.

The invention is particularly useful in buildings where the service is not very intensive and where an operator is not employed, such, for example, as apartment houses. During certain times of the day, the calls may be far apart and, under such conditions, the elevator car responds to each call in the least possible time, regardless of where the car may be at the time that the call is made and the car may then be sent directly to any desired floor by the passenger. During certain other times of the day, there may be several calls overlapping each other and, under such conditions, the car stops to pick up passengers desiring to go in the direction in which the car is traveling and stops to discharge these passengers at their desired destinations; and when the car has stopped at the farthest floor at which these passengers are discharged, it may proceed in the same direction to and stop at the farthest floor from which a call has been made by an intending passenger desiring to be carried in the other direction, whereupon its direction of travel may be reversed. Further, when the car is idle, that is, when there are no calls to be responded to, a passenger, upon entering the car, has preference over an intending passenger at a floor as regards starting the car for a time long enough to enable him to push the button for his desired destination. Also, when the car is loaded to its normal capacity, that is, when there is no room in the car to take on more passengers, calls from the floors are not responded to so that useless stops are avoided. The car stops, however, to discharge passengers and, when room is available in the car, stops are again made to pick up passengers. Thus, a highly efficient service is rendered under all conditions of operation.

One feature of the invention involves a push button controlled elevator car which, when traveling in either direction, stops automatically to pick up intending passengers desiring to be carried in the direction in which the car is traveling and, under certain conditions, stops automatically to pick up intending passengers desiring to be carried in a direction opposite to that in which the car is traveling.

Another feature resides in an elevator system having up and down push buttons at the floors wherein the car, when traveling in the up direction, stops automatically at the floors at which up buttons are pushed and, in the event that down buttons are pushed at floors above the highest

floor at which an up button is pushed, continues its travel in the up direction, after its stop at the highest floor at which an up button is pushed, to the highest floor at which a down button is pushed and stops at such floor, and, when traveling in the down direction, stops automatically at the floors at which down buttons are pushed and, in the event that up buttons are pushed at floors below the lowest floor at which a down button is pushed, continues its travel in the down direction, after its stop at the lowest floor at which a down button is pushed, to the lowest floor at which an up button is pushed and stops at such floor.

A third feature involves the giving of preference as to the starting of the car and establishing its direction of travel to a passenger within the car over an intending passenger at a floor for a predetermined time interval after the gate has been closed, under certain conditions of operation.

A fourth feature resides in the provision of a push button control system for an elevator car which may be alternatively such that the direction of travel of the car may be reversed at any floor or such that the direction of travel of the car may be reversed only at the terminal floors.

A fifth feature is to have the car always stop automatically at a selected floor when traveling in a certain direction but not when traveling in the opposite direction except under certain conditions of operation.

A sixth feature resides in causing the car, when loaded to its normal capacity, to automatically run past floors at which it would otherwise stop to pick up intending passengers.

A seventh feature resides in the provision of an indicator carried by the car for advising intending passengers at the floors as to the direction of car travel.

An eighth feature is the provision of a floor controller for controlling the direction of travel of the car and the stopping of the car at the floors which is of simple construction and reliable and positive in operation.

A ninth feature is the provision of an electromagnetic switch adapted to be latched in one position which is of simple construction, cheap to manufacture and which is positive in operation.

Other features and advantages will become apparent from the following description and appended claims.

In the drawings:
 Figure 1 is a simplified schematic representation of an elevator system;

Figure 2 is a front elevation, with parts broken away, of the floor controller;

Figure 3 is a side elevation of the same, also with parts broken away;

5 Figure 4 is a horizontal section taken along line 4-4 of Figure 3;

Figure 5 is a face view of the arrangement of the floor controller direction switches, stop contacts and car preference switches;

10 Figure 6 is a detail of the pawl switch with its contacts in engagement;

Figure 7 is a view similar to Figure 6 but with the contacts separated;

Figure 8 is a view taken along line 8-8 of 15 Figure 6;

Figure 9 is a view taken along line 9-9 of Figure 8;

20 Figure 10 is a detail of a portion of the floor controller crosshead taken along line 10-10 of Figure 4;

Figure 11 is a side elevation of a floor switch;

Figure 12 is a plan view of the same, with parts in section;

25 Figure 13 is a diagrammatic representation of the arrangement of the switches mounted on the master panel;

Figure 14 is a diagrammatic representation of the control panel, showing particularly the relation of the coils and contacts of various electro- 30 magnetic switches;

Figure 15 is a simplified diagram of the power and control system;

35 Figure 16 is a portion of a diagram, similar to Figure 15, of another arrangement of a part of the control system;

Figure 17 is a portion of a diagram, similar to Figure 15, of still another arrangement of a part of the control system;

40 Figure 18 is a view in front elevation of the direction indicator; and

Figure 19 is a view similar to Figure 17, but with the signs removed.

45 For a general understanding of the invention, reference may be had to Figure 1 wherein various parts of the system are indicated by legend. The system will be described for a five floor installation. It is to be understood, however, that the system may be arranged for any number of floors, five being chosen merely for purposes of 50 description.

The elevator car and counterweight are driven by the hoisting motor. The elevator car is illustrated as positioned at the third floor, the counterweight being behind the car and therefore not shown. The hoisting motor is controlled by various electromagnetic switches mounted on control panel No. 1. The car is caused to stop at various floors by means of the floor controller. This controller also determines the direction of 60 travel of the car.

The car is provided with a gate and a well door is provided at each floor. A door lock cam motor is provided for controlling the locking and unlocking of the well doors. A governor is provided for controlling the speed of the car the governor being driven by a governor rope releasably attached to the elevator car. An electromagnetic brake is provided for assisting in bringing the elevator car to a final stop.

65 70 Up and down push buttons are arranged at the intermediate floors. An up push button is arranged at the bottom floor while a down push button is arranged at the top floor. These buttons, to be known as hall buttons, are for causing the starting of the car in a direction deter-

mined by the floor controller and for causing the floor controller to stop the car at the floors. The elevator car is provided with an independent set of push buttons, one button being provided for each floor. These push buttons, to be known as car buttons, are for causing the car to start in a direction determined by the floor controller and for causing the floor controller to stop the car at the floors. The hall buttons and car buttons are preferably arranged to act through 10 floor switches mounted on control panel No. 2.

A direction indicator is provided in the car for advising intending passengers at a floor at which the car is stopped as to the direction of travel of the car. A safety switch is also arranged in 15 the car, this switch being provided for bringing the car to a stop under emergency conditions.

Reference may now be had to Figures 2 to 10 inclusive which illustrate the various details of a preferred form of floor controller. This controller, designated as a whole by the numeral 310, comprises a frame formed by a base plate 311, four standards 312, 313, 314, and 315 and a top plate 316. The standards are secured in sockets formed in bosses 317 on the base plate 25 311 and sockets formed in bosses 318 on the top plate 316. The base plate 311 is also formed with a centrally disposed pedestal 320. This pedestal and the bosses 321 and 322 formed on the base plate are arranged to provide bearings 30 for an operating shaft 323, only the bearing provided in the pedestal being illustrated. The pedestal 320 is further arranged to provide a vertical bearing 324 and to support a ball thrust bearing 325 for a vertical screw 326. This screw, 35 at its top, extends into a bearing 327 formed in the top plate 316. A bevel gear 328 is secured, as by a pin 330, to the lower end of screw 326. Another bevel gear 331, engaging gear 328 in driving relation, is secured, as by pin 332, to the 40 operating shaft 323. Operative engagement between the bevel gears is maintained by positioning collars 333 on shaft 323. Thus, the operating shaft, upon its rotative movement, acts through the bevel gears to impart rotative 45 movement to screw 326.

A suitable arrangement for causing rotative movement of the operating shaft 323 is illustrated in Figure 1. This driving arrangement comprises two steel tapes 335 and 336 attached 50 to the car. Tape 335 extends from the top of the car to an overhead sheave 337 around which it is wound in a manner similar to a measuring tape. The other tape 336 extends from the bottom of the car around a tension sheave 338 and 55 then up to a second overhead sheave 340 upon which it is similarly but oppositely wound. These overhead sheaves are keyed to the operating shaft 323 of the floor controller, one tape winding up as the other unwinds in the driving 60 operation. This silent drive is as positive as a sprocket chain and is unaffected by sliding or stretching ropes.

A crosshead, designated as a whole by the character 334, is arranged on screw 326. This 65 crosshead is split into two halves, 341 and 342, clamped together as by bolts 343. Ribs are formed on the inside of the crosshead, dividing the interior into three chambers, 344, 345, and 70 346, as shown in Figure 10. The center chamber 345 is for receiving lubricant. The upper and lower chambers 344 and 346 are filled with bearing metal, threaded to fit the screw 326. Thus, upon rotative movement of screw 326, the cross- 75

head is moved longitudinally of the screw. Owing to the fact that the operating shaft 323 is driven by tapes attached to the car, the resulting movement of the crosshead is in accordance 5 with the movement of the car.

Projections 347 and 348 extend oppositely from the half 341 of the crosshead, these projections terminating in forked ends 350 and 351, respectively. The forked end 350 engages a vertically 10 extending bar 352 while the forked end 351 engages a vertically extending bar 353, these forked ends cooperating with their respective bars to form guides for the crosshead. These bars extend between the top plate 316 and the 15 base plate 311, bar 352 being arranged in a socket formed in boss 321 on base plate 311 and in a socket formed in boss 354 on top plate 316, and bar 353 being similarly arranged in a socket formed in boss 322 on base plate 311 and a 20 socket formed in boss 355 on top plate 316.

A bracket 356, formed on half 342 of the crosshead, carries the pawl magnet, designated as a whole by the character 357, and the pawl switches, designated as a whole by the characters 25 358, 360 and 361. The pawl magnet will be described later. The pawl switches are for controlling the slowing down and stopping of the elevator car. As will be seen from later description, switch 360 opens first and will 30 therefore be termed the pawl first slow-down switch. Switch 361 opens next and will be termed the pawl second slow-down switch. Switch 358, which is employed to cause the stopping of the car, as will be seen from later description, opens last and will be termed the pawl 35 stop switch.

Each pawl switch comprises a stationary contact 362 and a movable contact 363. The stationary contacts are mounted on an insulating 40 plate 364, secured to bracket 356 as by screws 365. The stems 367 of the contacts 362 are threaded and extend through threaded bushings 366 set in the insulating plate 364 to permit adjustment. A lock washer 368 and lock nut 370 are provided on 45 each contact stem for locking the stationary contact in its adjusted position, binding nuts 371 being provided in addition on the outer end of the stem for connecting the contact in the system.

Each movable contact 363 is mounted in the 50 outer end of a contact arm of an operating lever, lever 372 being for the pawl first slow-down switch, lever 373 being for the pawl second slow-down switch and lever 374 being for the pawl stop switch. As the construction and mounting of 55 each movable contact is the same, the arrangement of only one of them, namely, the movable contact for the pawl second slow-down switch 361, will be described. This movable contact is slidably mounted in an aperture 375 formed in the outer end of the contact arm, being insulated therefrom by means of an insulating bushing 376 and washer 377. The bushing and washer are mounted on the contact stem 378 with a flange 380, formed on bushing 376, abutting against the contact block 381. Nuts 382 serve to hold the contact parts in assembled relation and to connect the movable contact in the system. The outer end of the contact arm is arranged between flange 380 and washer 377, being maintained 60 against washer 377 by means of a spring 383 when the movable contact is disengaged from its co-operating stationary contact. With the switch in closed position, the spring 383 serves to press the movable contact into engagement with its corresponding stationary contact.

All the operating levers are pivotally mounted on a shaft 384, supported at one end by a hanger 385 secured to bracket 356 as by a bolt 386, and supported at the other end by the pawl magnet frame, as will be explained later. The contact 5 arm of the pawl first slow-down switch operating lever 372 is enlarged below the movable contact to provide an opening 387, the sides 388 of the opening forming the continuation of the lever. This lever is formed with two other arms 390 and 10 391, these arms extending oppositely from the pivot point of the lever and at right angles to the contact arm to form a walking beam. The opening provided in the contact arm of the lever is continued through the arms 390 and 391 and there 15 enlarged to extend outwardly from each side of the pivot shaft. The sides of arm 390 are joined beyond the opening and the arm is enlarged from this point to its outer end to form a weight 392. Also, the sides of arm 391 are joined beyond the 20 opening by a yoke 393, the arm extending beyond the yoke for a purpose that will be described later. A lug 394 is formed on one of the sides of arm 391, while an oppositely disposed lug 395 is formed on the other side of arm 391. 25

The construction of operating levers 373 and 374 is somewhat modified. However, as levers 373 and 374 are of the same construction, only one of them, namely lever 374, will be described. In addition to the contact arm, this lever is formed 30 with another arm 396. This arm extends outwardly from the pivot point and is enlarged to form a weight 399. A lug 397 depends from the inner end of arm 396 and is threaded to receive an adjustable abutment screw 398. The threaded 35 opening in the lug is positioned so that the abutment screw is disposed in the path of movement of lug 394 on lever 372. In a similar manner, the threaded opening provided in the lug on operating lever 373 is positioned so that its abutment screw is disposed in the path of lug 395 on lever 372. 40 The weighted arm of each operating lever acts as a bias, tending to restore the switch to closed position. The operating lever 372 of the pawl first slow-down switch 360 is provided with an adjustable abutment screw 400 positioned in the contact arm so as to engage with bracket 356 with 45 the switch in closed position.

The bracket 356, as previously explained, also carries the pawl magnet 357, the pawl magnet being secured thereto as by bolts 401 extending through the bracket into the pawl magnet frame 402. The pawl magnet frame comprises a vertical portion 403 and a horizontal portion 404. The vertical portion supports the other end of shaft 384, being provided with an aperture through which the shaft extends. The outer end of horizontal portion 404 is bifurcated to receive the laminated core 405 of the magnet, the core being secured to the horizontal portion as by a pin 406. 50 Depending legs 407 are formed on the horizontal portion 404 on each side of the opening for the core. The core extends downwardly into the pawl magnet coil 400. The coil is secured to the frame by a spool clamp 408, this clamp being secured to the legs 407 as by screws 410. 55 60

The armature 411 of the pawl magnet is also mounted on shaft 384. The inner end of the armature is bifurcated to extend on each side of the vertical portion of the pawl magnet frame. 70 The shaft 384 extends through the bifurcated end of the armature and the armature is secured thereto as by a pin 412. The outer end of the armature is also bifurcated to receive the armature core 413, the core being secured thereto as by a 75

pin 414. The armature core extends upwardly into the pawl magnet coil 100.

Two spaced projections 415 depend from the armature below the pivot point and a projection 416 depends from the vertical portion 403 of the pawl magnet frame. A pin 417 is secured to projection 416 and extends between the projections 415 on the armature. The outer end of this pin is of reduced diameter. Two washers 418 and 420 are arranged on this reduced portion. A spring 421 is provided between these washers, this spring maintaining the outer washer 420 against a cotter pin 422 provided in the outer end of pin 417 and, with the armature in unattracted position, the inner washer 418 against the shoulder formed on pin 417. When the pawl magnet coil is energized, the armature core is pulled upwardly within the coil, moving the armature to attracted position. During this movement, the projections 415 engage washer 418 and cause compression of spring 421. When the pawl magnet coil is deenergized, the unbalanced weight of the armature and spring 421 act to move the armature into unattracted position, the spring 25 acting as a kick-off spring to prevent the retaining of the armature in attracted position by residual magnetism and to give rapid initial movement. A lug 423 formed on the inner end of the armature engages projection 416 during the 30 return of the armature, thus determining the armature's unattracted position.

A lever 424 is positioned on shaft 384 within the opening 387 in operating lever 372 of the pawl first slow-down switch 360. This lever is pinned 35 to the shaft so as to have rotative movement imparted thereto upon movement of the pawl magnet armature. Lever 424 is formed with two spaced upwardly extending arms 425 and 426 and two spaced downwardly extending arms 427 and 428. Apertures 430 are provided in the ends of arms 425 and 426 to receive a shaft 431. Similarly, apertures 432 are provided in the ends of arms 427 and 428 to receive a shaft 433. Shaft 431 has a centrally disposed aperture to slidably receive the inner end of a link 434. Also, shaft 433 has a centrally disposed aperture to slidably receive the inner end of a link 435. The outer end of link 434 is formed with an enlarged portion 436 provided with a slot 437. Similarly, the 50 outer end of link 435 is formed with an enlarged portion 438 provided with a slot 440.

The outer end of arm 390 of operating lever 372 is provided with a slot 441. Aligned apertures are provided in the sides of slot 441 to 55 pivotally receive a shaft 443. The upper end of a pawl 242 extends into the slot 441. The shaft 443 extends through the pawl and is secured thereto as by a cotter pin 444. Thus, the shaft 443 forms a pivotal connection between the pawl 242 and arm 390. The pawl extends downwardly from its pivot point through the slot 440 of link 435 and is pivotally connected thereto as by a shaft 445. Cotter pins 446 are arranged at each 60 end of shaft 445 outside of the link to retain the shaft in position.

The outer end of arm 391 of operating lever 372 is also provided with a slot, designated 447. Aligned apertures are provided in the sides of slot 447 to pivotally receive a shaft 450. The lower end of a pawl 195 extends into the slot 447. The shaft 450 extends through the pawl and is secured thereto as by cotter pin 451. Thus, as 70 in the case of shaft 443, shaft 450 forms a pivotal connection between pawl 195 and arm 391. The

pawl extends upwardly from its pivot point through the slot 437 of link 434 and is pivotally connected thereto as by a shaft 452. Cotter pins 453 are arranged at each end of the shaft outside of the link to retain the shaft in position. 5

A washer 454 is mounted on the inner end of link 434 beyond the shaft 431, the washer being held thereon as by a cotter pin 455. Another washer 456 is arranged on the link 434 on the other side of shaft 431. A compression spring 457 is arranged on the link between the shoulder formed by the enlarged portion 436 and the washer 456. In a similar manner, a washer 458 is arranged on the inner end of link 435 beyond shaft 433 and is held in place as by a cotter pin 16 460. Another washer 461 is arranged on the link 435 on the other side of shaft 433. A compression spring 462 is arranged on the link between the shoulder formed by the enlarged portion 438 and the washer 461. These compression springs act 20 to yieldingly maintain their respective links extended from their shafts to the full extent permitted by the inner washers and cotter pins.

Owing to the fact that both the pawl magnet armature and the lever 424 are pinned to the 25 shaft 384 and the fact that the pawls are connected to the lever 424, the position of the pawl magnet armature determines the positions of the pawls. With the pawl magnet deenergized and the armature in unattracted position, the pawls 30 are in their outermost or extended positions, such as illustrated in Figure 6. Upon the pawl magnet coil being energized, however, and the pawl magnet armature attracted, lever 424 is moved counter-clockwise as viewed in Figure 6, pulling 35 the pawls inwardly about their pivots on the arms of operating lever 372. The pawls, when extended, are arranged to engage collars mounted on standards 314 and 315. The engagement of a collar and pawl causes the operation of the pawl 40 switches, as will be described later, to control the slowing down and stopping of the car. These collars, therefore, will hereinafter be known as stopping collars and are designated 196. There 45 are separate stopping collars for each direction of car travel, those for up car travel being provided on standard 314, while those for down car travel being provided on standard 315. There are four of these collars on each standard, those on standard 314 being for the second, third, fourth and 50 fifth floors, and those on standard 315 being for the first, second, third and fourth floors. The collars are secured to the standards as by set screws 459 so as to be readily adjustable.

In operation, assume that the car has started 55 in the down direction from the fifth floor. The floor controller operating shaft 323, driven by means of the steel tapes in the manner previously described, rotates screws 326 through bevel gears 331 and 328. The crosshead 334, therefore, is 60 driven downwardly by screw 326 in accordance with the movement of the elevator car. As the pawl magnet coil 100 is energized while the car is running, pawl magnet armature 411 is in attracted position and the pawls 195 and 242 are retracted 65 so as not to engage the stopping collars.

Assume now that a third floor button has been 70 pushed. As the car reaches the third floor stopping zone, the pawl magnet coil 100 is deenergized. The operation of effecting the energization and deenergization of the pawl magnet coil will be described later. Pawls 195 and 242 are now forced out into their extended or stop positions by the unbalanced weight of the arm- 75

ture and kick-off spring 421. As the elevator car, and therefore the crosshead, continues its downward movement, the point is reached where pawl 242 engages the down third floor stopping collar 196. This is the position of the parts as illustrated in Figure 6. As the crosshead is driven farther in the down direction, the walking beam, formed by arms 390 and 391 of operating lever 372, is swung clockwise, as viewed in Figure 6, about shaft 384. As this clockwise movement occurs, the upper end of the contact arm of lever 372 moves outwardly away from the stationary contact 362 of the pawl first slow-down switch. Spring 383 expands until the contact arm engages insulating washer 377, whereupon further movement of the contact arm causes the separation of the contacts of the pawl first slow-down switch. Also, as the clockwise movement of the walking beam occurs, lug 395 engages the abutment screw 20 of the operating lever of the pawl second slow-down switch and thereafter the lug 394 engages the abutment screw of the pawl stop switch. Upon the continued movement of the walking beam after the engagement of lug 395 and abutment screw 398 of the pawl second slow-down switch, the operating lever 373 of the pawl second slow-down switch is moved clockwise about shaft 384, causing the separation of the pawl second slow-down switch contacts. Upon continued movement of the walking beam after the engagement of lug 394 and abutment screw 398 of the pawl stop switch, the operating lever of the pawl stop switch is swung clockwise about shaft 384, causing the separation of the pawl stop switch contacts. The adjustment of this mechanism is such that the pawl first slow-down switch contacts, the pawl second slow-down switch contacts and the pawl stop switch contacts separate in the order named. As a result of the separation of these contacts, the car, and therefore the crosshead, is gradually slowed down and finally brought to a stop at the third floor in a manner to be described later.

When the car is running in the up direction and the pawls are moved into their stop positions, the clockwise movement of the walking beam, and therefore the separation of the contacts of the pawl switches, is effected by the engagement of pawl 195 and a stopping collar on standard 314. As pawl 242 is effective for down car travel and pawl 195 for up car travel, pawl 242 may be termed the down pawl while pawl 195 may be termed the up pawl. It will be noted upon reference to Figure 6 that as the walking beam is moved clockwise about shaft 384 due to the continued downward movement of the crosshead with the down pawl in engagement with the down third floor stopping collar, the outer edge of the up pawl engages the up third floor stopping collar. As the clockwise movement of the walking beam continues, the up pawl is swung inwardly about its pivot on the walking beam, the spring 457 yielding to permit the link 434 to slide inwardly in its aperture in shaft 431. Upon the car being brought to rest level with the landing, up pawl 195 is forced under the up third floor stopping collar by spring 457, this being the position of the parts as illustrated in Figure 7. A similar operation takes place when stopping the car in the up direction. As has been seen from previous description, with the pawl magnet deenergized, the position of the pawl magnet armature, and therefore the lever 424, is fixed by the engagement of lug 423 on the armature and projection 416 of the pawl magnet frame. Thus, the lever 424 is restrained

from further clockwise movement. Although the links 434 and 435 may move inwardly with respect to lever 424, their outward movement is restricted by their inner washers 454 and 458. With further clockwise movement of lever 424 prevented, upon clockwise movement of the walking beam of lever 372, the angle between arm 391 of lever 372 and arms 425 and 426 of lever 424, and the angle between arm 390 of lever 372 and arms 427 and 428 of lever 424 are increased. Thus, as the clockwise movement of the walking beam takes place, the pawls are swung inwardly about their pivot shafts on the walking beam. Therefore, should there be excessive movement of the crosshead due to the fact that the car has not been stopped, no injury to the floor controller results because the pawls are finally withdrawn from operative engagement with the stopping collars by the links.

The pawl switches are held in open position until the pawl magnet coil 100 is again energized. When this coil is energized, the pawl magnet armature is attracted, causing counter-clockwise movement of shaft 384 and therefore of lever 424. As a result, the pawls are withdrawn from operative engagement with the stopping collars. The weighted arms of the operating levers of the pawl switches then act to move their respective operating levers into position with the pawl switch contacts in engagement. The pawls are restored to their final retracted positions by the counter-clockwise movement of the walking beam.

Referring now more particularly to Figures 2, 3, 4, and 5, a plurality of bars 462 of insulating material are arranged between standards 312 and 313 to form mountings for the floor controller stationary contacts. Both of these standards are provided with a plurality of adjustable collars 463, the corresponding collars on each standard being arranged in horizontal alignment to support the insulating bars 462. Each of these collars 463 may be of a U-bolt construction, the ends of the U-bolt being threaded to receive the clamping nuts 464. Spacing plates 465 may be arranged between each insulating bar and the standards 312 and 313. The stationary contacts are arranged on the bars 462 in columns. The contacts in column 466 are employed in initiating the stopping of the car in response to the up hall buttons for the intermediate floors and the hall button for the top floor and will therefore be termed up hall stop contacts. The contacts in column 467 are employed in initiating the stopping of the car in response to the down hall buttons for the intermediate floors and the hall button for the bottom floor and will therefore be termed down hall stop contacts. The contacts in column 468 are employed in initiating the stopping of the car in response to car buttons and will therefore be termed car stop contacts. The stationary contacts are L shaped and are secured to the insulating bars 462 as by bolts 470. Additional nuts 469 are provided on one of the bolts for each contact to facilitate the connecting of the contact in the system. Both up and down hall stop contacts and car stop contacts are provided for all intermediate floors. The top floor down hall stop contact and bottom floor up hall stop contact are omitted as, in the system chosen for purposes of description, only one hall button is provided at each of these floors.

The floor controller is provided also with traveling contacts or brushes for engaging the above described stationary contacts. These brushes are mounted on an insulating panel 471, the panel

being secured, as by bolts 472, to brackets 473 formed on crosshead projections 347 and 348. There are six of these brushes, designated 97, 98, 99, 227, 228, and 234. Brushes 97, 98, and 99 are arranged in a horizontal row. Brushes 227, 228, and 234 are below brushes 97, 98, and 99 and are also arranged in a horizontal row. Brushes 97, 98, and 99 cooperate with the stop contacts to initiate the stopping of the car when traveling in the up direction and may therefore be termed up stop brushes. Brushes 227, 228, and 234 cooperate with the stop contacts to initiate the stopping of the car when traveling in the down direction and may therefore be termed down stop brushes. Brushes 99 and 227 are in vertical alignment and are positioned on the insulating panel 471 for cooperation with up hall stop contacts in column 466. Brushes 98 and 228 are also in vertical alignment and are positioned on the insulating panel for cooperation with the car stop contacts in column 468. Also, brushes 97 and 234 are in vertical alignment and are positioned on the insulating panel for cooperation with the down hall stop contacts in column 467. Upon the engagement of brush 99 with a "live" up hall stop contact in column 466, during up car travel, the stopping operation is initiated to bring the car to rest at the floor corresponding to the up hall stop contact engaged. This brush may therefore be termed the up hall stop brush. Upon the engagement of brush 98 with a "live" car stop contact in column 468, during up car travel, the stopping operation is initiated to bring the car to rest at the floor corresponding to the car stop contact engaged. This brush may therefore be termed the up car stop brush. Upon the engagement of brush 228 with a "live" car stop contact in column 468, during down car travel, the stopping operation is initiated to bring the car to rest at the floor corresponding to the car stop contact engaged. This brush may therefore be termed the down car stop brush. Upon engagement of brush 234 with a "live" down hall stop contact in column 467, during down car travel, the stopping operation is initiated to bring the car to rest at the floor corresponding to the down hall stop contact engaged. This brush may therefore be termed the down hall stop brush. Brush 227 is for cooperating with contacts in column 466 to initiate the stopping of the car, under certain operating conditions during down car travel, to bring it to rest at a floor for which an up hall button has been pushed, as will be described later. This brush may therefore be termed the up call down hall stop brush. Brush 97 is for cooperating with contacts in column 467 to initiate the stopping of the car, under certain operating conditions during up car travel, to bring it to rest at a floor for which a down hall button has been pushed, as will be described later. This brush may therefore be termed the down call up hall stop brush. Although employed in the system to be described, brushes 97 and 227 may be omitted for certain types of service. As the brushes are identical in construction, the details of only one of them, namely brush 234, will be described.

Referring particularly to Figures 2 and 3, brush 234 comprises a brush contact piece 474 mounted on the outer end of a contact lever 475. The outer end of this lever is slotted to receive the contact piece, this piece being secured thereto as by pins 476. The contact lever is pivotally mounted on a shaft 477 between the two arms 75 478 of a bracket 480. The bracket 480 is secured

to the panel 471 as by a screw 481 and a stud 482. Both the screw and stud extend through an elongated slot 483 in the panel, this arrangement being provided to permit vertical adjustment of the position of the brush. The stud 482 extends outwardly from the back of the panel and is provided with binding nuts 484 for connecting the brush in the system. The lever 475 is bent inwardly below its pivot point, this inwardly bent portion cooperating with the bottom 10 of the bracket 480 to determine the extended position of the brush. A spring 485 is provided between the bracket and the lever for biasing the brush to its extended position. Upon the engagement of the brush contact piece and a stationary contact, the contact lever is rocked about its pivot shaft, spring 485 yielding to permit this movement. Thus, a positive rubbing contact between the brush contact piece and stationary contact is assured. As the brush contact piece 20 leaves the stationary contact, spring 485 restores the brush to its extended position. Each of the brushes is adjustably mounted in a slot arrangement as described above for brush 234. According to the preferred arrangement, the contact levers of the up stop brushes extend downwardly from their pivot shafts while the contact levers of the down stop brushes extend upwardly from their pivot shafts.

It is to be understood that additional brushes 30 may be provided on panel 471 and additional columns of contacts for cooperating therewith may be provided on insulating bars 462 for controlling other circuits, such as for lights or magnetic door locks, one extra brush designated 486 35 and one extra column of contacts designated 487 being shown by way of illustration. If this extra brush were employed to control magnetic door locks instead of employing the cam operated door lock arrangement chosen for purposes 40 of illustration, the brush would be arranged so as to be in engagement with the contact in column 487 corresponding to the floor at which the car is stopped when the car is at rest level with the floor. The brush is illustrated in this position.

In operation, assume that the car is started downwardly from the fifth floor in response to the down third floor hall button. As the car moves in the down direction, the crosshead, and 50 therefore the brushes 97, 98, 99, 227, 228, and 234, pawl magnet and pawl switches, is moved downwardly in accordance with the movement of the elevator car, as has previously been explained. If the down fourth floor hall button 55 or fourth floor car button has not been pushed, the down fourth floor hall stop contact and the fourth floor car stop contact are "dead", so that as the contact pieces for the down hall stop brush 234 and down car stop brush 228 strike their 60 corresponding stationary contacts on the insulating bar 462 for the fourth floor, the contact levers of these brushes rock on their pivots, permitting the brushes to sweep across the contacts without completing any circuits. Under 65 the conditions assumed, up call down hall stop brush 227 also will sweep across the fourth floor contact in column 467 without completing a circuit. As a result of the down third floor hall button having been pushed, the down third floor 70 hall stop contact in column 467 is "alive". Thus, as the brush contact piece of brush 227 sweeps across this stop contact, a circuit is completed for initiating the slowing down of the elevator car and for causing the deenergization of the 75

pawl magnet coil 100. The position of the stopping collars 196 relative to the position of the stationary stop contacts is such that, for example in the case assumed, pawl 242 is released above the third floor stopping collar on standard 315. As the car continues its movement, the pawl switches are opened in the manner previously described, causing further slowing down of the car and finally causing it to be brought to rest level with the third floor landing. The down stop brushes are carried past their corresponding stationary contacts during the stopping operation so that, with the car at rest at the third floor, the relative position of the stopping brushes and contacts is as illustrated in Figure 3. As the cooperation of the other brushes with their stop contacts to initiate slowing down of the elevator car is the same as that described for the down hall stop brush and third floor down hall stop contact, such operation will not be described.

Up to this point, only that portion of the floor controller which controls the slowing down and stopping of the car has been described. The floor controller is also arranged to determine the direction of car travel, direction switches and a cooperating traveling direction cam being provided for this purpose. The direction switches are mounted on the insulating bars 462, there being one of these switches for each floor. The first floor direction switch is designated 229, the second floor direction switch 218, the third floor direction switch 257, the fourth floor direction switch 83 and the fifth floor direction switch 246. As these switches are identical in construction, only one of them, namely the third floor direction switch 257, will be described.

Referring particularly to Figures 3 and 5, this direction switch comprises a brush contact arm 488 pivotally mounted on a bracket 490. This bracket is secured to the insulating bar 462 as by a stud 491. The upper end of the bracket extends outwardly from the insulating bar and is bifurcated to receive the brush contact arm 488, the pivot shaft 492 for the brush contact arm extending through the sides of the bifurcation. A switch lever 493 is pivotally mounted on the brush contact arm. This arm is formed with a slotted lug to receive the switch lever, the pivot shaft 494 for the switch lever extending through the lugs. The upper end of the switch lever forms a movable contact 495 for cooperation with a stationary contact 496, secured to the insulating bar 462 as by a screw 497. A spring 498 is provided for biasing the switch lever into position with the movable contact and stationary contact in engagement, a lug being formed in the bottom end of the lever and the stud 491 being extended beyond the bracket to form spring seats for the spring. The upper end of the brush contact arm is bent toward the insulating bar 462 from its pivot shaft 492 and is provided with projections 500. These projections cooperate with the bracket 490 to determine the extended position of the brush contact arm. Binding nuts 501 are provided on screw 497 and on stud 491 for connecting the switch in the system.

The direction cam, designated as a whole by the numeral 502, is carried by the crosshead, being mounted on panel 471. The cam is positioned vertically on the panel to engage the brush contact arms of the direction switches. The cam is arranged in three spaced sections, namely, up direction cam section 84, down direction cam section 220, and center direction cam

section 272, as may be seen upon reference to Figures 2 and 3. These sections are secured to the panel as by bolts 503, the upper bolt for up direction cam section 84 and the lower bolt for down direction cam section 220, being provided with binding nuts 504 for connecting the sections in the system. No binding nuts are provided for the bolt securing the center direction cam section, this section not being connected in the system and being insulated from the up and down sections. The inner ends of the up and down cam sections are formed at an angle to the vertical, as shown in Figure 2, and the adjacent edges of the center cam section are angled to correspond. This is done to prevent the brush contact arm of a direction switch dropping into the grooves between the cam sections during movement of the crosshead when the brush contact arm is transferred from one section of the cam to another. A pin 505 is provided for maintaining the proper position of the center cam section 272. The upper end of the up direction cam section and the lower end of the down direction cam section are beveled back toward the panel.

In operation, assume that the elevator car, and therefore the crosshead, is traveling in the down direction and that a point is reached where the initial engagement of the down direction cam section 220 with the brush contact arm 488 of the first floor direction switch 229 occurs. As the downward movement of the crosshead continues, the beveled surface of the down direction cam section swings the brush contact arm clockwise (as viewed in Figure 3) about its pivot shaft. During this movement, switch lever 493 is pushed inwardly, spring 498 acting to maintain the movable contact portion 495 of the switch lever in engagement with the stationary contact 496. Thus, positive rubbing contact engagement between the movable contact portion of the switch lever and the stationary contact is assured until after a firm contact is made between the brush contact arm and the down direction cam section. Upon further clockwise movement of the brush contact arm about its pivot shaft, however, the lower end of the brush contact arm engages the lower end of the switch lever. Thus, as the downward movement of the direction cam continues, the brush contact arm and the switch lever are moved clockwise as a unit against the force of spring 498, causing the separation of the movable contact portion of the lever from the stationary contact. Upon the vertical surface of the down direction cam section moving onto the brush contact arm, the parts of the direction switch assume the relative positions illustrated for the third floor direction switch in Figure 3. Upon the elevator car reaching the first floor, the center direction cam section 272 moves onto the brush contact arm of the first floor direction switch. As this center section is not connected in the system, the first floor direction switch is isolated with the car at rest at the first floor.

Upon upward movement of the crosshead, as the beveled surface of the down direction cam section moves onto the brush contact arm of the first floor direction switch, spring 498 moves the brush contact arm and switch lever counter-clockwise as a unit about the pivot shaft of the brush contact arm until the engagement of the movable contact portion of the switch lever and the stationary contact occurs. From this point on until the down direction cam section disengages the brush contact arm, spring 498 causes continued counter-clockwise movement of the

brush contact arm about its pivot shaft, while maintaining the movable contact portion of the switch lever in engagement with the stationary contact. As a result, a positive rubbing contact engagement between the movable contact portion and the stationary contact is obtained. As the down direction cam section leaves the first floor direction switch, the projections 500 formed on the brush contact arm engage the switch bracket to prevent further movement of the parts of the direction switch. It is to be noted that rubbing contact engagement is had during both opening and closing of the switch. This is of particular importance during the switch opening operation, as it insures positive contact between the movable contact portion of the switch lever and the stationary contact until a firm contact is made between the brush contact arm and the direction cam section. It is also important during the switch closing operation, as a positive engagement of the switch contacts is assured. As the cooperation of the up direction cam section 84 and the direction switches is the same as that described for the down direction cam section, no description thereof will be given.

As may be seen upon reference to Figures 2, 3, and 4, a lug 506 is formed on the bracket for stop brush 97 and a similar lug 507 is formed on the bracket for stop brush 234. These lugs are on the sides of the brackets adjacent the direction cam. A roller 194 of insulating material is pivotally mounted on lug 506, while a roller 241, also of insulating material, is pivotally mounted on lug 507. Roller 194 is directly adjacent up direction cam section 84, while roller 241 is directly adjacent down direction cam section 220. The roller 194 is for lifting the brush contact arms of the direction switches off the up direction cam section during up car travel and will be termed the up insulating roller. Roller 241 is for lifting the brush contact arms of the direction switches off the down direction cam section 220 during down car travel and will be termed the down insulating roller. The up insulating roller is positioned so as to lift the brush contact arm of a direction switch from the up direction cam section at the same time that the up stop brushes engage the stop contacts for the floor corresponding to the direction switch whose brush contact arm is thus affected. Similarly, the down insulating roller 241 is positioned so as to lift the brush contact arm of a direction switch from the down direction cam section at the same time that the down stop brushes engage the stop contacts for the floor corresponding to the direction switch whose brush contact arm is thus affected. Although employed in the system described in connection with Figure 15, these insulating rollers may be omitted for certain types of service.

The over-all length of the direction cam is chosen so as to span three direction switches spaced to conform to the distance between floors of an average installation. The down direction cam section is longer than the up direction cam section, owing to the fact that greater floor heights usually occur at the lower floors. As will be seen from the wiring diagram, the direction switches are connected in series relation with the fifth floor direction switch 246 connected in a circuit for establishing up car travel. The up direction cam section 84 is also connected in a circuit for causing up car travel, while the

down direction cam section 220 is connected in a circuit for establishing down car travel. The manner in which the direction switches and direction cams control the direction of car travel will be described in detail in connection with the wiring diagram of Figure 15. It may be explained briefly, however, that the direction cam causes the direction switches for floors above the floor at which the car is stopped to be in an up circuit and for floors below the floor at which the car is stopped to be in a down circuit, so that, if the car is below the floor at which a button is pushed, the car is caused to start in the up direction, while, if the car is above the floor at which a button is pushed, the car is caused to start in the down direction.

The floor controller is provided also with mechanism for insuring preference being given to car buttons over hall buttons in starting the car. This mechanism comprises a plurality of switches arranged to be operated by a cam. There is one of these switches for each intermediate floor, they being mounted on the intermediate floor insulating bars. These switches will be termed car preference switches, that for the fourth floor being designated 264, that for the third floor being designated 265 and that for the second floor being designated 268. These switches may be of the same construction as the direction switches and are so illustrated. No description of their construction, therefore, will be given.

The operating cam 269 for the car preference switches is carried by the crosshead, being mounted on panel 471 as by screws 499. The cam is positioned on the panel so that, with the car at rest at an intermediate floor, it engages the brush contact arm of the car preference switch for that floor, causing this switch to be open. The cam will hereinafter be referred to as the car preference cam. The function of the car preference switches and cam will be explained in connection with the description of the wiring diagram of Figure 15.

A pair of angle bars 510 and 511 extend from the bottom to the top of the floor controller, being secured to lugs 512 formed on the base plate 311 and to lugs 513 formed on the top plate 316 as by bolts 514. A panel 515 is secured to these angle bars as by bolts 508, spacing sleeves 509 being provided on the bolts to extend the panel out from the floor controller. Flexible conductors (not shown) connect the various electrical parts carried by the crosshead to binding posts (also not shown) on panel 515. These flexible conductors are suspended in very much the same manner that flexible cables are suspended from the elevator car.

It is believed that it will be seen from the previous description that the floor controller is essentially a model of the elevator car and hatchway. The floor levels are represented by the insulating bars 462 mounted on standards 312 and 313. The elevator car is represented by the crosshead, this crosshead, as previously explained, traveling on the vertical screw 326 driven by the car through the medium of a tape drive. Upon a button being pushed, the direction cam and direction switches determine the direction of car travel. As a result of the pushing of a button, the pawl magnet coil becomes energized, causing the disengagement of the pawls from the stopping collars. The pawl switches are thus closed, causing the circuits to be completed to effect the starting of the car. Assuming up car travel, as the car passes a floor, the direction cam transfers

the direction switch for that floor from an up to a down circuit. Upon the engagement of an up stop brush and a "live" stop contact, the slowing down of the car is initiated. At the same time, the pawl magnet is demagnetized, releasing the pawls. Upon continued upward movement of the crosshead, the up pawl catches on an up stop collar, resulting in the consecutive opening of the pawl switches to bring the car to a stop at the 10 floor. It is to be noted that the threaded portion of the vertical screw 326 does not extend the full height of the controller. This threaded portion is terminated at the top at such point as to permit the crosshead to run off the screw before the top 15 is reached, thus eliminating the possibility of the crosshead running into the top plate. Similarly, the threaded portion is terminated at the bottom at such point as to permit the crosshead to run off the screw before the bottom is reached, thus 20 preventing the crosshead being driven into the bevel gear 328. A bumper collar 479 and a cushioning washer 489 of leather or other suitable material are arranged on the shaft 326 above gear 328. Thus, in the event that the crosshead runs 25 off the bottom of the screw, it strikes the bumper collar, the cushioning washer acting to take up any shock.

The adjusting of the various parts of the floor controller is the same for each floor and therefore adjustment for only one floor will be described. The elevator car is brought to a level with the floor landing for which adjustment is to be made. This will place the crosshead in the position which it assumes when the car is level 35 with this floor. The insulating bar is then adjusted on the standards, by means of the U-bolt collars, so that the contacting surface of the brush contact arm of the direction switch for that floor is on the center of the insulated center 40 direction cam section 272. The stop brushes are then adjusted in their slots 483 so as to be such distance from the stop contacts for that floor that the desired slow-down range is obtained. The distance from the landing at which the slowing 45 down is initiated depends upon the speed of the car for any given installation. With the pawl magnet demagnetized and the pawls extended, the down stopping collar for that floor is moved upwardly on the standard until it just engages the down pawl. This stopping collar is then moved upwardly an amount to give a further slowing down and stopping range to suit the requirements of the particular installation. Owing to the engagement of this collar with the down 50 pawl, this upward movement causes the tilting of the pawl switch levers and the downward movement of the up pawl. With the parts in this position, the up stopping collar is moved downwardly until it engages the up pawl. With 55 all the floors adjusted, the pawl switches may be set to open at the desired points by adjusting the abutment screws 398 and 400 and the position of the stationary contacts.

To simplify the description, a system is chosen 60 wherein only two pawl switches are employed, namely, the pawl first slow-down switch 360 and the pawl stop switch 358. As only one pawl slow-down switch is employed, this switch will be termed the pawl slow-down switch in the description 65 of the system and its contacts will be designated 137. The pawl stop switch contacts will be designated 136. For convenience of illustration, the brush contact arm and switch lever of each direction switch will be shown as a single 70 member, designated 82 and termed a switch arm.

Reference may now be had to Figures 11 and 12 which illustrate the details of the preferred form of floor switch. The floor switches are identical in construction, one being provided for each push button. For certain types of service, these 5 switches may be mounted on floor controller panel 515, particularly where there are only a small number of floors. Otherwise, these switches are mounted on a separate panel. It will be assumed that a separate panel is employed and this panel 10 will be termed control panel No. 2 and designated 516 (see Figure 13). Parts of the switch are shown in section and parts are omitted in Figure 12 in order that the construction of the switch 15 may be more readily seen.

The switch comprises two pairs of contacts, 72, 73 and 74, 75, the characters 72 and 74 designating the stationary contacts and the characters 73 and 75 designating the movable contacts. Contacts 72, 73 are for controlling the stopping 20 of the car and will be termed stop contacts while contacts 74, 75 are for controlling the starting and running of the car and will be termed start contacts. The stationary contacts are of the same construction, each comprising a contact 25 piece 517 secured in a contact holder 518. The stem 520 of the contact holder extends through the panel and at the rear thereof is provided with nuts 521 for securing the holder to the panel and for connecting the contact in the system. The 30 movable contacts also are of the same construction and only one of them, namely, contact 73, will be described. A bracket 522 is secured to the panel, as by a bolt 523. This bracket has two outwardly extending sides 524 between which a 35 contact arm 525 is mounted. The lower end of the contact arm is bent to conform to a pivot pin 526 extending through the sides of the bracket. An aperture 527 is provided in the bracket through which a pin 528 extends, the panel 516 40 being provided with a recess 530 to receive the head of the pin. This pin extends through an aperture 531 in the contact arm and is provided with a cotter pin 532 on its outer end to limit the outward movement of the arm about its 45 pivot. Above the pin 528, the contact arm is formed with an inclined portion 533. Above the inclined portion, the contact arm terminates in a hook 534. This hook consists of a vertical portion 535 and a horizontal portion 536, the 50 width of the horizontal portion being considerably reduced. A contact blade 537 also is mounted on pin 528, being provided with an aperture 538 through which the pin extends. The contact blade is also provided with a slot 539 through 55 which the horizontal portion 536 of the contact arm extends. The contact piece of stationary contact 72 is disposed in the path of movement of the contact blade 537. A spring 540 is arranged on pin 528 for biasing the contact blade 60 to disengaged position. The nuts 541 for bolt 523 at the rear of the panel also serve for connecting the movable contact in the system.

A pair of rollers 542 are provided for moving the movable contacts to engaged position. These 65 rollers are arranged on the inner end of armature 543 for cooperation with the contact arms 525. The armature 543 is channel shaped and the roller pin 544 for the rollers extends through the legs 545 of the channel. The armature is fulcrumed on a stand 546 as by means of a bolt 547 extending through the channel legs, the web 548 of the channel being provided with a slightly elongated opening 550 through which the stand 70 extends. The stand is supported by the magnet 75

frame 551 secured to panel 516, as by bolts 552. This frame extends outwardly from the panel and, in addition to supporting the stand 546, supports magnet cores 553 and 554, one on each side of the stand. The outer core 553 is provided with a magnet coil 70 while the inner core 554 is provided with a magnet coil 190. Coil 70 is for causing the engagement of the contacts and will be termed the closing coil. Coil 190 is for causing the disengagement of the contacts and will be termed the reset coil. The outer end of the armature 548 is provided with a weight 555 arranged between the legs and secured thereto as by pins 556, preferably of non-magnetic material. An opening 557 is formed in the outer end of the armature through the web 548. This opening extends into a recess 558 formed in the weight 555, this opening being such as to expose a portion of one of the non-magnetic pins. This arrangement is provided to permit core 553 to extend upwardly into the armature when the armature is in switch closed position. Similarly, the inner end of the armature is provided with an opening 560 to permit core 554 to extend upwardly into the armature when the armature is in reset position. A pin 561 of non-magnetic material extends between armature legs 545 above the opening 560.

In operation, it will be assumed that the various parts of the switch are in the positions illustrated. Upon the pushing of the button for which the floor switch is provided, closing coil 70 is energized. As a result, the outer end of the armature is attracted and the armature is rocked clockwise about its fulcrum. During this movement, rollers 542 roll up the inclined portions 533 of their respective contact arms, causing counter-clockwise movement of these arms about their pivots, the weight 555 assisting in causing this movement. The contact blades 537 are carried with the contact arms, springs 540 yielding to permit the movement. As a result, the contact blades are moved into engagement with the contact pieces of the stationary contacts. As the counter-clockwise movement of the contact arms continues, the contact blades are slidably pivoted thereon against the force of springs 540, resulting in positive rubbing contact engagement. As the rollers roll onto the vertical portions 535 of the contact arms, the armature is brought to a stop by the engagement of the exposed pin 556 with the top of core 553. As the parts are constructed and arranged so that the armature is brought to a stop on or beyond the dead center point of the contact arms with respect to the pivot point of the armature, the contacts are latched in engagement. Thus, upon the closing coil 70 being deenergized as a result of the pressure on the push button being released, the contacts remain in engagement.

Upon the reset coil 190 being energized, the inner end of the armature is attracted and the armature is rocked counter-clockwise about its fulcrum. The exposed pin 556, being of non-magnetic material, prevents the armature being held in switch closed position due to residual magnetism. During this movement, springs 540 act to cause the separation of the contact blades from the contact pieces of the stationary contacts. These springs also assist in restoring the armature to reset position. The contact blades are brought to rest by the engagement of the contact arms with the cotter pins 532 while the armature is brought to rest by the engagement of pin 75 561 with the top of core 554. This pin, being of

non-magnetic material, prevents the armature being held in reset position by the effect of residual magnetism when attracted by the closing coil 70.

Referring to Figure 13, the floor switches are arranged on the panel 516 in groups according to floors. There are three of these switches for each intermediate floor group, there being an up hall button, a down hall button and a car button provided for each intermediate floor. There is also a car button for each terminal floor. As previously explained, however, there is only one hall button for each terminal floor. Thus, there are only two floor switches in each of the terminal floor groups. These switches have been characterized generally in accordance with the floor and push button which they represent. For example, 2C indicates that the switch is for the second floor and is controlled by the car button for that floor, 3U indicates that the switch is for the third floor and is controlled by the up hall button for that floor, and 4D indicates that the switch is for the fourth floor and is controlled by the down hall button for that floor. Inasmuch as an intending passenger pushing the fifth or top floor hall button would desire to be carried in the down direction, the hall button fifth floor switch has been characterized 5D. Similarly, as an intending passenger pushing the first or bottom floor hall button would desire to be carried in the up direction, the hall button first floor switch has been characterized 1U.

Service switches 51, 52 and 111 also may be mounted on panel 516. Service switch 51 is for transferring four circuits and has been illustrated as a four pole, double throw knife switch. Service switch 52 is for transferring one circuit and has been illustrated as a single pole, double throw knife switch. Service switch 111 is for closing a circuit and has been illustrated as a single pole, single throw knife switch. These switches may be manipulated to obtain various types of service as will be explained later.

Control panel No. 1 with its various control switches is illustrated in Figure 14. The electromagnetic switches provided on this panel have been designated as follows:

A—potential switch,	50
B—up reversing switch,	
C—down reversing switch,	
D—up auxiliary reversing switch,	
E—down auxiliary reversing switch,	
F—up direction relay,	
G—down direction relay,	
H—accelerating switch,	
J—fast speed switch,	55
K—automatic non-stop relay,	
L—first slow-down switch,	
M—second slow-down switch,	
N—third slow-down switch,	
O—door and gate time relay,	60
P—car preference time relay,	
R—auxiliary car preference time relay,	
S—stop switch,	
T—field switch,	
U—auxiliary field switch,	65
V—home station relay.	

Throughout the description which follows, these letters, in addition to the usual reference numerals, will be applied to the parts of the above enumerated switches. For example, contacts B147 70 are contacts on the up reversing switch while actuating coil A146 is the coil that operates the potential switch. The reactance coils employed will be similarly designated by the letter X. The characterizations employed for the floor 75

switches are also employed in the wiring diagram in order that the parts of the various floor switches may be readily distinguished.

Reference may now be had to Figure 15 which illustrates diagrammatically the various control and power circuits. No attempt is made in this figure to show the coils and contacts of the switches in their associated positions, a "straight" diagram being employed wherein the coils and contacts of the various switches and parts of other electrical apparatus are separated in such a manner as to render the circuits involved relatively simple. For a clearer understanding of the invention, the stationary contacts of the switches are illustrated in cross section. The relation of the coils and their contacts may be seen upon reference to Figure 14.

The hoisting motor is illustrated as of the direct current type, supplied with power from a direct current source and provided with resistances for controlling its acceleration and retardation. It is to be understood, however, that other types of hoisting motors and other arrangements for controlling acceleration and retardation may be employed, that illustrated being chosen for convenience of description. The direct current supply mains are indicated by the numerals 21 and 22, main 21 being positive and main 22 being negative. The hoisting motor is designated as a whole by the numeral 23, its armature being designated 24, its separately excited field winding being designated 25, its series field winding being designated 26 and its interpole field winding being designated 27. Discharge resistance 28 is provided for the separately excited field winding. Resistance 30 is provided for controlling the voltage applied to the separately excited field winding. Both a minimum starting resistance and a maximum starting resistance are provided for the motor. The minimum starting resistance is designated 31. The maximum starting resistance is divided into sections designated 32, 33, and 34. A slow-down resistance is arranged in shunt to the motor armature, this resistance being divided into sections 35, 36, 37, and 38. A stop resistance is also arranged in shunt to the motor armature, this resistance being designated 40. The release coil for the electromagnetic brake is designated 41. Coil 41 is provided with a discharge resistance 42 and with a cooling resistance 43. The armature of the door lock cam motor 44 is designated by the numeral 45, the field winding being designated 46. The safety switch in the car is designated 47. It is preferred to provide the car with a platform switch having three pairs of contacts (see Figure 1), one of these pairs of contacts being designated 29, another pair being designated 39 and the remaining pair being designated 48. The platform may also be arranged to operate a weighing switch 178. The platform is arranged to be biased to position with the weighing switch open and with platform switch contacts 29, 39, and 48 in engagement, springs 289 being shown for this purpose for convenience of illustration. Various safety, emergency, limit, terminal stopping and other switches and apparatus may be employed, such devices being omitted to simplify the description. Other switches and apparatus and the contacts controlled by the doors and gate will be referred to later.

The direction indicator is provided with two lamps, one for indicating up car travel and the other for indicating down car travel. The up direction indicating lamp is designated 49 while

the down direction indicating lamp is designated 50. The direction indicator will be described later.

Assume that the car is stopped at the third floor as illustrated by the position of the floor controller parts, that the third floor well door is closed, that the car gate is open and that service switches 51 and 52 are closed in positions "a". It is to be noted that the four blades 214, 254, 261 and 262 of service switch 51 are shown separated, this being done to suit the type of diagram employed. The four blades of switch 51 and switch 52 are illustrated as closed in positions "a" in this figure. It is preferred to provide each well door with two pairs of contacts, one pair to be closed when the door is closed but the other pair to be closed only when the door is closed and locked. In order to distinguish these contacts, those which are closed when their respective doors are closed will be termed door contacts while those which are closed only when their respective doors are closed and locked will be termed door lock contacts. The door contacts are represented in the diagram by a single set of contacts, designated by the numeral 53. Similarly, the door lock contacts are indicated by a single set of contacts, designated 54. Due to the fact that the door lock cam motor 44 is not energized, the third floor well door is not locked and therefore the third floor door lock contacts are separated. Contacts 54 may therefore be represented as separated. Owing to the fact that the third floor well door is closed, however, the third floor door contacts, as well as the door contacts for the well doors at the other floors, are in engagement. Contacts 53 may therefore be represented as in engagement.

It is to be noted that contacts 53 are in the circuit for the actuating coil R55 of auxiliary car preference time relay. Under the above assumed conditions, the circuit for coil R55 is completed, this circuit being traced from positive main 21, line 56, line 57, by way of line 58 through door contacts 53 and contacts 060 of the door and gate time relay, by way of line 59 through coil R55, by way of line 61 through movable platform switch contacts 48 by-passing contacts 62 controlled by the gate, the gate contacts being separated owing to the gate being open and platform switch contacts 48 being in engagement when the car is empty, line 63, to the negative main 22. As relay R is in operated condition, its contacts R64 are separated, these contacts being in the circuit for the car preference time relay actuating coil P65. It will be assumed that the car preference time relay contacts P67 and P69 are in engagement. In the wiring diagram, the switches above referred to have been illustrated in accordance with the conditions assumed. It is to be noted that platform switch contacts 39 are arranged in parallel with contacts P67 and that platform switch contacts 29 are arranged in parallel with contacts P69, contacts 29 and 39 being in engagement when the car is empty. With either contacts P67 and P69 or platform switch contacts 29 and 39 in engagement and with door contacts 53 and door and gate time relay contacts in engagement, the car may be started in response to the pushing of a hall button, as will be seen from later description.

Assume now that an intending passenger at the third floor desires to use the car. Owing to the fact that the third floor well door is unlocked, this intended passenger may open the door preparatory to entering the car. Upon the

door being opened, its door contacts are separated. With door contacts 53 separated, the car can not be started in response to the pushing of a hall button. Thus, with no other buttons pushed, an 5 intending passenger, upon opening the well door, is given preference as to the starting of the car and therefore as to its direction of travel. This will be better understood as the description proceeds. Also, the separation of door contacts 53 10 breaks the circuit for the actuating coil R55 of the auxiliary car preference time relay. This relay, therefore, drops out immediately, its contacts R64 engaging to complete the circuit for coil P65 of the car preference time relay. This 15 circuit may be traced from positive main 21, line 56, line 57, by way of line 66 through contacts R64 and coil P65, line 61, line 63, to the negative main 22. Relay P operates immediately, causing the separation of its contacts P67 and P69.

20 Upon the passenger entering the car, the platform switch contacts 29, 39, and 48 are separated owing to the passengers' weight. Weighing switch 178 does not close unless there is full load in the car. The purpose of this switch 25 will be explained in the latter part of the description. Each well door is preferably arranged to close automatically, as by a spring. Thus, upon the passenger releasing the third floor well door, the door closes and the door contacts controlled thereby are restored to their engaged 30 condition. However, even with door contacts 53 in engagement, preference is maintained for the passenger as regards starting the car owing to the fact that platform switch contacts 29 and 39 35 and contacts P67 and P69 are separated. In order that certain circuits may be made to effect the starting of the car when there is a passenger in the car, the gate must be closed to cause the engagement of the gate contacts 62 to by-pass 40 platform switch contacts 48 which are separated. Upon the engagement of both door contacts 53 and of gate contacts 62, the circuit for auxiliary car preference time relay actuating coil R55 is again completed, the relay operating to break 45 the circuit for car preference time relay actuating coil P65. Relay P does not drop out immediately, however, its operation being delayed by the action of a suitable form of timing arrangement such as a dash-pot, as illustrated in Figure 14.

50 As the car may be started in response to the pushing of a hall button once contacts P67 and P69 of relay P engage, the timing arrangement for this relay is adjusted to insure an interval of time between the time that the door contacts 55 53 and gate contacts 62 close and the time that contacts P67 and P69 engage which is sufficient to permit the passenger in the car to push the car button for his desired destination. Thus, in the event that the passenger does not push the 60 car button for his destination before closing the door and gate are closed to push this button.

65 It will be assumed that the passenger desires to be carried to the fourth floor and presses the 70 fourth floor car button 68. The pushing of this button completes the circuit for the car button fourth floor switch closing coil 70. The circuit for this coil may be traced from the positive main 21, line 56, by way of line 71 through push button 75 ton 68 and coil 70, line 63, to the negative main 22. The floor switch operates to cause the engagement of its stop contacts 72, 73 and of its start contacts 74, 75. The stop contacts 72, 73 complete a circuit from the positive main 21, 76 line 61 through reset coil 190 of the fourth floor car but-

ton switch (4C) to the floor controller fourth floor car stop contact 76, rendering this contact "alive". In order to avoid confusion, the reference characters 74, 75 for the start contacts of all the floor switches are placed at the top of the 5 columns formed by these contacts. Thus, the start contacts which are in engagement may be determined by the designating characterizations employed for the floor switches. In the example assumed, the car button fourth floor switch has 10 operated. Thus, the start contacts engaged are opposite the characterization 4C for this floor switch. The start contacts 74, 75 of this switch complete a circuit for the actuating coil of one of the direction relays. 15

The direction relay whose actuating coil is energized is determined by the direction cam and direction switches. It is to be noted that all of the direction switches are connected in line 245 in series relation with direction switch 246 for 20 the fifth floor connected to the actuating coil F17 of the up direction relay. As previously explained, the direction cam is arranged to span three of the direction switches. With the car at rest at a floor, the switch arm 82 of the direction 25 switch for that floor rests on the insulated center direction cam section 272, while the switch arm of the direction switch for the floor above is in engagement with the up direction cam section 84 and the switch arm of the direction 30 switch for the floor below is in engagement with the down direction cam section 220. Thus, as the down direction cam section is connected to the actuating coil G96 of the down direction relay and as the up direction cam section 84 is 35 connected to the actuating coil F17 of the up direction relay, the direction switch arm in engagement with cam section 220 and all direction switches for floors below are connected to coil 40 G96 while the direction switch arm in engagement with cam section 84 is connected to coil F17. The direction switches for floors above that corresponding to the direction switch whose switch arm engages cam section 84 are connected to coil F17 through the fifth floor direction switch 45 246. The direction switch for the floor at which the car is positioned being open, owing to the engagement of its switch arm with the center direction cam section 272, and this cam section being disconnected from the other sections prevents the connection of direction switches for floors above this floor with coil G96 and for floors below this floor with coil F17 by way of line 245. 50

With the car at the third floor, the switch arm of the third floor direction switch is in engagement with the insulated center direction cam section 272, the switch arm of the second floor direction switch is in engagement with down direction cam section 220, while the switch arm of the fourth floor direction switch is in engagement with the up direction cam section 84. As the start contacts 74, 75 of the fourth floor car button switch are in circuit with the switch arm of the fourth floor direction switch, the circuit established by these contacts is for the actuating coil F17 of the up direction relay. 60

This circuit may be traced from the positive main 21, line 56, line 57, line 78, line 80, by way of line 81 through contacts 74, 75 (4C), switch arm 82 of floor controller fourth floor direction 70 switch 83, floor controller up direction cam section 84, line 85, by way of line 86 through coil F17, contacts G87 of the down direction relay and contacts C88 of the down reversing switch, line 61, line 63, to the negative main 22. It is to be 75

noted that this circuit is not controlled by door contacts 53, door and gate time relay contacts O60, platform switch contacts 29 and 39 or car preference time relay contacts P67 and P69. The circuit for the up direction indicating lamp 49 is also completed by the engagement of contacts 74, 75, this lamp being connected in parallel with coil F17. This lamp, therefore, lights, indicating that the car is to travel in the up direction, as will be explained later.

The up direction relay, upon operation, causes the separation of contacts F90 and F91 and the engagement of contacts F92, F93, F94, and F95. Contacts F90 are in the circuit for the actuating coil G96 of the down direction relay and down direction indicating lamp 50. Thus, with contacts F90 separated, this coil and lamp cannot be energized. The separation of contacts F91 disconnects the down call up hall stop brush 97 from the up car stop brush 98. The purpose of this arrangement will be seen as the description proceeds. The engagement of contacts F93 prepares a circuit for the coil 100 of the pawl magnet and actuating coil U101 of the auxiliary field switch. The engagement of contacts F94 prepares a circuit for the actuating coil B102 of the up reversing switch and the actuating coil D103 of the up auxiliary reversing switch. The purpose of contacts F92 will be explained later. The engagement of contacts F95 completes a circuit for the closing coil S104 of the stop switch and the actuating coil V107 of the home station relay. This circuit may be traced from the positive main 21, line 56, by way of line 57 through safety switch 47, line 105, contacts F95, by way of line 106 through coil V107, coil S104 and contacts O108 of the door and gate time relay, by way of line 61, through gate contacts 62, line 63, to the negative main 22.

The operation of the home station relay causes the engagement of its contacts V110. It will be assumed, however, that service switch 111 is open. The engagement of contacts V110, therefore, completes no circuit. The purpose of service switch 111 and the home station relay V will be explained later. The stop switch S is of the same construction as a floor switch, described in connection with Figures 11 and 12. In order to avoid confusion, however, the coils and contacts of the stop switch are given different reference characters. The closing coil of the stop switch has already been designated S104. The reset coil of the stop switch is designated S112, while the pairs of contacts of this switch are designated S113 and S114, respectively. Contacts S113 and contacts S114 are closed and latched in response to the energization of closing coil S104, contacts S114 further preparing the circuit for the coil 100 of the pawl magnet and the coil U101 of the auxiliary field switch and contacts S113 completing the circuit for the door and gate time relay actuating coil O115 and the potential switch actuating coil A116. This circuit may be traced from the positive main 21, line 56, by way of line 57 through safety switch 47, line 105, contacts F95, line 106, by way of line 117 through contacts S113, by way of line 118 through coil O115 and also back to line 105 and by way of this line through coil A116 in parallel with line 118 and coil O115, by way of line 61 through gate contacts 62, line 63, to the negative main 22.

The door and gate time relay O, upon operation, causes the separation of contacts O108 and of contacts O60. Contacts O108, upon separation, break the circuit for the closing coil S104

of the stop switch and actuating coil V107 of the home station relay. The home station relay drops out immediately. However, as the stop switch is latched in its operated position, its contacts remain in engagement. The separation of contacts O60 breaks the circuit for the actuating coil R55 of the auxiliary car preference time relay. As a result, relay R drops out, re-establishing the circuit for coil P65 of the car preference time relay which immediately operates from the position to which it has moved to its energized position. Thus, under the assumption that the car button is pushed before the end of the time interval, relay P returns from the position to which it has moved back to the position where its contacts P67 and P69 are fully separated. Thus, contacts P67 and P69 remain separated.

The potential switch A, upon operation, causes the separation of contacts A121 and the engagement of contacts A122, A123, A124, A125, and A183. The purpose of contacts A183 will be explained later. The separation of contacts A121 breaks the circuit including discharge resistance 28 in shunt to the separately excited field winding. The engagement of contacts A122 and of A123 prepares the circuit for the armature of the hoisting motor 23. The engagement of contacts A124 still further prepares the circuit for coil 100 of the pawl magnet and actuating coil U101 of the auxiliary field switch. The engagement of contacts A125 completes the circuit for the door lock cam motor 44. This circuit may be traced from positive main 21, line 56, by way of line 57 through safety switch 47, by way of line 126 through contacts A125, armature 45 and series field winding 46 of the door lock cam motor, by way of line 61 through gate contacts 62, line 63, to the negative main 22.

Referring briefly to Figure 1, the door lock cam motor 44 operates through linkage 127 to withdraw the retiring cam 128 from engagement with roller 130 on the door lock lever 131 of the third floor well door interlock. The door lock lever then acts to cause the locking of the third floor well door and the engagement of the door lock contacts for the third floor well door. As illustrated, a door lock lever and door lock contacts are provided for each floor, each lever being pivotally mounted on its respective door. It is to be understood that the illustration of the interlocks is purely schematic, the door locking mechanism for each door not being shown. It is preferred that the locking mechanism and contacts be arranged in such manner that the door must be locked prior to the engagement of the door lock contacts.

Referring back to Figure 15, the contacts 54, representing all the door lock contacts in series relation as previously explained, are now closed, completing the circuit for the pawl magnet coil 100 and the actuating coil U101 of the auxiliary field switch. This circuit may be traced from positive main 21, line 56, by way of line 57 through safety switch 47, by way of line 132 through door lock contacts 54, contacts A124, pawl magnet coil 100 and coil U101 in parallel and contacts S114, by way of line 133 through contacts F93, by way of line 61 through gate contacts 62, line 63, to the negative main 22.

Auxiliary field switch U, upon operation, causes the engagement of its contacts U134 to prepare the circuit for field switch actuating coil T135. The pawl magnet, upon the energization of its coil 100, retracts its pawls 195 and 242, permit-

ting contacts 137 of the pawl slow-down switch and contacts 136 of the pawl stop switch to close. Pawl slow-down switch contacts 137 are in the circuit for the actuating coil J138 of the fast speed switch. Pawl stop switch contacts 136, upon engagement, complete the circuit for the actuating coil D103 of the up auxiliary reversing switch and actuating coil B102 of the up reversing switch. The circuit for coils D103 and B102 may be traced from positive main 21, line 56, by way of line 57 through safety switch 41, by way of line 132 through door lock contacts 54 and contacts A124, by way of line 140 through pawl stop switch contacts 136, contacts F94, by way of line 141 through coils D103 and B102, by way of line 86 through contacts C88, line 61, line 63, to the negative main 22.

The up auxiliary reversing switch D, upon operation, causes the separation of contacts D180 and the engagement of contacts D142, D143, and D144. The purpose of contacts D180 will be explained later. The engagement of contacts D142 connects up hall stop brush 99 and up car stop brush 98 through reset coil S112 of the stop switch to the negative main, rendering these brushes "alive". The engagement of contacts D143 completes a holding circuit around contacts F95 for the door and gate time relay actuating coil O115 and the potential switch actuating coil A116. The engagement of contacts D144 completes a holding circuit around contacts F94 for the coils D103 and B102.

The up reversing switch B, operating simultaneously with up auxiliary reversing switch D, causes the separation of its contacts B145 and B146 and the engagement of its contacts B147, B148, B150, and B151. Contacts B145 are in the circuit for the actuating coils E152 and C153 for the down auxiliary reversing switch and down reversing switch, respectively. Thus, with contacts B145 separated these coils can not be energized and, therefore, the operation of the down auxiliary reversing switch and the down reversing switch is prevented. It is to be noted that contacts B145 are also in the circuit for coil G96 and lamp 50, thus preventing the energization of this coil and lamp even though the circuit should be otherwise complete. The separation of contacts B146 disconnects the stopping resistance 40 from across the motor armature. Contacts B147 and B148, upon engagement, complete the circuits for the motor armature 24 and the separately excited field winding 25. The circuit for the motor armature may be traced from positive main 21, through contacts A122, by way of line 154 through contacts B147 and contacts C155 of the down reversing switch, by way of line 156 through current reactance coil X157, armature 24 and interpole field winding 27, by way of line 158 through contacts B148 back to line 154, to the right in line 154 through minimum starting resistance 31, sections 32, 33, and 34 of the maximum starting resistance and series field winding 26, through contacts A123, to the negative main 22. The circuit for the separately excited field winding may be traced from positive main 21, through contacts A122, by way of line 154 through contacts B147, through portion 160 of stop resistance 40, line 161, by way of line 159 through contacts T185 of the field switch and field winding 25, back to line 161, through contacts A123, to the negative main 22. Contacts B150 will be referred to later. Contacts B151 complete the circuit for the brake release coil 41. This circuit may be traced from

positive main 21, through contacts A122, by way of line 154 through contacts B147, through portion 160 of stop resistance 40, by way of line 161 through contacts B151, brake contacts 162 and brake release coil 41, through contacts A123, 5 to the negative main 22.

The brake being released as a result of the energization of its release coil 41, current being supplied from the mains to the armature of the hoisting motor and the motor field windings being energized, the motor starts in a direction to cause upward movement of the car. As the brake releases, the brake contacts 162 separate, inserting cooling resistance 43 in series with the brake release coil. 15

Contacts B150, along with contacts B147, complete the circuit for the actuating coil J138 of the fast speed switch. This circuit may be traced from positive main 21, through contacts A122, by way of line 154 through contacts B147, 20 by way of line 163 through contacts B150, line 164, by way of line 165 through coil J138 and pawl slow-down switch contacts 137, through contacts A123, to the negative main 22. The fast speed switch, upon operation, causes the separation of contacts J166 and the engagement of contacts J167, J168, and J170. Contacts J166, upon separation, disconnect the slow-down resistance from across the motor armature. Owing to the time constant of the brake, the inertia of the hoisting motor and the fact that contacts J166 separate at substantially the same time that reversing switch contacts B147 and B148 engage, the slow-down resistance is disconnected from across the motor armature before 35 the motor starts. It is to be noted that the separation of contacts J166 also breaks the circuit for the actuating coils of the slow-down switches, these coils being arranged for connection across the motor armature. Contacts J167, 40 upon engagement, complete the circuit for the actuating coil T135 of the field switch, connecting this coil across the armature of the hoisting motor. This circuit may be traced from the upper brush of the motor armature, by way of line 45 156 upwardly through current reactance coil X157, line 154 to the right, by way of line 169 through contacts U134, coil T135 and contacts J167, line 158 to the left back to line 156, by way of line 156 through interpole field winding 50 27, to the lower armature brush. The operation of switch T will be described later. Contacts J168, upon engagement, complete the circuit for the actuating coil H171 of the accelerating switch, connecting this coil across the armature 55 of the hoisting motor. This circuit may be traced from the upper brush of the motor armature, by way of line 156 upwardly through current reactance coil X157, by way of line 154 to the left through contacts C155, by way of line 163 through contacts B150, contacts J168 and coil H171 to a point on minimum starting resistance 31, through portion 172 of minimum starting resistance 31 and line 154 to the left, by way of line 158 through contacts B148 back 60 to line 156, by way of line 156 through interpole field winding 27, to the lower armature brush. Contacts J170, upon operation, short-circuit minimum starting resistance 31 through contacts H173 of the accelerating switch. As a 70 result, the voltage applied to the hoisting motor armature is increased, causing an increase in the motor's speed.

The actuating coil H171 of the accelerating switch, being connected across the armature of 75

the hoisting motor, is subject to the motor's counter-E. M. F. This switch is provided with a plurality of pairs of contacts arranged to engage in sequence as the motor counter-E. M. F. increases. Thus, as the motor speed rises and its counter-E. M. F. increases, contacts H174 engage to short-circuit section 32 of the maximum starting resistance, further decreasing the amount of resistance in circuit with the motor armature.

10 As a result, the voltage applied to the motor armature is again increased, increasing the speed of the motor. In a similar manner, contacts H175 and thereafter H176 engage as the counter-E. M. F. of the motor rises, short-circuiting sections 33 and 34, respectively, of the maximum starting resistance to increase the voltage applied to the motor armature, resulting in further increase of the motor speed.

Upon still further rise of the counter-E. M. F. 20 of the motor, contacts H177 engage to short-circuit the series field winding 26. Immediately after the engagement of contacts H177, contacts H173 separate. Contacts H173 and the connections thereto are employed to eliminate any possibility of runaway conditions as a result of poor contact at contacts H177 or other conditions which would permit substantially full motor current to flow through the series field winding at a time when this winding should be short-circuited.

25 Thus, for example, were the movable contact of contacts J170 connected directly to line 158, and the movable contacts of contacts H176 and H177 connected together and contacts H173 and its connections eliminated, should contacts H177 30 not engage or should they make poor contact, full motor current or a large portion thereof would flow through the series field winding with the result that the motor field might be so weakened, during the period that the motor was regenerating, that runaway conditions might result. With 35 the connections as shown, however, any faulty engagement of contacts H177 would not result in a runaway condition owing to the fact that under such conditions, with contacts H173 separated, 40 the minimum starting resistance would be in circuit with the series field winding, reducing the flow of current therethrough.

It is preferred to control the current supplied to the separately excited field winding in such 50 manner that full voltage is applied to the winding upon starting the hoisting motor, reducing the value of the applied voltage just prior to the shunting of the series field winding in order that smooth and gradual acceleration be obtained. 55 This is accomplished by adjusting the field switch T so as to operate at a value of motor counter-E. M. F. just below that required to effect the engagement of accelerating switch contacts H177. Switch T, upon operation, causes the separation 60 of its contacts T185 to remove the short circuit for resistance 30 in series with the separately excited field winding 25. It is preferred to provide a condenser 186 across contacts T185 to prevent arcing.

65 With the starting resistances and series field winding short-circuited and with resistance inserted in circuit with the separately excited field winding, the hoisting motor comes up to full speed. Should the motor, from any cause, overspeed above a certain amount, contacts 187 of the governor switch engage to short-circuit portion 188 of resistance 30, increasing the voltage applied to the separately excited field winding. In this manner, the field strength of the motor is 70 increased, causing the motor to slow down. The 75

governor and governor switch operated thereby are illustrated in Figure 1.

It is to be noted that, as the car moves in the up direction, the center direction cam section 272 leaves the switch arm 82 of the third floor direction switch 257 and this arm is engaged by the down direction cam section 220. Thus, the third floor direction switch is transferred to a down circuit.

As the car approaches the fourth floor landing, 10 up car stop brush 98 engages fourth floor car stop contact 76. As both the brush and the contact are "alive", a circuit is completed for the reset coil 190 of the car button fourth floor switch and the reset coil S112 of the stop switch. This 15 circuit may be traced from positive main 21, line 56, line 57, line 191, by way of line 192 through reset coil 190 and contacts 72, 73 of the car button fourth floor switch, fourth floor car stop contact 76, up car stop brush 98, by way of line 20 193 through contacts D142 and reset coil S112, line 61, line 63, to the negative main 22. The car button fourth floor switch actuating coil 70 is not energized at this time owing to the fourth floor car button 68 being released. Also, the stop 25 switch actuating coil S104 is not energized at this time owing to the fact that the door and gate time relay contacts O108 are separated. Thus, upon energization of the reset coils of these switches, the switches are restored to their 30 former positions. Reset coils 190 and S112 are proportioned in such manner that the reset of the stop switch is effected prior to the reset of the car button fourth floor switch.

The stop switch, upon being reset, causes the 35 separation of contacts S113 and of contacts S114. It is to be noted that the circuit for the reset coil of the car button fourth floor switch is not broken as a result of the resetting of the stop switch, thus insuring the resetting of both of 40 these switches. The car button fourth floor switch, upon being reset, causes the separation of its stop contacts 72, 73 and of its start contacts 74, 75. The separation of contacts 72, 73 is to prepare this switch for further operation and 45 also to render fourth floor car stop contact 76 "dead". At the same time that the circuit for the reset coils of the car button fourth floor switch and the stop switch is completed, the circuit for the actuating coil F77 of the up direction relay is broken by the engagement of up insulating roller 194 and floor controller fourth floor direction switch 83, it being assumed that no other buttons have been pushed. The circuit for this coil is broken also by the separation 50 of car button fourth floor switch start contacts 74, 75. The up direction relay, upon dropping out, causes the separation of contacts F92, F93, F94, and F95 and the reengagement of contacts F90 and F91. The separation of contacts 55 F94 is without effect as the circuit for the actuating coils B102 of the up reversing switch and D103 of the up auxiliary reversing switch is maintained by contacts D144. The purpose of the separation of contacts F92 will be explained later. 60 The purpose of the reengagement of contacts F91 also will be explained later. Contacts F90, as previously explained, are in the circuit for actuating coil G96 of the down direction relay and the down direction indicating lamp 50. This coil and 65 lamp, however, cannot be energized as a result of the reengagement of contacts F90 owing to the fact that contacts B145 remain separated. The separation of contacts F95 and of contacts S113 of the stop switch does not cause the deen- 70 75

ergization of actuating coil O115 of the door and gate time relay and the actuating coil A118 of the potential switch, owing to the fact that these coils are maintained energized by contacts D143 of the up auxiliary reversing switch. The separation of contacts F93 and of contacts S114 of the stop switch, however, breaks the circuit for the actuating coil U101 of the auxiliary field switch and coil 100 of the pawl magnet.

10 The auxiliary field switch, upon dropping out, causes the separation of its contacts U184, breaking the circuit for the actuating coil T185 of the field switch. The field switch drops out immediately, causing the reengagement of its contacts 15 T185 to short-circuit resistance 30 in series with the separately excited field winding of the hoisting motor. As a result of the short-circuiting of resistance 30, the motor field strength is increased, causing the motor to slow down.

20 As a result of the deenergization of the pawl magnet coil 100, the pawls are reextended for engagement with the stopping collars. Thus, as the car, and therefore the floor controller cross-head, continues its upward movement, the up 25 pawl 198 engages the up fourth floor stopping collar 196, causing the separation of pawl slow-down switch contacts 187. The separation of contacts 187 breaks the circuit for the actuating coil J188 of the fast speed switch. This switch, 30 upon dropping out, causes the separation of contacts J167, J168 and J170 and the reengagement of contacts J166. Contacts J167 are in the circuit for the actuating coil T185 of the field switch, this circuit having previously been broken by the 35 separation of contacts U134. The separation of contacts J168 breaks the circuit for the actuating coil H171 of the accelerating switch. The separation of contacts J170 opens a circuit which, upon the dropping out of switch H as will be described below, reinserts minimum starting resistance 31 in circuit with the hoisting motor armature. The reengagement of contacts J166 reconnects the slow-down resistance across the armature of the hoisting motor. Accelerating 40 switch H, dropping out as a result of the deenergization of its actuating coil H171, causes the separation of contacts H174, H175, H176, and H177 and the reengagement of contacts H173. The reengagement of contacts H173 is in preparation for the next starting operation. The separation of contacts H174, H175, H176, and H177 removes the short circuit for sections 32, 33 and 55 34 of the maximum starting resistance and for the series field winding 26. The reinclusion of the minimum and maximum starting resistances in circuit with the armature of the hoisting motor, the removal of the short circuit for the series field winding 26 and the reconnection of the slow-down resistance across the hoisting motor armature cause further slowing down of the motor.

60 It is to be noted that the reengagement of contacts J166 not only reconnects the slow-down resistance across the motor armature, but also reestablishes the circuit for the actuating coil L197 of the first slow-down switch. This coil also is connected across the motor armature, its circuit being from the upper motor armature brush by way of line 198 through coil L197, voltage reactance coil X200, line 201, contacts J166, line 65 158 to the right, by way of line 156 through interpole field winding 27 to the lower armature brush. The purpose and operation of this switch as well as that of switches M and N will be explained later. The purpose of voltage reactance 70 coil X200 also will be explained later.

Upon the arrival of the car at a short distance from the fourth floor landing, pawl stop switch contacts 136 are separated, breaking the circuit for the actuating coils D103 of the up auxiliary reversing switch and B102 of the up reversing switch. Switch D, upon dropping out, causes the reengagement of contacts D186 and the separation of contacts D142, D143, and D144. Contacts D186 will be referred to later. Contacts D142 are in the circuit connecting up hall stop brush 99 and up car stop brush 98 with the negative main, the separation of these contacts rendering these brushes "dead". Contacts D144 are in the circuit for coils D103 and B102, the circuit for these coils having been broken by pawl stop switch contacts 15 136. Contacts D143, upon separation, break the circuit for the actuating coil A118 of the potential switch and for the actuating coil O115 of the door and gate time relay.

20 The up reversing switch B, dropping out simultaneously with the up auxiliary reversing switch D, causes the separation of contacts B147, B148, B150, and B151 and the reengagement of contacts B145 and B146. Contacts B150 are in the circuit for the actuating coils J188 of the fast 25 speed switch and H171 of the accelerating switch, the circuits for these coils having previously been broken. Contacts B145 prepare the circuits for coils E152 of the down auxiliary reversing switch, C153 of the down reversing switch and G96 of 30 the down direction relay and the down direction indicating lamp 59. The circuits for these coils and lamp can not be completed at this time in response to hall buttons, however, as will be seen from later description. The separation of contacts B147 and B148 breaks the circuit for the motor armature, the reengagement of contacts B146 connecting stop resistance 40 in shunt to the motor armature. The separation of contacts B151 breaks the circuit for the release coil 41 of 40 the electromagnetic brake. As a result, the brake is applied, the brake thus assisting the stop resistance and slow-down resistance to bring the hoisting motor to a stop. The brake contacts 162, upon reengagement, short-circuit resistance 45 43.

50 The potential switch A, upon dropping out, causes the separation of contacts A122, A123, A124, A125, and A183 and the reengagement of contacts A121. Up reversing switch contacts B147 and B148, upon separation, also broke the circuit for the separately excited field winding 25, contacts A121, upon reengagement, reconnecting resistance 28 in shunt to the separately excited field winding to afford a path for the field discharge current and thus maintain sufficient field strength to complete the dynamic braking action. Contacts A122 and A123 are in the circuit for the hoisting motor armature, broken by the separation of contacts B147 and B148. Contacts A124 60 are common to the actuating coils of the up auxiliary reversing switch, up reversing switch, auxiliary field switch, and pawl magnet, the circuits for these coils being previously broken as above described. Contacts A183 will be referred to 65 later. Contacts A125, upon separation, break the circuit for the door lock cam motor 44.

70 The brake being applied, the hoisting motor armature and field windings being disconnected from the mains and the slow-down and stop resistances being connected across the motor armature, the elevator car is brought to a stop at the fourth floor landing. It is to be noted that, as the car arrives at the fourth floor, up direction cam section 84 disengages the switch arm 75

82 of the fourth floor direction switch and this arm is engaged by the insulated center direction cam section 272. With the car at rest level with the fourth floor landing, the contact surface of this switch arm rests on the center of cam section 272. Thus, the fourth floor direction switch is disconnected from the direction relay actuating coils.

Upon the deenergization of the door lock cam 10 motor 44, a spring 210 acts to move the retiring cam 128 away from the car, as may be seen upon reference to Figure 1. The retiring cam engages the operating roller 138 of the fourth floor well door interlock, causing the separation of the 15 fourth floor door lock contacts and the unlocking of the door. Thus, the passenger may open the gate and door and step from the car. The opening of the door causes the separation of door contacts 53. The opening of the gate causes the 20 separation of gate contacts 62. As the passenger steps from the car, however, platform switch contacts 48 engage, by-passing the gate contacts.

As was above explained, the circuit for the actuating coil O115 of the door and gate time relay was broken upon the separation of contacts D143. This relay does not drop out immediately, however, its operation being delayed by a suitable form of timing arrangement such as a dash-pot, as illustrated in Figure 14. Thus, 30 even though coil O115 is deenergized, its contacts O60 and O108 do not immediately reengage. It is to be noted that with contacts O108 separated, the car can not be started owing to the fact that the circuit for the actuating coil S104 of the stop 35 switch can not be completed. The timing arrangement for the door and gate time relay is adjusted to insure an interval of time after the stopping of the car and before it may again be started which is sufficient to permit the passenger to open the gate and door. Upon the 40 expiration of the time interval, contacts O108 and O60 reengage. Contacts O108 prepare the circuit for the actuating coil of the stop switch.

As has previously been explained, upon release 45 of the door, it is closed automatically, causing the reengagement of the door contacts 53. With contacts 53 and contacts O60 in engagement, the circuit is again completed for the auxiliary car preference time relay actuating coil R55, this 50 circuit being through platform switch contacts 48. Relay R operates as previously described to break the circuit for the car preference time relay actuating coil P65. Relay P does not drop out immediately, owing to the action of its timing arrangement, and therefore contacts P67 and P68 do not immediately engage.

It has been shown in the above description that the car may be started by a car button and is thereafter stopped at the floor corresponding 60 to the button pushed. In the example assumed, the car was below the floor corresponding to the button pushed, thus resulting in the car being started in the up direction. It will be seen from the description that follows, however, that the 65 car may be started in the down direction in response to a car button for a floor below that at which the car is positioned. Also, it will be seen that the car may be started in response to the pushing of any car button other than the one for the floor at which the car is positioned and that it will be brought to a stop at the floor for which the button is pushed.

It has also been shown that with the car at rest at a floor, preference is given an intending 70 passenger at that floor as to the starting of the

car and therefore its direction of travel, provided the well door is opened before any other buttons are pushed. The starting of the car and its direction of travel may also be controlled by means of the hall buttons. The starting of the car in response to the pushing of a hall button will next be described. In order that the operation of the system to start the car in the down direction may also be shown, it will be assumed that, with the car at the fourth floor, the down second floor 10 hall button 211 is pushed. Platform switch contacts 48, by-passing gate contacts 62, take the place of the gate contacts in the circuits. Owing to the fact that contacts O60, door contacts 53 and platform switch contacts 39 are in engagement, the car is started immediately the hall button is pushed, regardless of whether contacts P67 are in engagement or not.

Upon pushing the down second floor hall button 211, a circuit is completed for the down hall 20 button second floor switch closing coil 70. This circuit may be traced from positive main 21, line 56, through push button 211 and coil 70, line 63, to the negative main 22. This floor switch operates to cause the engagement of its stop contacts 25 72, 73 and of its start contacts 74, 75. Contacts 72, 73 complete a circuit from the positive main through the reset coil 190 of this switch, and also through contacts K239 of the automatic non-stop relay in engagement under the conditions 30 assumed, to floor controller second floor down hall stop contact 213, rendering this contact "alive". The purpose and operation of the automatic non-stop relay will be explained in the latter part of the description. Contacts 74, 75 35 complete a circuit for the actuating coil G96 of the down direction relay and down direction indicating lamp 50. This circuit may be traced from positive main 21, line 56, line 57, by way of line 58 through door contacts 53, contacts O60 40 and platform switch contacts 39 and also contacts P67 in parallel therewith provided they are restored to engaged position, blade 214 of service switch 51, line 215, line 216, through contacts 74, 75 (2D), line 217, second floor direction switch 45 218, line 245, switch arm 82 of the third floor direction switch 257 and floor controller down direction cam section 220, by way of line 221 through coil G96 and lamp 50 in parallel, contacts F90 and contacts B145, line 61, line 63, to 50 the negative main 22.

The down direction indicating lamp lights, indicating that the car is to travel in the down direction, as will be explained later. The down direction relay, upon operation, causes the separation of contacts G87 and G222 and the engagement of contacts G223, G224, G225, and G226. Contacts G87 are in the circuit for the actuating coil F77 of the up direction relay and the up direction indicating lamp 49. Thus, with contacts G87 separated, this coil and lamp can not be energized, contacts G87 and their corresponding contacts F90 of the up direction relay serving as electrical interlocks, as is well understood. The separation of contacts G222 disconnects the up call down hall stop brush 227 from the down car stop brush 228, contacts G222 corresponding with contacts F91 of the up direction relay. Contacts G224 correspond with contacts F93 of 60 the up direction relay and prepare a circuit for pawl magnet coil 100 and coil U101 of the auxiliary field switch. Contacts G225 correspond with contacts F94 of the up direction relay and prepare a circuit for coils E152 and C153 of the 65 70 75

down auxiliary reversing switch and down reversing switch, respectively.

Contacts G223, upon engagement, complete a circuit, by-passing door contacts 53, door and gate time relay contacts O69, platform switch contacts 39, car preference time relay contacts P67 and blade 214 of service switch 51, to coil G96 and lamp 50, this circuit being from the positive main 21, line 56, line 57, line 78, line 80, line 251, service switch 52 in position "a", line 252, by way of line 260 through contacts G223, switch blade 261 of service switch 51 in position "a", line 215, line 216, contacts 74, 75 of the down hall button second floor switch to coil G96 and lamp 50 as above traced. It is to be noted that contacts G223 correspond with contacts F92 of the up direction relay, contacts F92 serving the same purpose when the car is started in the up direction in response to the pushing of a hall button, as will be seen from later description. Contacts G226 are arranged in parallel with contacts F95 of the up direction relay and complete the circuit for the actuating coils V107 and S104 of the home station relay and stop switch, respectively, this circuit having been previously traced.

The operation of the stop switch has been previously explained, its contacts S113 completing the circuit for the actuating coils of the door and gate time relay O and the potential switch A as previously traced. The door and gate time relay O operates as previously described to cause the separation of contacts O108 and O60, contacts O108 breaking the circuit for the actuating coil S104 of the stop switch, now latched in operated position, and contacts O60 breaking the circuit for the actuating coil R55 of the auxiliary car preference time relay. Contacts R64, therefore, reengage to complete the circuit for coil P65 of the car preference time relay, this latter relay operating to restore contacts P67 and P69 to full disengaged position. It is to be noted that the separation of contacts O60 or of contacts P67 does not break the circuit for coil G96 and lamp 50, this circuit being maintained through contacts G223 as above explained. The potential switch A operates in the manner previously described to disconnect the discharge resistance 28 from across the separately excited field winding, to prepare the circuit for the hoisting motor armature, to further prepare the circuit for the pawl magnet coil 100 and auxiliary field switch actuating coil U101, and to complete the circuit for the door lock cam motor 44. The door lock cam motor operates to lock the fourth floor door and to cause the engagement of the door lock contacts.

As previously explained, door lock contacts 54, upon engagement, complete the circuit for the pawl magnet coil 100 and auxiliary field switch actuating coil U101. The auxiliary field switch operates to prepare the circuit for the field switch actuating coil T135. The pawl magnet retracts its pawls, causing the engagement of pawl stop switch contacts 136 and pawl slow-down switch contacts 137.

Pawl stop switch contacts 136 complete the circuit for the actuating coils E152 and C153 of the down auxiliary reversing switch and down reversing switch, respectively. This circuit may be traced from the positive main 21, line 56, by way of line 57 through safety switch 41, by way of line 132 through door lock contacts 54 and contacts A124, by way of line 140 through pawl stop switch contacts 136, contacts G225, by way of line 230 through coil E152 and coil C153, by way

of line 221 through contacts B145, line 61, line 63, to the negative main 22.

Down auxiliary reversing switch E, upon operation, causes the separation of contacts E181 and the engagement of contacts E231, E232 and E233. Contacts E181 correspond with up auxiliary reversing switch contacts D180 and their purpose will be explained later. Contacts E231 correspond with up auxiliary reversing switch contacts D142 and connect down car stop brush 228 and down hall stop brush 234 through reset coil S112 of the stop switch to the negative main, rendering these brushes "alive". Contacts E232 correspond with up auxiliary reversing switch contacts D143 and establish a holding circuit around contacts G226 for the door and gate time relay actuating coil O115 and the potential switch actuating coil A116. Contacts E233 correspond with up auxiliary reversing switch contacts D144 and establish a holding circuit around contacts G225 for coils E152 and C153.

The down reversing switch C, operating simultaneously with down auxiliary reversing switch E, causes the separation of contacts C88 and C155 and the engagement of contacts C235, C236, C237, 25 and C238. Contacts C88 correspond with up direction switch contacts B145 and are in the circuit for the up auxiliary reversing switch and up reversing switch actuating coils and also in the circuit for the coil F77 and lamp 49, contacts C88 30 and B145 serving as electrical interlocks, as is well understood. Contacts C155 correspond with up direction switch contacts B146 and disconnect the stopping resistance 40 from across the motor armature. Contacts C235 and C236 correspond with up reversing switch contacts B147 and B148 and complete the circuit for the hoisting motor armature and for the separately excited field winding. The circuit for the hoisting motor armature may be traced from positive main 21, 40 through contacts A122, by way of line 158 through contacts C235 and contacts B146, by way of line 156 through interpole field winding 27, armature 24 and current reactance coil X151, by way of line 154 through contacts C236, minimum 45 and maximum starting resistances and series field winding 26, contacts A123, to the negative main 22. The circuit for the separately excited field winding may be traced from positive main 21, through contacts A122, by way of line 158 through contacts C235, through portion 240 of stop resistance 40, line 161, by way of line 159 through contacts T185 and field winding 25, back to line 161, through contacts A123, to the negative main 22. Contacts C237 correspond with up reversing switch contacts B150 and will be referred to later. Contacts C238 correspond with up reversing switch contacts B151 and complete the circuit for the brake release coil 41. It is believed this circuit will be obvious from that previously traced for the brake release coil.

The brake being released as a result of the energization of its release coil 41, current being supplied from the mains to the armature of the hoisting motor, the direction of the flow of current through the armature being reversed from that previously described, and the motor field windings being energized, the motor starts in a direction to cause downward movement of the 70 car.

Contacts C237, along with contacts C235, complete the circuit for the actuating coil J138 of the fast speed switch prepared by pawl slow-down switch contacts 137. It is believed that this cir- 75

cuit will be obvious from that previously traced for this coil. Furthermore, it is believed that the operation of the switches J, T, and H to cause the acceleration of the hoisting motor will be understood from the previous description relating to the operation of these switches to accelerate the motor during starting the car in the up direction.

As the car leaves the fourth floor, the fourth floor direction switch is transferred to the up circuit, that is, it is connected to coil F17 of the up direction relay. Upon the down direction cam section 220 engaging the second floor direction switch, the holding circuit for the down direction switch actuating coil is transferred to extend directly from the second floor direction switch to the down direction cam section, the circuit by way of the third floor direction switch being broken by the opening of the second floor direction switch. Thus, the circuit for the down direction relay actuating coil is not broken as a result of the engagement of the down insulating roller and insulated center direction cam section 272 with the third floor direction switch. As the car passes the third floor, the third floor direction switch is transferred to the up circuit. During the movement of the car, the third floor stop contacts are engaged by their respective brushes. No circuits are completed, however, as none of the third floor buttons have been pushed and therefore these stop contacts are "dead".

As the car approaches the second floor landing, down hall stop brush 234 engages the second floor down hall stop contact 213, completing the circuit for the reset coil 190 of the down hall button second floor switch and the reset coil S112 of the stop switch. Thus, these switches are reset. At the same time, the circuit for the actuating coil G96 of the down direction relay is broken by the engagement of down insulating roller 241 and the switch arm 82 of the second floor direction switch 218, it being assumed as before that no other buttons have been pushed. Thus, the second floor down hall stop contact 213 is rendered "dead" and the circuit for the actuating coil U101 of the auxiliary field switch and pawl magnet coil 100 is broken. The auxiliary field switch causes the dropping out of the field switch T. Contacts T185, therefore, reengage to short-circuit field resistance 30, slowing down the motor.

As a result of the deenergization of the pawl magnet coil, the pawls are reextended for engagement with the stop collars. Thus, as the car, and therefore the floor controller crosshead, continues its downward movement, the down pawl 242 engages the down second floor stopping collar 196, causing the separation of pawl slow-down switch contacts 137 and thereafter the separation of pawl stop switch contacts 136. As a result of the separation of the pawl slow-down and pawl stop switch contacts, the motor is further slowed down and finally stopped at the second floor landing. It is believed that this stopping operation will be understood from previous description relating to the stopping of the car at the fourth floor landing, the down auxiliary reversing switch and down reversing switch being involved rather than the up auxiliary reversing switch and up reversing switch in the previous description. As the car comes to rest at the second floor landing, the insulated center direction cam section 272 moves into engagement with the second floor direction switch. Thus, with the

car at rest at the second floor, the second floor push buttons are isolated.

Upon the separation of contacts A125 in the above stopping operation, the door lock cam motor 44 is deenergized, this motor acting as 5 previously described to cause the unlocking of the second floor well door. As has previously been explained, the actuating coil O115 of the door and gate time relay is deenergized at the same time as the actuating coil A116 of the 10 potential switch, the dropping out of relay O being delayed, however, by its timing arrangement. It was also shown that the car cannot be started again until contacts O108 engage, thus affording 15 time for the opening of the door. Should the 20 intending passenger, in the above example, not open the second floor well door within the allowed time interval, the car may be started again in response to the pushing of another hall button, owing to the reengagement of contacts O60 25 as well as contacts O108. Thus, where the intending passenger, after pushing a hall button, decides that he does not desire the use of the car, the car does not become stalled at the floor for which the button was pushed but may be started 30 again in response to the pushing of a hall button after the time interval of relay O has elapsed. In the event that the intending passenger is merely tardy in opening the door, he may retain control of the car even after this time interval has 35 elapsed, provided he opens the door to effect the separation of door contacts 53 before the door is locked in response to the pushing of a hall button.

It will be assumed in the above example that 35 the intending passenger at the second floor opens the second floor well door within the allowed time interval. As will be seen from later description, once the direction relay drops out, no circuit can be established for the actuating coil of either 40 direction relay, owing to the fact that contacts O60 are separated. Thus, upon the initiation of the stopping operation in the assumed example, preference is given the intending passenger as to the control of the car. Furthermore, this preference is maintained, once the door is opened, because of the separation of door contacts 53, regardless of whether contacts O60 are in engagement or not.

Upon the passenger stepping into the car, platform switch contacts 29, 39, and 48 separate. Upon the release of the door, the door closes, causing the reengagement of door contacts 53. Control of the car cannot be taken away from the passenger, however, as contacts P67 and P69 55 as well as contacts 29 and 39 are separated. Upon the closure of the gate, gate contacts 62 engage to by-pass platform switch contacts 48, completing the circuit for coil 55 of the auxiliary car preference time relay, assuming contacts O60 60 in engagement. Relay R operates as before to break the circuit for coil P55 of the car preference time relay. As previously explained, however, contacts P67 and P69 of this relay do not engage immediately, sufficient time being allowed for the passenger to press the car button for the floor to which he desires to be carried.

It will be assumed that the passenger desires to be carried to the first floor and pushes the first floor car button 209. As a result, the car 70 button first floor switch operates to render the floor controller first floor car stop contact 219 "alive" and to complete the circuit for the actuating coil G96 of the down direction relay and the down direction indicating lamp 50, this cir- 75

cuit being by way of switch arm 82 of floor controller first floor direction switch 229 and floor controller down direction cam section 220 in engagement therewith. Further than this, it is believed that the starting of the car in response to the pushing of the first floor car button will be obvious from the previous description. Also, it is believed that the stopping of the car at the first floor will be obvious from the previous description, the stopping operation being initiated by the engagement of the down car stop brush 228 and stop contact 219.

It has now been shown that, where a down hall button is pushed and where the car is at rest at a floor above that for which the button was pushed, the car is started in the down direction and is stopped at the floor corresponding to the button pushed. It is believed obvious from the above description that, where an up hall button is pushed and where the car is at rest at a floor below that for which the button is pushed, the car is started in the up direction and stopped at the floor corresponding to the button pushed.

Let it be assumed, for example, however, that a down hall button is pushed and that the car is at rest at a floor below that corresponding to the button pushed. Under such conditions, the car is started in the up direction and stopped at the floor corresponding to the button pushed. In order that this operation may be understood, it will be assumed that, with the car at rest at the first floor, an intending passenger at the fourth floor desires to be carried in the down direction and pushes the down fourth floor hall button 243. A circuit is thereby completed for the closing coil 70 of the down hall button fourth floor switch, this switch operating to cause the engagement of its stop contacts 72, 73 and its start contacts 74, 75. Contacts 72, 73 connect the floor controller fourth floor down hall stop contact 244 to the positive main. Owing to the fact that the button pushed is for a floor above the car, start contacts 74, 75 complete a circuit for the actuating coil F77 of the up direction relay and for the up direction indicating lamp 49. This circuit may be traced from positive main 21, line 56, line 57, by way of line 58 through door contacts 53 and door and gate time relay contacts O60, by way of line 263 through platform switch contacts 29 and also car preference time relay contacts P69 in parallel therewith, provided sufficient time has elapsed to result in engagement of these contacts, through blade 262 of service switch 51, line 255, by way of line 216 through fourth floor car preference switch 264, through contacts 74, 75 (4D), line 81, floor controller fourth floor direction switch 83, line 245, fifth floor direction switch 246, by way of line 86 through coil F77 and lamp 49, to the negative main as previously traced. From this point on, the operation of the system to start the car in the up direction is the same as has been described for starting the car in the up direction in response to the pushing of the fourth floor car button. The description of this operation, therefore, will not be repeated. It is to be noted, however, that the engagement of contacts F92 of the up direction relay completes a circuit for coil F77 and lamp 49, by-passing contacts 53, O60, 29, and P69 and switch blade 262 of service switch 51. This circuit may be traced from positive main 21, line 56, line 57, line 78, line 80, line 251, service switch 52 in position "a", line 252, by way of line 253 through contacts F92, switch blade 254 of service switch 51 in position "a", line 255, by way of line 75 216 through car preference switch 264, through

contacts 74, 75 of down hall button fourth floor switch, line 81, to coil F77 and lamp 49 as above traced. Thus, the separation of contacts O60, during the starting operation, does not result in the deenergization of coil F77.

During the upward movement of the car, the direction cam transfers the direction switches from up to down circuits. As the car approaches the fourth floor landing, up direction cam section 84 engages the switch arm 82 of floor controller 10 fourth floor direction switch 83, causing the opening of this switch. Up direction relay does not drop out as a result of the opening of this switch, however, as the engagement of cam section 84 and switch arm 82 establishes a by-pass circuit around switch 83 to the up direction relay actuating coil F77, this circuit being by way of line 85. Upon the up insulating roller 194 lifting switch arm 82 off cam section 84 as a result of the continued upward movement of the car, the circuit for coil 20 F77 is broken, causing relay F to drop out. As a result, contacts F91 reengage, connecting the down call up hall stop brush 97 to the negative main 22 by way of up car stop brush 98, line 193, contacts D142 and stop switch reset coil S112. 25 As previously explained, reengagement of contacts F91 occurs just as the brush 97 engages fourth floor down hall stop contact 244. As a result, a circuit is completed for the reset coil 190 of the down hall button fourth floor switch and the reset coil S112 of the stop switch, contacts K239 being in engagement at this time under the assumed load conditions, as will be explained later. These switches are therefore reset, causing the slowing down and stopping of the car at the fourth floor 35 landing. The intending passenger may now open the door and step into the car and push the car button for his desired destination to which he will be carried.

Thus, it will be seen that the car may be started 40 in the up direction in response to the pushing of the down hall button and stopped, while traveling in the up direction, at the floor at which the down hall button was pushed. The system will operate in a similar manner under similar conditions to 45 start the car in the down direction in response to the pushing of an up hall button for a floor below the one at which the car is positioned and to stop the car, while traveling in the down direction, at the floor at which the up hall button was 50 pushed.

In each of the above examples, it was assumed 55 that only one button was pushed and it was shown that the car may be started in response to the pushing of either a car button or a hall button, with its direction of travel determined by the position of the direction cam with respect to the direction switches and therefore by the position of the car with respect to the floor for which the button was pushed, regardless of 60 whether it was a car button or an up or a down hall button. It was also shown that the car is stopped automatically at the floor for which the button was pushed. Thus, when only one button is pushed, "individual" push button operation is 65 obtained. The system also operates to stop at each floor for which a button is pushed, in the event that buttons for more than one floor are pushed, thus giving "collective" push button operation. This stopping is in the natural order of 70 floors for each direction of travel, regardless of the order in which the buttons are pushed. In order that such operation may be readily understood, it will be assumed that, with the car at rest at the first floor, one of the up hall buttons 75

for another floor, for example the up third floor hall button 247, is pushed. This completes the circuit for the closing coil 70 of the up hall button third floor switch, this switch operating to cause the engagement of its stop contacts 72, 73 and of its start contacts 74, 75. The engagement of contacts 72, 73 connects floor controller third floor up hall stop contact 248 to the positive main. The engagement of contacts 74, 75 (3U) completes the circuit for lamp 49 and coil F77 of the up direction relay, this relay operating as previously described to cause the locking of the first floor well door and the starting of the car. As before, the engagement of contacts F92 of the up direction relay completes a circuit for coil F77 and lamp 49, by-passing contacts 53, O60, 29, and P69 and switch blade 262 of service switch 51. This circuit may be traced from positive main 21, line 56, line 51, line 78, line 80, line 251, service switch 52 in position "a", line 252, by way of line 253 through contacts F92, switch blade 254 of service switch 51 in position "a", line 255, by way of line 216 through fourth floor car preference switch 264, through contacts 74, 75 of the up hall button third floor switch, line 256, floor controller third floor direction switch 257, by way of line 245, through floor controller direction switches 83 and 246, by way of line 86 through coil F77 and lamp 49, to the negative main as previously traced.

Assume further that before the engagement of the up hall stop brush 99 and the second floor up hall stop contact 250, the second floor up hall button 258 is pushed, causing the operation of the up hall button second floor switch. The engagement of start contacts 74, 75 of the up hall button second floor switch completes an additional circuit for coil F77 and lamp 49, this circuit being by way of contacts F92, by-passing contacts O60 which are separated at this time, and also by way of third floor car preference switch 265 as well as fourth floor car preference switch 264 in line 216. Thus, contacts F92 serve the additional purpose of permitting the establishment of additional circuits for coil F77 and lamp 49 in response to subsequently operated up hall buttons, and also down hall buttons under certain conditions as will be seen from later description. The engagement of stop contacts 72, 73 of the up hall button second floor switch connects floor controller second floor up hall stop contact 250 to the positive main 21 to render the contact "alive", contacts K239 being in engagement as will be explained later.

Upon the engagement of up hall stop brush 99 and the second floor up hall stop contact 250 as the car approaches the second floor landing, a circuit is completed for reset coil 190 of the up hall button second floor switch and reset coil S112 of the stop switch. Also, arm 82 of the second floor direction switch 218 is engaged by up insulating roller 194. Although the additional circuit for coil F77 and lamp 49 is broken by the lifting of arm 82 of switch 218 off cam section 84 and also by the separation of contacts 74, 75 of the up hall button second floor switch, the circuit for this coil and lamp is maintained by way of contacts F92, contacts 74, 75 of the up hall button third floor switch and third floor direction switch 257. Thus, relay F remains in operated condition and lamp 49 stays lighted. The reset of the stop switch S, however, causes the car to slow down and stop at the second floor landing.

The second floor well door being unlocked as

a result of the dropping out of the potential switch in the stopping operation, the intending passenger may open the well door and step into the car. The door and gate time relay, as previously explained, serves to prevent the restarting of the car before an intending passenger has had sufficient time to open the door and gate. Upon the closure of the door, and also the gate to by-pass platform switch contacts 48, the door is locked and the car starts immediately, provided door and gate time relay contacts O108 are in engagement, owing to the fact that relay F is in operated condition. Thus, under the conditions assumed, the time element provided by the car preference relay P to allow the passenger in the car to select his destination without the possibility of interference due to the pushing of hall buttons is eliminated. This is desirable as the passenger taken on at the second floor has previously indicated that he wished to go in the up direction by having pushed the up second floor hall button. This direction of travel having already been established, the car is started immediately the gate and door are closed, thus saving considerable time and giving maximum service. It will be assumed that this passenger desires to be carried to the fourth floor and that he pushes the fourth floor car button. The car button fourth floor switch thereupon operates to render the fourth floor car stop contact 76 "alive" and to complete an additional circuit for coil F77 and lamp 49. This circuit may be traced from positive main 21, line 56, line 51, line 78, line 80, by way of line 81 through contacts 74, 75 of the car button fourth floor switch to coil F77 and lamp 49 as previously traced.

Upon the engagement of up hall stop brush 99 and the third floor up hall stop contact 248 as the car approaches the third floor, a circuit is completed for the reset coils of the up hall button third floor switch and stop switch, contacts K239 being in engagement. These switches are therefore reset. The reset of the stop switch causes the slowing down and stopping of the car at the third floor landing. As before, however, the up direction relay F does not drop out as a result of the resetting of the up hall button third floor switch and the engagement of up insulating roller with the third floor direction switch, the circuit for coil F77 and lamp 49 being maintained through start contacts 74, 75 of the car button fourth floor switch.

Upon the car being stopped at the third floor, the intending passenger at that floor opens the door and gate and steps into the car. Assume that during this time the up fourth floor hall button is pushed. The up hall button fourth floor switch, operating in response to the pushing of this button, connects the fourth floor up hall stop contact 266 to the positive main and completes an additional circuit for coil F77 and lamp 49, this circuit being by way of contacts F92. Upon the closure of the door and gate, the door is locked and the car started immediately as before, assuming the reengagement of contacts O108.

It will be assumed that this passenger, now in the car, desires to be carried to the fifth floor and pushes the fifth floor car button. As a result, the fifth floor car stop contact 267 is rendered "alive" and another circuit is completed by way of contacts 74, 75 of the fifth floor car button switch for coil F77 and lamp 49.

Upon the approach of the car to the fourth floor landing, up hall stop brush 99 engages con-

- tact 266 and up car stop brush 98 engages contact 76, completing circuits for the reset coils of both the up hall button fourth floor switch and the car button fourth floor switch and for 5 the stop switch. These switches are therefore reset, the stop switch causing the car to slow down and stop at the fourth floor landing. Thus, it is seen that where the car is traveling in the up direction and where a car button and an up 10 hall button for the same landing have been operated, their respective floor switches are both reset upon the initiation of the stopping operation for that floor. The up direction relay, as before, remains in operated condition, its circuit 15 being maintained through contacts 74, 75 of the car button fifth floor switch.

Upon the closure of the door and gate after the passenger at the fourth floor has gotten into the car, with contacts O108 in engagement, the 20 car is immediately started in the up direction. This last passenger, desiring to be carried to the fifth floor, may push the fifth floor car button. The car button fifth floor switch being in operated condition, however, the pushing of the 25 button has no other effect than to momentarily energize the closing coil of the switch.

Upon the engagement of up car stop brush 98 with the fifth floor car stop contact 267, the stop switch and the car button fifth floor switch 30 are both reset. Also the circuit for coil F77 of the up direction relay and lamp 49 is broken as a result of up insulating roller 194 lifting arm 32 of floor controller fifth floor direction switch 246 off up direction cam section 84 and the separation of contacts 74, 75 of the fifth floor car button switch. Thus, the up direction relay drops out and the car is brought to a stop at the fifth floor landing. During the upward movement of the car, the direction cam transfers the 35 direction switches for the first, second, third and fourth floors to down circuits and, with the car at the fifth floor, isolates the fifth floor direction switch.

It is to be noted that the circuit for coil F77 40 is broken upon the last stop in the up direction, regardless of the floor at which this last stop is made for, with no buttons pushed for floors above this floor, there is no circuit remaining to maintain the coil energized.

Upon the passengers stepping from the car and the reclosure of the fifth floor well door, circuits are prepared for starting the car in the down direction, since the fifth floor is the upper terminal floor. It is to be noted that, with contacts O60 and O108 of the door and gate time 45 relay in engagement, the car is started immediately in response to the pushing of a down hall button upon the passengers having stepped from the car and the closure of the door, owing to the reengagement of the platform switch contacts 29, 50 39, and 48. The operation of the system during down car travel to respond to a plurality of down hall buttons and also car buttons is similar to that above described for operation in the up direction where several up hall buttons and car buttons were pushed. It is believed, therefore, 55 that such operation will be understood without further description. It is to be noted that contacts G223 of the down direction relay serve the same purpose during down operation as contacts F92 of the up direction relay during up operation, permitting the establishment of additional circuits for coil G96 in response to the pushing of down hall buttons.

70 It will be seen from the above description that,

when the car is traveling in the up direction, stops are made in response to all up hall buttons and car buttons in the natural order of floors, regardless of the order in which the buttons are pushed. Similarly, when the car is traveling in the down direction, stops are made in response to all down hall buttons and car buttons in the natural order of floors, regardless of the order in which the buttons are pushed.

Assume now that the car is at the first floor 10 and that the down second floor hall button 211 is pushed. As previously explained, the up direction relay F is operated as a result of the operation of the down hall button second floor switch, causing the starting of the car in the 15 up direction. If no other buttons are pushed, upon the engagement of up insulating roller 194 with switch arm 82 of floor controller second floor direction switch 218, the circuit for coil F77 is broken and the up direction relay drops out. 20 Owing to the fact that second floor down hall stop contact 213 is "alive", contacts K239 being in engagement, the reengagement of contacts F91 completes the reset circuit for the down hall button second floor switch and stop switch reset coils 25 by way of down call up hall stop brush 97 and line 193, causing the resetting of these switches and the stopping of the car at the second floor landing.

It will be assumed, however, that the down 30 fourth floor hall button is pushed prior to the engagement of the up insulating roller 194 and switch 218. As a result, an additional circuit is established for coil F77 by way of contacts F92 and floor controller fourth floor car preference 35 switch 264. Upon the engagement of the up insulating roller 194 and switch 218, therefore, coil F77 is not deenergized and therefore contacts F91 do not reengage. Thus, the engagement of brush 97 with contact 213 does not complete a 40 circuit for the reset coil of the down hall button second floor switch and for the reset coil of the stop switch S, for, although contact 213 is "alive", down call up stop brush 97 is "dead" owing to the fact that contacts F91 remain separated. 45 These switches, therefore, are not reset and the car continues past the second floor landing without stopping. It is to be noted that, with the down hall button second floor switch remaining operated, its stop contacts 72, 73 do not separate and up second floor hall stop contact 213 remains "alive". Also the start contacts 74, 75 of this switch remain in engagement. These start contacts, however, cannot complete a circuit at this time for the actuating coil G96 of the down 50 direction relay as a result of the engagement of the down direction cam section 220 with direction switch 218, owing to contacts F90 and B145 being separated.

Assume now that, prior to the engagement of up insulating roller 194 and floor controller third floor direction switch 257, the down third floor hall button is pushed. As a result, the down hall button third floor switch is operated, causing the engagement of the stop contacts 72, 73 to 60 render the third floor down hall stop contact 271 "alive" and the engagement of its start contacts 74, 75 to establish an additional circuit for coil F77 by way of contacts F92 and car preference switches 264 and 265. As before, however, upon the engagement of the up insulating roller 194 with the floor controller third floor direction switch 257, coil F77 is not deenergized and the down hall button third floor switch and stop switch are not reset. Thus, the car passes the 65 70 75

third floor landing without stopping. As in the case of the down hall button second floor switch, contacts 72, 73 of the down hall button third floor switch remain in engagement, keeping the down 5 third floor hall stop contact "alive" and its contacts 74, 75 remain in engagement.

Upon the engagement of the up insulating roller 194 with the switch arm 82 of the floor controller fourth floor direction switch 83, the 10 circuit for coil F71 is broken. Contacts F91, therefore, reengage, and, with the down call up hall stop brush 97 in engagement with "live" contact 244, the circuit is completed to effect the resetting of the down hall button fourth floor 15 switch and the stop switch. As a result, the car is brought to a stop at the fourth floor landing.

It will be assumed that the intending passenger at the fourth floor desires to be carried to the first floor. Upon his entering the car, the reclosure of the door and gate, and the pushing of the first floor car button, the car is started in the down direction. It is to be noted that, upon the operation of the down direction relay in response to the engagement of the start contacts 25 74, 75 of the car button first floor switch, contacts G223 engage. The engagement of these contacts establishes additional circuits for coil G96 of the down direction relay, one of these circuits being by way of second floor car preference switch 268 in line 216 and contacts 74, 75 of the 30 down hall button third floor switch and the other by way of contacts 74, 75 of the down hall button second floor switch, these floor switch contacts, as previously explained, being in engagement.

Upon the engagement of down hall stop brush 234 and the third floor down hall stop contact 271, a circuit is completed for the reset coils of the 40 down hall button third floor switch and the stop switch. These switches, therefore, are reset and the car is brought to a stop at the third floor landing. It is to be noted that coil G96 is not deenergized as a result of the engagement of the down insulating roller 241 with the floor controller third floor direction switch 257 and the separation of contacts 74, 75 of the down hall button third floor switch, its circuit being maintained by way of contacts 74, 75 of the down hall button second floor switch and also contacts 74, 50 75 of the car button first floor switch.

Upon the intending passenger having stepped into the car and the reclosure of the door and gate, the car is started immediately in the down direction, assuming contacts O108 in engagement. The system operates in a similar manner to effect the stopping of the car at the second floor landing in response to the down second floor hall button and also to stop the car at the first floor landing in response to the first floor car button. It is not believed, therefore, that such operations need be described in detail. It is to be noted that coil G96 is deenergized as a result of engagement of down insulating roller 241 with the floor controller first floor direction switch 229 and the separation of contacts 74, 75 of the first floor car button switch. Assuming that the passengers taken on at the third and second floors also desire to be carried to the first floor landing, upon all the passengers stepping from the car and the reclosure of the first floor well door, the circuits are prepared for starting the car in the up direction, the first floor being the lower terminal floor.

Assume now that the car is started from the first floor in response to the pushing of the down 75 second floor hall button, but that prior to the en-

gagement of the up insulating roller 194 with its switch 218, the up third floor hall button is pushed. As a result, the up hall button third floor switch is operated, causing the engagement of its stop contacts 72, 73 to render up third floor 5 hall stop contact 248 "alive", and of its start contacts 74, 75 to establish an additional circuit for the actuating coil F71 of the up direction relay by way of contacts F92. As before, the car passes the second floor landing without stopping. As 10 assume further that, prior to the engagement of the up insulating roller 194 with the floor controller third floor direction switch 257, the down fourth floor hall button is pushed. As a result, the down hall button fourth floor switch 15 is operated, causing the engagement of its stop contacts to render the fourth floor down hall stop contact 244 "alive" and of its start contacts 74, 75 completing an additional circuit for coil F71 by way of contacts F92 and switch 264. Upon 20 the engagement of the up hall stop brush 99 with the up third floor hall stop contact 248, a circuit is completed for the reset coils of the up hall button third floor switch and the stop switch. These switches, therefore, are reset and the car is 25 brought to a stop at the third floor landing. The circuit for coil F71, however, is maintained by way of contacts 74, 75 of the down hall button fourth floor switch, switch 264 and contacts F92. Upon the intending passenger at the third floor having 30 entered the car, the closure of the door and gate and the engagement of contacts O108, the car is started immediately in the up direction. It will be assumed that this passenger desires to be carried to the fifth floor and pushes the fifth floor 35 car button. As a result, the fifth floor car stop contact 267 is rendered "alive" and an additional circuit is completed by way of contacts 74, 75 of the car button fifth floor switch for the actuating coil F71 of the up direction relay. 40

Upon the engagement of the up insulating roller 194 with the floor controller fourth floor direction switch 83 the circuit is not broken for coil F71 and therefore contacts F91 remain separated. Thus, the circuit is not completed for the reset 45 coils of the down hall button fourth floor switch and the stop switch, so that the car continues past the fourth floor landing without stopping.

Upon the engagement of up car stop brush 98 and fifth floor car stop contact 267, the car button fifth floor switch and the stop switch are reset, causing the stopping of the car at the fifth floor landing. Also, the circuit for coil F71 is broken, causing the dropping out of the up direction relay. Upon the passenger stepping from 55 the car, the reclosure of the fifth floor well door and the reengagement of contacts O60 and O108 of the door and gate time relay, the car is started immediately in the down direction. This is due to the fact that the start contacts of both the 60 down hall button fourth floor switch and the down hall button second floor switch are in engagement and also to the fact that platform switch contacts 39 reengage to by-pass car preference relay contacts P67 upon the passenger stepping out of the car. It is believed that the operation of the system to stop at the fourth and second floor landings to pick up the intending passengers at these floors and the carrying of these passengers to their desired destinations will be 65 understood from previous description without detailed explanation.

It may be pointed out, however, that where a down hall button and car or up hall button for the same floor have been pushed, or where all 75

these buttons have been pushed, the corresponding floor switches are all reset upon the car being stopped at that floor during up car travel provided this is the last stop in the up direction. 5 Should there be buttons pushed for floors beyond, which remain unresponded to, however, the down hall button floor switch is not reset. In such case, the intending passenger desiring to be carried in the down direction is advised by the lighted up 10 direction indicating lamp that the car is to proceed from the floor in the up direction. This will be explained in more detail in later description. Similar operation is had during down car travel under such conditions. It is believed that 15 this will be obvious from previous description without further explanation.

It will be seen from previous description that 20 response is had to all buttons, regardless of the time or the order in which the buttons are pushed, since the contacts of the floor switches, once in engagement, are maintained so until released by reset operations. The stops are made 25 in the natural order of floors, even though the buttons are pushed out of said order. Stops in 30 response to car buttons are made for either direction of travel, that is, the car buttons cause the stopping of the car regardless of whether it is traveling in the up or down direction. As regards the hall buttons, however, during up car 35 travel, the car stops in response to all up hall buttons, and in response to a down hall button, provided no buttons remain unresponded to for floors above the floor corresponding to this down hall button. Similarly, during down car travel, the car stops in response to all down hall buttons, and in response to an up hall button, provided no buttons remain unresponded to for 40 floors below the floor corresponding to this up hall button. Further, it is to be noted that when, with the car traveling in a certain direction, a hall button for that direction is pushed after the car passes the point at which the stop is initiated for the floor at which this button is located, the car reverses after its last stop in that direction 45 and stops at that floor while traveling in the opposite direction, provided there are no buttons pushed for floors beyond that floor, and, in the event of such buttons being pushed, reverses again after its last stop in the opposite direction 50 and proceeds to that floor where it is stopped. Thus, response is had to all buttons, regardless of the time that the buttons are pushed.

As regards starting the car, with the car at rest at any floor, it starts in response to the pushing of any button, either car or hall button, other than for the floor at which the car is positioned. 55 The car can not be started in response to the pushing of a button for the floor at which it is standing, owing to the fact that the floor controller direction switch for that floor is in engagement with insulated center direction cam section 272. The direction of travel of the car is determined by the position of the direction cam with respect to the direction switches and, therefore, the position of the car with respect to the floor corresponding to the button pushed and not, in case of the hall buttons, by whether an up or a down hall button is pushed. Thus, as regards starting, all buttons for floors above that 60 at which the car is positioned are up buttons while all those for floors below that at which the car is positioned are down buttons.

Once the car is started in a certain direction, 70 additional circuits may be established by both car and hall buttons to maintain that direction

of car travel. When the car is traveling in the up direction, the direction switches for the consecutive floors are picked up by the up direction cam section 84, that is, connected by way of this cam section directly to coil F17 of the up direction relay, and thereafter transferred to down circuits. Also, when the car is traveling in the down direction, the direction switches for the consecutive floors are picked up by the down direction cam section 220 and thereafter transferred to up circuits. It will be seen, therefore, 10 that the control of the direction of travel may be obtained by means of a direction switch for each floor and by a cooperating short direction cam arranged to span three direction switches set 15 for average floor heights, regardless of the number of floors.

When running in the up direction, the running circuit, that is, the circuit from the start contacts of the floor switches to the actuating coil 20 of the up direction relay, is not exclusively taken up by up direction cam section 84 until the last stop in the up direction, this running circuit being maintained prior to the last stop by way of the direction switches for floors above the cam. When traveling in the down direction, however, the running circuit is always by way of the down direction cam section 220 and is directly through the direction switches in contact therewith. Thus, for example, where a second floor button 25 has been pushed and the car is just passing the third floor, running downwardly, the running circuit for coil G96 is directly through the second floor direction switch arm and down direction cam section. However, should it have been a first 30 floor button which was pushed, the running circuit is through the second floor direction switch only until the first floor direction switch arm is engaged by the down direction cam section, whereupon the circuit to the second floor direction switch is broken at the first floor direction switch and the running circuit is directly through the first floor direction switch arm and the cam section.

As previously explained, the down direction 45 cam section is longer than the up direction cam section, owing to the fact that the lower floors are usually of greater height than the intermediate and upper floors. The down direction cam section is preferably of such length as to insure 50 the engagement of the down direction cam section with the switch arm of the first floor direction switch prior to the engagement of the down insulating roller with the second floor switch arm, with these direction switches set for an average 55 installation. Thus, the direction cam may be of a standard length for all installations, effecting a great saving in production costs. Should there be such a floor height that, during down car travel, the down insulating roller engages the switch 60 arm of the direction switch for the floor above before the engagement of the down direction cam section with the switch arm of the direction switch for this high floor, the resulting disestablishment of the down running circuit may be 65 prevented by the addition of an extra direction switch between these direction switches and in series relation therewith. This extra direction switch would be mounted on an extra insulating bar on the floor controller, positioned so that the extra direction switch arm would be engaged by the down direction cam section prior to the engagement of the down insulating roller with the switch arm of the direction switch above. This extra direction switch would also permit the es- 70 75

5 tablishment of a starting circuit for coil G88 with the car stopped at the floor above in the event that the height of the floor below were so great that the down direction cam section would not be in engagement with the switch arm of the direction switch for the floor below.

Should the car be at rest at a certain floor and an intending passenger at that floor open the well door prior to the pushing of any hall buttons, he is given preference as to the establishing 10 of the direction of car travel. Otherwise, if the passenger closed the gate before pressing a button, it would be possible for the car to be summoned by a hall call in a direction opposite to that of the car passenger's intended destination. The car button preference is obtained, as 15 previously explained, by the action of the car preference time relay P and platform switch contacts 39. Should a hall button for the direction of travel opposite to that desired by the car passenger be pushed after the opening of the door, however, the floor switch corresponding thereto is operated, causing the engagement of its start contacts 74, 75 to prepare the circuit for the opposite direction of car travel. This circuit is completed after the last stop in the direction of travel established by the car button. Once the direction of travel has been established and additional circuits have been completed for the direction relay actuating coil, the car is started automatically in the same direction after each stop, upon the closing of the door, the closing of the gate when there is some one in the car, and the reengagement of contacts O108, so long as any 20 of these additional circuits exist. Should buttons have been operated in the meantime to prepare circuits for the opposite direction of travel, the car is reversed immediately after the last stop upon the closing of the door at the floor at which the last stop is made and the reengagement of contacts O108, under conditions where no passengers remain in the car, the time interval incident to relay P being eliminated. This results in considerable saving of time. The time 25 interval incident to relay P is also eliminated where a hall button is pushed for the same direction of car travel after the initiation of the stopping operation for the last stop in that direction and the dropping out of the direction relay, under conditions where all remaining passengers leave the car at the floor at which the stop is made. Thus, if the car is running in the up direction and the last stop in that direction is made 30 at the third floor in response to the third floor car button, should the up hall button for the fourth floor or the hall button for the fifth floor be pushed at any time after the up direction relay drops out, the car is started immediately in the up direction after the passenger or passengers leave the car at the third floor upon the closing of the third floor well door and the engagement of contacts O60 and O108, owing to the 35 reengagement of the platform switch contacts.

Should the last stop in either direction be in response to a hall button, preference is given the intending passenger, as to determining the direction of car travel, by the action of relays O, R, and P and the contacts of the platform switch. Thus, should such last stop be in response to a 40 hall button corresponding to the direction of travel of the car as it approached the floor at which this stop is made, upon the passenger entering the car and pushing a car button such as to cause the same direction of car travel, with the 45 door and gate closed and with contacts O108 in

engagement, the car is started immediately in the same direction as it approached the floor, even though hall buttons have been previously pushed preparing circuits for the opposite direction of car travel. Similarly, should such last 5 stop be in response to a hall button corresponding to the opposite direction of car travel from that in which the car approached the floor at which this stop is made, upon the passenger entering the car and pushing a car button such as 10 to cause car travel in the opposite direction, with the door and gate closed and with contacts O108 in engagement, the car is started immediately in the opposite direction, even though hall buttons have been pushed for the same direction of car 15 travel as that in which the car approached the floor after such stopping operation was initiated but prior to the pushing of the car button.

In connection with the action of relays O, P, and R to give preference to car buttons over hall 20 buttons as regards starting the car and determining the direction of car travel, the floor controller car preference switches 264, 265, and 268 act to insure this preference being given under certain conditions of operation. As previously 25 explained, there is one of these switches for each intermediate floor, they being arranged in series relation in line 216. These car preference switches connect contacts 75 of the hall button floor switches together, switch 268 being arranged between those of the up and down second floor hall button switches, switch 265 between those of the up and down third floor hall button switches and switch 264 between those of the up and down fourth floor hall button switches. When the car arrives 30 at an intermediate floor, the car preference switch for that floor is opened by the car preference cam 269, thus disconnecting contacts 75 of floor switches above this switch from those of the floor switches below this switch. In order that the 35 function of the floor controller car preference mechanism may be understood, assume that the car is at rest at the third floor and that an intending passenger steps into the car. Assume further that this passenger desires to be carried to the fourth floor and that before he pushes the 40 fourth floor car button 68, a hall button for a floor below the third floor, for example the up second floor hall button 258, and that a hall button for a floor above the third floor, for example the 45 down fourth floor hall button 243, are pushed. The start contacts 74, 75 (4D) and 74, 75 (2U) are in engagement, therefore, at the time that 50 start contacts 74, 75 (4C) engage. As the stationary contacts 74 of the fourth floor car button switch and the down fourth floor hall button switch are connected together, the engagement of the start contacts 74, 75 of the fourth floor car button switch connects line 216 above third floor car preference switch 265 to the positive main by 55 way of line 78. Owing to the fact that switch 265 is open, however, this circuit does not continue to the start contacts of the up second floor hall button switch. Thus, the simultaneous energization 60 of the actuating coils of both direction switches 65 upon the engagement of the start contacts of the car button fourth floor switch is prevented and preference for the car buttons over the hall buttons is assured.

It is to be noted that with the operation as 70 above described, the direction of car travel may be reversed at any floor. It may be desirable under certain traffic conditions, however, to change the operation of the system so as to cause the car, once started, to proceed to a terminal floor be- 75

fore reversing. Under such conditions, the last stop of the car is always at a terminal floor where it remains until another button is pushed. Such operation may be obtained by throwing over serv-

5 ice switch 51 to cause its blades 214, 256, 261, and 262 to occupy position "b". It is to be noted that, with blades 214 and 262 of service switch 51 in position "b", the common line 216 for the start contacts 75 of the hall button floor switches is

10 connected at both ends directly to the positive main 21 by way of line 78. Thus, the giving of preference to car buttons over hall buttons is eliminated. This is desirable owing to the fact that the last stop of the car is always at a terminal landing from which the car can be started in only one direction, regardless of whether a car button or an up or down hall button is pushed.

15 Assume that the car is at rest at the first floor with service switch 51 in position "b". Upon the 20 pushing of any button, either car or up or down hall button, a circuit is completed for the actuating coil F77 of the up direction relay. As soon as this relay operates, it establishes its own holding circuit by way of contacts F92. This holding circuit may be traced from positive main 21, line 56, line 57, line 78, line 80, line 251, service switch 25 52 in position "a", line 252, by way of line 253 through contacts F92, blade 254 of service switch 51 in position "b", line 273, line 274, floor con-

30 troller fifth floor direction switch 246, by way of line 86 through coil F77, to the negative main, as previously traced. The car, once started, stops at the floors corresponding to the car buttons and up hall buttons pushed as previously de-

35 scribed. Although with service switch 51 in position "b" the car may be started in the up direction in response to a down hall button, it does not stop at the floor for which the down hall button was pushed in response to that button during up 40 car travel owing to the fact that the up direction relay is maintained in operated condition by the circuit through floor controller direction switch 246 and therefore contacts F91 remain separated, preventing the connection of the down call up hall stop brush 97 to the negative main. Also, the 45 car does not stop in response to other operated down hall buttons while traveling in the up direction for the same reason. The car is started automatically after stops at intermediate floors, 50 as before. Upon the engagement of up insulating roller 194 with floor controller fifth floor direction switch 246 as the car approaches the fifth floor, however, the circuit for coil F77 of the up direction relay is broken. The up direction relay, 55 therefore, drops out and, as a result of the separation of its contacts F93 to deenergize pawl magnet coil 100 and auxiliary field switch coil U101, causes the slowing down and stopping of the car at the fifth floor landing, regardless of 60 whether the stop switch is reset or not. Should buttons have been pushed which are not yet responded to, the car reverses after stopping at the fifth floor and stops, during its downward travel, at the floors corresponding to the down 65 hall buttons which remained unresponded to as the car reached the fifth floor and also to other down hall buttons and car buttons operated prior to the disengagement of the proper brushes and the stop contacts corresponding to these buttons.

70 Also, should certain or all of the buttons which remained unresponded to after the stop at the fifth floor have been up hall buttons or should up hall buttons be pushed during down car travel, the car would reverse again at the first floor and 75 proceed upwardly to answer these calls.

In the event that the stop switch is not reset during the above described stopping operation at the fifth floor and there are buttons yet to be responded to, the car is reversed immediately the 5 up direction switch drops out. This is due to the fact that contacts B145 complete the circuit for the actuating coil G96 of the down direction relay by way of the start contacts of the floor switch or switches in engagement. The time element due to the door and gate time relay is eliminated 10 under such conditions owing to the fact that stop switch contacts S118 remain latched in engagement. Should all buttons have been responded to when the car stops at the fifth floor, the car remains at this floor until another button is 15 pushed.

In the event that either the car or hall button for the fifth floor is pushed during up car travel, not only does the up direction relay drop out as above described upon the car approaching the 20 fifth floor, but also the fifth floor car or hall button switch, depending on whether the fifth floor car button or hall button was pushed, and the stop switch are reset. As a result, the car is not reversed immediately under conditions where 25 buttons are yet to be responded to, but the door and gate time relay becomes effective to permit sufficient time for the opening of the door and gate.

The system operates in a similar manner when 30 the car is started from rest at the fifth floor, the car continuing in operation after each stop in the down direction until the first floor is reached. It is believed, therefore, that no detailed 35 description of such operation is necessary.

The system may also be arranged to cause the car finally to stop at a selected floor or "home station" if desired. Such operation may be obtained by closing service switch 111. In order that the operation of the system under such 40 conditions may be readily understood, assume that service switch 51 is in position "a" or, in other words, that the system is arranged so as to permit reversal of car travel at any floor. It is to be noted that line 275, containing service 45 switch 111 and home station relay contacts V110, is connected on the right to the closing coil 70 of the up hall button second floor switch and on the left to the positive main 21. In this manner, the second floor is rendered the "home station." 50

Assume, therefore, that all buttons have been 55 responded to and that the car is at rest at the "home station". Assume further that an intending passenger at the second floor opens the well door and steps into the car. As before, preference 60 as to the starting of the car is given to the car buttons. Should the passenger desire to be carried to the first floor and push the first floor car button, the car is started in the down direction. During the starting operation, the home station 65 relay actuating coil V107, being in series with the closing coil S104 of the stop switch, is energized, causing the engagement of contacts V110 as previously explained. As a result, the closing coil 70 of the up hall button second floor switch is 70 energized. This switch operates to cause the engagement of its stop contacts 72, 73 in the circuit for up second floor hall stop contact 250 and the engagement of its start contacts 74, 75. The energization of the actuating coil V107 of the home station relay is only momentary, however, its circuit being broken by the separation of door and gate time relay contacts O108. Thus, contacts V110 remain in engagement only long 75

enough to insure the operation of the up hall button second floor switch.

Upon the car having stopped at the first floor and the passenger having left the car, the circuit for coil F77 of the up direction relay is completed by way of contacts 74, 75 of the up hall button second floor switch immediately upon the closing of the door and the engagement of contacts O60 and O108, causing the starting of the car in the up direction. Upon the engagement of the up hall stop brush 99 with stop contact 250 as the car approaches the second floor, the stop switch is reset, causing the slowing down and stopping of the car at the second floor landing. Also, the up hall button second floor switch is reset, home station relay contacts V110 being separated. Should no other buttons have been pushed to establish additional circuits for coil F77, the circuit for this coil is also broken, owing to the engagement of up insulating roller 194 with floor controller direction switch 218 and the reset of the up hall button second floor switch. Should no such buttons have been pushed and should the first floor hall button not have been pushed after the car left the first floor, the car remains at the second floor to await the pushing of another button.

The system otherwise operates as previously described. The car may be started in the up direction in response to a car button or an up or a down hall button for a floor above the second floor. Upon the starting of the car, as before, the home station relay V, and therefore the up hall button second floor switch, is operated. After the last stop in the up direction, the car is started in the down direction regardless of whether buttons for floors below the floor at which the last stop is made have been pushed or not, owing to the fact that the start contacts 74, 75 of the up second floor hall button switch are in engagement and establish a circuit for the actuating coil G96 of the down direction relay. In the event that neither the first floor car button nor hall button has been pushed, the car is stopped at the second floor as a result of the engagement of down insulating roller 241 with the second floor direction switch, as the car approaches the second floor in the down direction, and the consequent reengagement of contacts G222 to effect the reset of the stop switch and the up hall button second floor switch. Should either or both of the first floor buttons have been operated, the additional circuit established for coil G96 prevents the dropping out of the down direction relay and therefore prevents the reengagement of contacts G222 to cause the stopping of the car at the second floor. The car is stopped at the second floor, however, even though a first floor button has been operated, in the event that either the second floor car button or down second floor hall button has been operated. In any event, the car is returned to the "home station" after all buttons for floors other than the second floor have been responded to.

Assume now that the system is arranged so as to cause the car to reverse only at the terminal floors, that is, with service switch 51 in position "b". The car may be caused to return to the "home station" under such conditions by closing service switch 111 as above stated and also by throwing service switch 52 in position "b". Thus, assuming that all calls have been answered and that the car is at rest at the "home station", upon an intending passenger entering the car and pushing the first floor car button, the car is

started in the down direction. During this starting operation, the home station relay operates to cause the engagement of its contacts V110 and therefore the operation of the up hall button second floor switch as above explained. Thus, after the stop at the first floor has been completed, that is, after the reengagement of the platform switch contacts, the reclosure of the door and the reengagement of contacts O108, the car is started in the up direction, the circuit for coil F77 of the up direction relay being completed by way of contacts 74, 75 of the up hall button second floor switch. The up direction relay, upon operation, establishes a holding circuit for its actuating coil by way of its contacts F92, this circuit being traced from positive main 21, line 56, line 57, line 78, switch blade 214 of service switch 51 in position "b", line 215, by way of line 216 through car preference switch 268, through start contacts 74, 75 of the up hall button second floor switch, line 217, service switch 52 in position "b", line 252, by way of line 253 through contacts F92, switch blade 254 of service switch 51 in position "b", line 273, line 274, floor controller fifth direction switch 246, by way of line 86 through coil F77, to the negative main 22 as previously traced.

Upon the engagement of up hall stop brush 99 with stop contact 250 as the car approaches the second floor, the stop switch is reset, causing the slowing down and stopping of the car at the second floor landing. Also, the up hall button second floor switch is reset, home station relay contacts V110 being separated. Also, the up direction relay drops out in the event that no other buttons have been pushed to establish additional circuits for its actuating coil F77, the circuit for this coil being broken by the separation of start contacts 74, 75 of the up hall button second floor switch. It is to be noted that the holding circuit above traced for coil F77 is not controlled by the floor controller second floor direction switch 218 and therefore the engagement of up insulating roller 194 with this switch as the car approaches the second floor does not break the circuit for coil F77. If no calls remain unresponded to, the car remains at its "home station" to await the pushing of another button.

Assume, however, that prior to the engagement of up hall stop brush 99 with stop contact 250, the down fourth floor hall button is pushed. As a result, an additional circuit is established for the actuating coil F77 of the up direction relay. This additional circuit may be traced from positive main 21, line 56, line 57, line 78, switch blade 214 of service switch 51 in position "b", line 215, by way of line 216 through switches 268 and 265, through start contacts 74, 75 of the down hall button fourth floor switch, line 81, floor controller fourth floor direction switch 83, line 245, floor controller fifth floor direction switch 246, by way of line 86 through coil F77 to the negative main as previously traced. Upon the engagement of brush 99 and stop contact 250, the stop switch and up hall button second floor switch are reset and the car is slowed down and stopped at the second floor landing, as above explained. The separation of start contacts 74, 75 of the up hall button second floor switch does not cause the dropping out of the up direction relay, the actuating coil of this relay being maintained energized by way of the circuit through start contacts 74, 75 of the down hall button fourth floor switch as above traced. Thus, under the above assumed conditions, with the door closed and with the gate or platform switch contacts in engagement, the

car is started in the up direction immediately upon the reengagement of contacts O108. As before, during this starting operation, the home station relay V causes the operation of the up hall button second floor switch. The reengagement of start contacts 74, 75 of this switch reestablishes a holding circuit for coil F17 through switch blade 262 of service switch 51 in position "b", car preference switches 264 and 265, service switch 52 in position "b", contacts F92, switch blade 254 of service switch 51 in position "b", and floor controller fifth floor direction switch 246. Assuming no other button is pushed, the car runs to the fifth floor before coming to a stop. The car does not stop at the fourth floor to answer the call registered by the down fourth floor hall button, owing to the fact that the up direction relay is maintained in operated condition and therefore contacts F91 remain separated.

20 The stop at the fifth floor, as previously explained, is caused by the engagement of up insulating roller 194 with floor controller fifth floor direction switch 246, the stop switch not being reset because no fifth floor button has been pushed. Upon the reengagement of contacts B145, therefore, the car is started immediately in the down direction as before. Relay G, upon operation during the down starting operation, causes the engagement of its contacts G223 to establish its own holding circuit. This holding circuit may be traced from positive main 21, line 56, line 57, line 78, switch blade 214 of service switch 51 in position "b", line 215, by way of line 216 through switch 268, through start contacts 35 74, 75 of up hall button second floor switch, line 217, service switch 52 in position "b", line 252, by way of line 260 through contacts G223, switch blade 261 of service switch 51 in position "b", line 280, line 281, floor controller first floor direction switch 229, by way of line 245 through floor controller second floor direction switch 218, floor controller third floor direction switch 251, down direction cam section 220, by way of line 221 through coil G96, to the negative main as previously traced. It is to be noted that line 217 is connected directly to floor controller second floor direction switch 218, by-passing service switch 52, contacts G223, switch blade 261 of service switch 51 and floor controller first floor direction switch 229. This by-pass will be referred to later.

55 As previously explained, the car stops at the fourth floor during down car travel to answer the call registered by the down fourth floor hall button. It will be assumed that the intending passenger at the fourth floor desires to be carried to the third floor. It is believed that the restarting of the car from the fourth floor, the stopping thereof to discharge the passenger at the third floor and the restarting of the car from the third floor will be obvious from previous description. It will be further assumed that the down second floor hall button has not been pushed. Upon the engagement of down insulating roller 244 with floor controller second floor direction switch 218, although the circuit for coil G96 by way of line 217 is broken, this coil is maintained energized by way of service switch 52, contacts G223, switch blade 261 of service switch 51, switch arm 82 of floor controller first floor direction switch 229 and down direction cam section 220. Contacts G222, therefore, remain separated, so that the engagement of up call down hall stop brush 227 with stop

contact 250 does not cause the stopping of the car at the second floor. Upon the engagement of down insulating roller 244 with floor controller first floor direction switch 229, the circuit for coil G96 is broken, causing the stopping of the car at the first floor landing. As no first floor button has been pushed, the stop switch is not reset and the car is started immediately in the up direction upon the engagement of down reversing switch contacts C88. Upon the engagement of up hall stop brush 99 with stop contact 250, as the car approaches the second floor, the car is slowed down and stopped at the second floor landing as previously described. It is believed that further operation of the system with service switch 51 closed and with service switches 51 and 52 in positions "b" will be obvious from previous description. No further description of such operation, therefore, will be given. It is to be noted, however, that, with service switch 52 in position "b", line 252 is connected to the start contacts 74, 75 of the up hall button second floor switch so that the holding circuit for the direction relay actuating coil is broken upon a stop at the "home station" after all calls have been answered. Thus, the continuous operation of the car with stops at the "home station" and terminals after all buttons have been responded to is prevented.

Any floor may be made the "home station", the second floor being chosen merely as an example. In order that some indication be made that the "home station" floor may be changed, an arrow is shown at the end of line 275 connected to closing coil 70 of up hall button second floor switch and another arrow is shown at the end of the line connecting service switch 52 to line 275. Thus, if it were desired to make the third floor the "home station", line 275 may be connected to the closing coil of the up hall button third floor switch and service switch 52 connected to line 256. Also, line 275 may be connected to the closing coil of a down hall button floor switch, if desired, with the connection for service switch 52 arranged accordingly. Assume, for example, that line 275 is connected to the closing coil of the down hall button second floor switch and that service switches 51 and 52 are in positions "a". Under such conditions, the car is always stopped at the second floor when traveling in the down direction but not when traveling in the up direction unless there are no calls for floors above the second floor yet unanswered or unless the second floor car button or up hall button has been pushed. With service switches 51 and 52 in positions "b", the car is always stopped at the second floor when traveling in the down direction but not when traveling in the up direction unless the second floor car button or up hall button has been pushed. Furthermore, line 275 may be connected to the closing coil of a car button floor switch for a certain floor with the connections for service switch 52 arranged accordingly, if it is desired to have the car always stop at that floor during both up and down car travel. As to whether line 275 is connected to the closing coil of a car button, up hall button or down hall button floor switch and as to which floor is made the "home station" would depend upon the requirements of the particular installation. In any event, the system operates to cause the return of the car to the "home station" selected after all calls have been responded to.

It is to be noted that condensers 249 and 259

are arranged in shunt to the actuating coils F17 and G96 respectively of the direction relays.

These condensers prevent arcs being drawn upon the circuits for their respective coils being broken.

5 Thus, where the dropping out of a direction relay is involved in initiating the stopping of the car at a floor, an accurate stop at that floor is assured.

As has been seen from previous description, 10 upon the energization of the actuating coil of the up direction relay, the up direction indicating lamp is lighted and upon the energization of the actuating coil of the down direction relay, the down direction indicating lamp is lighted. These 15 lamps are arranged in a two compartment box provided with direction indicating signs. The arrangement has been termed the direction indicator and is illustrated in Figures 18 and 19. The direction indicator is designated as a whole 20 by the character 283. The indicator box 284 is divided into two compartments, up compartment 285 and down compartment 286. The up direction indicating lamp 49 is positioned in the up compartment while the down direction indicating 25 lamp 50 is positioned in the down compartment. An up sign 287 is provided on the front of the up compartment and a down sign 288 is provided on the front of the down compartment so that when the up lamp is lighted the up sign is 30 illuminated while when the down lamp is lighted the down sign is illuminated. The direction indicator is in the car and may be positioned at any point overhead that insures its ready visibility to the intending passengers with the door 35 and gate open. The indicator is illustrated in Figure 1 as positioned in the rear of the car where it would be directly behind the opening for the gate and door.

As has been previously described, the up direction indicating lamp remains lighted during up car travel until the last stop in the up direction is initiated, i. e., until the up direction relay drops out. Upon the car being stopped during up travel at a floor under conditions where a 40 call or calls for floors above the floor at which the car is stopped remain unresponded to, the intending passengers at the floor at which the car is stopped are advised by the illuminated up sign that the car is to continue in the up direction. Thus, intending passengers desiring to be carried in the up direction will enter the car while intending passengers desiring to be carried in the down direction will wait until the car returns to the floor during its downward travel. 45 Similarly, the down direction indicating lamp remains lighted during down car travel until the last stop in the down direction is initiated. Upon the car being stopped during down travel at a floor under conditions where a call or calls for 50 floors below the floor at which the stop is made remain unresponded to, the intending passengers at the floor at which the car is stopped are advised by the illuminated down sign that the car is to continue in the down direction. Thus, intending passengers desiring to be carried in the down direction will enter the car while intending passengers desiring to be carried in the up direction will wait until the car returns to the floor during its upward movement. Should the stop be 55 in response to the last call in the direction of car travel, the circuit for the direction indicating lamp is broken as the stopping operation is initiated so that neither direction sign is illuminated with the car stopped at the floor. Thus, an 60 intending passenger at that floor is advised that

he is given control of the direction of travel of the car.

The system is arranged so that the car, when fully loaded, will automatically run past floors at which hall calls are registered until room is again provided in the car due to discharge of passengers. A suitable arrangement for this purpose is illustrated in Figure 15 and involves the weighing switch 178 and automatic non-stop relay K. With the car at rest at a landing, should enough 5 passengers enter the car to cause it to be fully loaded, the weighing switch 178 closes. The closing of this switch completes a circuit for the actuating coil K182 of the automatic non-stop switch. This circuit may be traced from positive 15 main 21, line 56, line 57, by way of line 291 through weighing switch 178, contacts D180 of the up auxiliary reversing switch, contacts E181 of the down auxiliary reversing switch and coil K182, line 61, line 63, to the negative main 22. 20 The automatic non-stop relay, upon operation, causes the separation of its contacts K239 and the engagement of its contacts K129. Contacts K129 prepare a holding circuit for coil K182. Contacts K239 break the circuit from the positive 25 main to the reset coils for all the hall button floor switches for the intermediate floors. The holding circuit for coil K182 is completed by the engagement of potential switch contacts A183. Thus, coil K182 remains energized by way of contacts 30 K129 and A183 upon the separation of contacts D180 or E181 and contacts K239 remain separated. Under such conditions, the car does not stop at intermediate floors in response to hall buttons, owing to the fact that the separation of 35 contacts K239 prevents the energization of the reset coils of the operated hall button floor switches for the intermediate floors. Contacts K239, however, do not prevent the stopping of the car at intermediate floors in answer to car 40 buttons. Thus, the car may stop at intermediate floors to discharge passengers. Also, contacts K239 do not prevent stops at the terminals in answer to car buttons or hall buttons.

Upon a stop being made, contacts A183 separate 45 to break the holding circuit for coil K182 of the automatic non-stop relay. Also, contacts D180 or contacts E181 reengage, depending upon which auxiliary reversing switch was operated. Should the exchange of passengers at this floor 50 be such that the car is again fully loaded, the circuit for coil K182 is completed and, upon the engagement of contacts A183, the holding circuit for this coil is reestablished. Thus, as before, the car does not answer hall buttons for 55 intermediate floors. Should there be room provided in the car due to discharge of passengers at a floor, however, the weighing switch 178 opens. Thus, coil K182 is not energized and contacts K239 are in engagement, permitting the 60 car to answer hall buttons at the intermediate floors. It is to be noted that contacts K239 do not prevent the operation of the hall button floor switches for the intermediate floors. Also, these contacts, when separated, prevent the 65 reset of these floor switches upon the engagement of the proper hall stop brush and stop contacts for these floors. Thus, this arrangement insures that the hall buttons for intermediate floors, once pushed, will be responded to.

70 As has been seen from previous description, the potential switch operates prior to the auxiliary reversing switches during the starting operation. Thus, contacts A183 engage before contacts D180 or E181 separate, insuring the estab- 75

lishment of the holding circuit for coil K182 before the operating circuit is broken. Contacts D180 and E181 are provided to prevent the completion of the circuit for coil K182, when the car is not fully loaded, due to inertia effects at the time that the car is started in motion or during acceleration.

Other automatic non-stop arrangements may be provided, as for example, an arrangement in which an electromagnetic switch responsive to load conditions is employed instead of the weighing switch. Such an arrangement is illustrated in Figure 16. Only a portion of the wiring diagram is shown in this figure, it being understood that the remainder of the system may be as illustrated in Figure 15. The load switch may be termed the stop control load switch and is designated as a whole in Figure 16 by the character W. This switch is provided with a current coil W292 and a voltage coil W293. The current coil W292 is arranged to be connected in shunt to the minimum start resistance and series field winding 26 by accelerating switch contacts H177 upon their engagement. The resistance of coil W292 is quite low so as not to cause the flow of an undesirable amount of current through the series field winding after contacts H177 engage. The voltage coil W293 is arranged to be connected across the mains 21, 22, a pair of auxiliary contacts H294 being provided on the accelerating switch for completing the circuit. Also, two resistances 295 and 296 are provided for controlling the voltage applied to coil W293, these resistances being arranged in series relation across down direction switch contacts C155. The stop control load switch is provided with only one pair of contacts designated W297, these contacts being arranged in place of automatic non-stop relay contacts K239 to control the circuit for the reset coils of the hall button floor switches for the intermediate floors.

With the car at rest at a floor, contacts W297 are separated. Assume that the car is started in the up direction. Upon the engagement of contacts H177 of the accelerating switch during acceleration, the current coil W292 is connected in circuit across the minimum start resistance and series field winding. At the same time that contacts H177 engage, auxiliary contacts H294 of the accelerating switch also engage, completing the circuit for the voltage coil W293. The circuit for coil W293 may be traced from positive main 21, through contacts A122, by way of line 154 through contacts B147, through resistances 295 and 296 connected in parallel by contacts C155, by way of line 300 through coil W293 and contacts H294, by way of line 158 through contacts B148, by way of line 301 through contacts H177 and coil W292, paralleling minimum start resistance 172 and series field winding 26, through contacts A123 to the negative main 22. With the polarity of connections as above traced, the voltage coil and current coil of the stop control load switch oppose each other. The effect of current coil W292, however, is not enough to prevent the operation of the stop control load switch unless there is full load in the car. Thus, under all but full load conditions, contacts W297 engage to connect the reset coils of the hall button floor switches for the intermediate floors to the positive main. Should the car be fully loaded, however, the current coil prevents the operation of the stop control load switch and, as a consequence, contacts W297 remain separated. As 75 in the case of contacts K239 of the automatic

non-stop relay, contacts W297, when separated, prevent stops at the intermediate floors in response to the hall buttons.

Upon starting the car in the down direction, the current coil is energized upon engagement of contacts H177, as before. At the same time, contacts H294 complete the circuit for the voltage coil W293. The circuit for coil W293 for down operation is different from that for up operation. The circuit for coil W293 may be traced from positive main 21, through contacts A122, by way of line 158 through contacts C235 and contacts B146, by way of line 300 through contacts H294 and coil W293, through resistance 296, by way of line 154 through contacts C236, line 158, by way of line 301 through contacts H177 and coil W292, paralleling minimum start resistance 172 and series field winding 26, through contacts A123 to the negative main 22. Also, owing to the fact that contacts B146 remain in engagement, contacts H294 connect voltage coil W293 across stop resistance 40 and resistance 295 in series relation. It is to be noted that the connections for coil W293 are reverse from those for up operation, while the connections for current coil W292 remain the same. Thus, current coil W292 and voltage coil W293 assist each other during the starting of the car in the down direction. Owing to the potentiometer effect of resistances 40, 295, and 296, the voltage applied to coil W293 during starting in the down direction is considerably less than that applied to this coil during starting in the up direction when resistances 295 and 296 are connected in parallel. These resistances are adjusted so that the cumulative action of coils W292 and W293 cause the operation of the stop control load switch to close its contacts W297 under all but full load conditions, the current coil W292 being weakest under full load conditions when starting the car in the down direction. Thus, it is seen from the above description that the stop control load switch acts during both up and down car travel to prevent the stopping of the car at the intermediate floors in response to hall buttons when the car is fully loaded. As in the case of the weighing switch arrangement of Figure 15, however, once room is provided in the car by the discharge of passengers, the car stops in the usual manner at the intermediate floors in answer to all buttons.

The completion of the circuit for the current coil W292 is delayed until the engagement of the last contacts of the accelerating switch to insure that this coil will not be subject to the initial heavy surge of current at starting. This coil may be arranged to be connected in at other points on the accelerating switch provided satisfactory adjustments may be obtained. The voltage coil W293 is connected in at the same time as the current coil in order that the desired operation may be obtained. Were this coil energized prior to the current coil, for example, the stop control load switch might be operated and held in under conditions where, if the two coils were energized simultaneously, the current coil would prevent operation.

If required by the type of service, the system may be arranged to effect the reset of the hall button floor switch for an intermediate floor under full load conditions when a stop is made at this floor in response to a car button. A suitable arrangement for this purpose is the provision of extra contacts on the stop switch which engage, upon the stop switch being reset, to by-pass contacts K239 or W297, depending upon the ar- 75

angement employed, in the circuit for the reset coils of the hall button floor switches for the intermediate floors. In Figure 17, extra stop switch contacts **S302** are illustrated in shunt relation to contacts **K239** of the automatic non-stop relay. Only a portion of the diagram is shown in this figure, it being understood that the remainder may be as illustrated in Figure 15. With the car at rest at a floor, both contacts **S302** and **K239** are in engagement, as illustrated. Upon the operation of the stop switch during the starting operation, contacts **S302** separate. Unless the car is fully loaded, contacts **K239** remain in engagement and the car stops in response to all buttons. Should the car be fully loaded, however, contacts **K239** are separated and the car does not stop at intermediate floors in response to hall buttons. However, the car stops at intermediate floors in response to car buttons. Under such conditions, not only is the car button floor switch reset but the hall button floor switch for that floor for the direction of car travel is reset as well, assuming that the corresponding hall button has been pushed. In order that this may be readily understood, assume that the car is fully loaded and is traveling in the up direction and that the up hall buttons for the third and fourth floors are operated. If the car button for the third floor is not operated, the car does not stop at the third floor owing to the fact that both contacts **K239** and **S302** are separated. Should the car button for the fourth floor be pushed, however, the car stops at the fourth floor. Upon the reset of the stop switch **S** as the stopping operation is initiated, contacts **S302** reengage, completing the circuit for the reset coil of the up hall button fourth floor switch. Thus, this switch, as well as the car button fourth floor switch, is reset. Room being provided in the car due to the discharge of one or more passengers at this floor, the intending passenger may enter the car. Unless the up fourth floor hall button is again pushed, the car is not stopped at this floor in response to this button upon its next trip, thus eliminating a false stop. This is particularly important where a bank of elevators are installed with the hall buttons common to all the elevators of the group as otherwise, with such an installation, the next car carrying less than full load which arrived at its stopping distance from the floor would stop in response to the hall button, owing to the fact that the hall button floor switch was not reset. The system as arranged according to Figure 17 operates in a similar manner during down car travel and such operation will not be described.

Referring back to Figure 15, as has previously been explained, contacts **J166** of the fast speed switch, upon their reengagement during the stopping operation, reconnect the slow-down resistance across the motor armature and reestablish the circuit for the actuating coil **L197** of the first slow-down switch. The first slow-down switch is provided with contacts **L203** for controlling the circuit for the actuating coil **M204** of the second slow-down switch, this latter switch in turn being provided with contacts **M206** for controlling the circuit for the actuating coil **N207** of the third slow-down switch. These coils are arranged for connection across the motor armature terminals and are thus rendered subject to the motor counter-E. M. F. These switches are provided with contacts for short-circuiting sections of the slow-down resistance. The first slow-down switch **L** is adjusted so as to operate

when the counter-E. M. F. of the motor is at or above a certain value at the time that contacts **J166** engage; the second slow-down switch is adjusted so as to operate when the counter-E. M. F. of the motor, at the time that contacts **L203** of the first slow-down switch engage, is at or above another predetermined value, higher than that at which the first slow-down switch operates; while the third slow-down switch is adjusted so as to operate when the counter-E. M. F. of the motor, at the time that contacts **M206** of the second slow-down switch engage, is at or above a still higher predetermined value.

The slow-down resistance, upon being connected across the motor armature by contacts **J166** during the stopping operation, acts to reduce the speed of the motor. Should the counter-E. M. F. of the motor be below the value at which the first slow-down switch is set at the time that contacts **J166** engage, none of the slow-down switches operate. Should the counter-E. M. F. be at or above this value, however, the first slow-down switch operates to cause the engagement of its contacts **L202** and **L203**. Contacts **L202** short-circuit section **35** of the slow-down resistance, causing further slow-down of the motor. Contacts **L203**, as above explained, complete the circuit for the actuating coil **M204** of the second slow-down switch. In the event that the counter-E. M. F. of the motor is below the value at which the second slow-down switch is set at the time contacts **L203** engage, the second slow-down switch does not operate. Should the counter-E. M. F. be at or above this value, however, the second slow-down switch operates to cause the engagement of its contacts **M205** and **M206**. Contacts **M205** short-circuit section **36** of the slow-down resistance, causing further decrease in the speed of the motor. Contacts **M206**, as above explained, complete the circuit for the actuating coil **N207** of the third slow-down switch. In the event that the counter-E. M. F. of the motor is below the value at which the third slow-down switch is set at the time that contacts **M206** engage, the third slow-down switch does not operate. Should the counter-E. M. F. be at or above this value, however, the third slow-down switch operates to cause the engagement of its contacts **N208**. These contacts short-circuit section **37** of the slow-down resistance, causing still further decrease in the motor speed. The slow-down switches, being responsive to the motor counter-E. M. F., are therefore subject to load. Thus, these switches may be adjusted to respond to such values of motor counter-E. M. F. as to obtain the desired slow-down for all load conditions.

As has been seen from previous description, voltage reactance coil **X200** is connected in series relation with the actuating coil **L197** of the first slow-down switch. This reactance coil is provided to insure the slow-down switches being rendered subject to load. The fast speed switch **J**, as previously explained, causes the reinsertion of the starting resistances and series field winding at the same time that it connects the slow-down resistance and actuating coil of the first slow-down switch across the motor armature. Thus, at the instant the fast speed switch drops out, the actuating coil of the first slow-down switch is subject to line voltage. The reactance coil **X200**, however, owing to its self induction, prevents the immediate building up of the current for the actuating coil of the first slow-down switch and thus delays the operation of this

switch. The reactance is adjusted so as to insure a sufficient time interval after the reengagement of contacts J166 to permit the counter-E. M. F. of the motor to adjust itself to load conditions. Thus, as the second slow-down switch is dependent on the operation of the first slow-down switch and as the third slow-down switch is dependent on the operation of the second slow-down switch, the operation of all the slow-down switches is delayed, rendering these switches subject to load.

With the operation of the slow-down switches delayed for the same interval of time regardless of load conditions, the car may run past the floor in stopping when the hoisting motor is lowering a load, i. e., delivering current to the mains, owing to the tendency of the load to keep the car in motion, while the car may stop short of the floor when the hoisting motor is lifting a load, i. e., drawing current from the mains, owing to the tendency of the load to bring the car to rest. It is desirable, therefore, to arrange the system so that the amount of delay provided for the slow-down switches is dependent on load conditions. This may be accomplished by the addition of the current reactance coil X157. The voltage reactance coil X200 and current reactance coil X157 are wound on the same core and thus constitute a compound reactor.

30 Under conditions where the motor is lowering a load, upon the reinsertion of the starting resistances and series field winding and the connection of the slow-down resistance across the motor armature during the stopping operation, 35 the current flowing in current reactance coil X157 is immediately decreased, this coil being connected outside the slow-down resistance. The connections for the reactance coils are such that, under these conditions, the effect of the 40 current coil is to reduce the delaying action of the voltage coil. Under conditions where the motor is lifting a load, upon the reinsertion of the starting resistances and series field winding and the connection of the slow-down resistance across 45 the motor armature during the stopping operation, the current flowing into the reactance coil X157 is immediately decreased. Under these conditions, the effect of the current coil is to assist the delaying action of the voltage coil, it 50 being noted that a decreasing current drawn from the line acts oppositely to a decreasing current supplied to the line. These coils are set so as to give such time delay under varying load 55 conditions that the car is brought to rest level with the floor. The slow-down switches are adjusted so that, once operated, they remain so until the car is brought to a stop. Thus, the sections of the slow-down resistance that are 60 short-circuited are maintained so as to assist the stop resistance and electromagnetic brake in bringing the motor to a stop. If desired, a switching arrangement operated in accordance with car movement may be provided in the hatchway for causing the car to be brought to an 65 exact level with each landing.

70 Safety switch 47 is provided for stopping the car in case of an emergency. Opening this switch breaks the circuit for the actuating coils and the potential switch and direction switch. These switches drop out to disconnect the motor armature from the mains and to cause the reconnection of the stop resistance and slow-down resistances across the motor armature and the application of the brake to bring the motor to 75 a stop. It is to be noted that safety switch 47

is positioned in line 57 below line 78. Thus, the opening of the safety switch does not break the circuit for the actuating coil of the operated direction relay, preventing a car passenger from reversing the direction of travel of the car by opening the safety switch and then pressing a car button. 5

Although the terminal stopping switch has been omitted to simplify the description, it is desired to briefly point out that the first contacts 10 of this switch to open would be arranged to control the circuit for the pawl magnet coil and the coil of the auxiliary field switch with the up contacts in series relation with contacts F93 and the down contacts in series relation with contacts G224. The second contacts of the terminal stopping switch to open would be arranged in circuit with the actuating coil of the fast speed switch, while the third contacts to open would be arranged in the circuit with the actuating coils 20 of the direction relays and reversing switches.

As many changes could be made in the above construction and many apparently widely different embodiments of this invention could be made without departing from the scope thereof, 25 it is intended that all matter contained in the above description or shown in the accompanying drawings shall be interpreted as illustrative and not in a limiting sense.

What is claimed is:

1. An electric elevator system comprising; an elevator car; a plurality of landings served by the car; a plurality of controls, one for each of said landings; means responsive to the operation of said controls for causing the car to slow 35 down and stop at each of the landings for which controls are operated; means for starting the car; and means for causing the car, when it has been started in a certain direction toward a predetermined intermediate one of said landings, to 40 be restarted by said starting means in that direction after each stop at least until said predetermined intermediate landing is reached, regardless of whether said control for such landing or any landing beyond is operated or not, and 45 for causing the car to run past such predetermined intermediate landing, when the control for any landing beyond is to be responded to, without stopping at such landing unless said control for such landing is operated. 50

2. An elevator system comprising; an elevator car; terminal and intermediate floors, a selected one of said intermediate floors being the home station for the car; push buttons for each of said floors; an automatic control for the home station 55 floor; and means for causing the car, when traveling in a certain direction, to stop at said home station in response to said automatic control except when any push button for a floor beyond the home station in said certain direction is 60 operated.

3. An elevator system comprising; an elevator car; terminal and intermediate floors, a selected one of said intermediate floors being the home station for the car; push buttons for each of 65 said floors; an automatic control for the home station floor; means for causing the car, when traveling in a certain direction, to stop at said home station in response to said automatic control; and means for preventing the first named 70 means causing the stopping of the car, when traveling in said certain direction, in response to said automatic control, in the event that any push button for any floor beyond said home station in said certain direction is operated. 75

4. An elevator system comprising; an elevator car; terminal and intermediate floors, a selected one of said intermediate floors being the home station for the car; push buttons for each of 5 said floors; an automatic control for the home station floor; means for causing the car, when traveling in either direction, to stop at said home station in response to said automatic control; and means for preventing the first named means 10 causing the stopping of the car, when traveling in a certain one of said directions, in response to said automatic control, in the event that any push button for any floor beyond said home station in said certain direction is operated.
- 15 5. A control system for an elevator car comprising; an up hall button and a down hall button at each of a plurality of floors; a car button for each floor; an automatic control for a selected one of said floors, said selected floor being the 20 home station; and means for causing the car, when traveling in a certain direction, always to stop at said home station in response to said automatic control and for causing the car, when traveling in the opposite direction, to stop at 25 said home station in response to said automatic control in the event that no hall button or car button for any floor beyond said home station in said opposite direction is operated but not when such buttons are operated.
- 30 6. A control system for an elevator car comprising; a control for a floor; means responsive to the operation of said control for causing the stopping of the car at said floor; and load responsive means for preventing the first named means 35 from causing the stopping of the car at said floor in response to said control when the load in the car is at or above normal full load for the car but for permitting said first named means causing the stopping of the car at said floor in 40 response to said control when the load in the car is less than said normal full load.
7. A control system for an elevator car comprising; a series of controls, one for each of a plurality of floors; means responsive to said controls for causing the stopping of the car at the floors corresponding to the controls operated; and load responsive means for preventing said first named means from causing the stopping of the car in response to said controls when the load in the car is at or above normal full load for the car but for permitting said first named means to cause the stopping of the car in response to said controls when the load in the car is less than said normal full load.
- 50 8. A control system for an elevator car comprising; a series of controls, one for each of a plurality of floors; means responsive to said controls for causing the stopping of the car at the floors corresponding to the controls operated, in the natural order of floors, regardless of the order in which the controls are operated; and load responsive means for preventing said first named means from causing the stopping of the car in response to said controls when the load in the car is at or above normal full load for the car.
- 55 9. A control system for an elevator car comprising; a series of controls, one at each of a plurality of floors; car actuating and stopping mechanism; means responsive to said controls for causing said mechanism to stop the car at the floors corresponding to the controls operated, in the natural order of floors, regardless of the order in which the controls are operated; and means responsive to the load in the car for preventing said first named means from causing 60
- 65 said mechanism to stop the car at the floors in response to said controls.
10. A control system for an elevator car comprising; a series of control switches, one at each of a plurality of floors; car actuating and stopping mechanism; means responsive to said control switches for causing said mechanism to stop the car at the floors corresponding to the control switches operated, in the natural order of floors, regardless of the order in which the control 10 switches are operated; and switching mechanism responsive to the load in the car for preventing said means from causing said mechanism to stop the car at the floors for which control switches are operated in response to said control switches 15 for said floors when the load in the car is at or above normal full load for the car.
11. A control system for an elevator car comprising; a plurality of switches, one for each of a plurality of floors, each of said switches being 20 adapted, upon operation, to remain in operated position until reset; car actuating and stopping mechanism; means responsive to said switches that are operated for causing said mechanism to stop the car at the floors for which the switches 25 are provided; means responsive to the stopping of the car at each of said floors for causing the resetting of the switch for such floor; and switching mechanism responsive to the load in the car for preventing said first named means from causing said mechanism to stop the car at the floors for which switches are operated in response to said switches for said floors when the load in the car is at or above normal full load for the car and for preventing under such conditions said 30 second named means from causing the resetting of the switches for such floors.
- 35 12. A control system for an elevator car comprising; a plurality of switches, one for each of a plurality of floors, each of said switches being 40 adapted, upon operation, to remain in operated position until reset; car actuating and stopping mechanism; means responsive to said switches that are operated for causing said mechanism to stop the car at the floors for which the switches are provided; means responsive to the stopping of the car at each of said floors for causing the resetting of the switch for such floor; and switching mechanism responsive to the load in the car for preventing said first named means from causing said mechanism to stop the car at the floors for which switches are operated in response to said switches for said floors when the load in the car reaches or exceeds a predetermined amount and for preventing under such 50 conditions said second named means from causing the resetting of the switches for such floors.
- 45 13. A control system for an elevator car comprising; a series of controls, one for each of a plurality of floors; a series of additional controls, one for each of said floors; car actuating and stopping mechanism; means responsive to the first named controls for causing said mechanism to stop the car, when traveling in a certain direction, at the floors corresponding to the first 55 named controls operated, in the natural order of floors, regardless of the order in which the first named controls are operated, and responsive to said additional controls for causing said mechanism to stop the car, when traveling in the opposite direction, at the floors corresponding to said additional controls operated, in the natural order of floors, regardless of the order in which the additional controls are operated; and switching mechanism responsive to the load in the car 60
- 65
- 70
- 75

for preventing said means from causing said mechanism to stop the car, when traveling in said certain direction and carrying normal full load or more, at the floors for which said first named controls are operated in response to said first named controls for said floors, and, when traveling in said opposite direction and carrying normal full load or more, at the floors for which said additional controls are operated in response to said additional controls for said floors.

14. A control system for an elevator car comprising; a series of control switches within the car, one for each of a plurality of floors; a series of additional control switches, one at each of said floors; car actuating and stopping mechanism; means responsive to said control switches within the car and to said additional control switches for causing said mechanism to stop the car at the floors for which control switches within the car and at which additional control switches are operated, in the natural order of floors, regardless of the order in which said control switches are operated; and switching mechanism responsive to the load in the car, for preventing said means from causing said mechanism to stop the car at the floors in response to said additional control switches when the car has become fully loaded, said switching mechanism permitting said means to cause said mechanism to stop the car at the floors in response to said control switches within the car regardless of the load in the car.

15. A control system for an elevator car comprising; a series of control switches within the car, one for each of a plurality of floors; a series of additional control switches, one at each of said floors; car actuating and stopping mechanism; means responsive to said control switches within the car and to said additional control switches for causing said mechanism to stop the car at the floors for which control switches within the car and at which additional control switches are operated, in the natural order of floors, regardless of the order in which said control switches are operated; and switching mechanism responsive to the load in the car, for preventing said means from causing said mechanism to stop the car at the floors in response to said additional control switches when the car has become fully loaded, but for permitting said car means to cause said mechanism to stop the car at the floors in response to said additional control switches after the load in the car is reduced due to discharge of passengers at any floor at which said means has caused said mechanism to stop the car in response to the control switch within the car for such floor.

16. An elevator system comprising; an elevator car; a plurality of floors; a gate for the car; hall buttons and car buttons for the respective floors; means responsive, with the car idle at any one of said floors, to the operation of any one of said buttons for the other floors for causing the starting of the car; and means for preventing the response of said means to the hall buttons for a predetermined time interval after the closing of the gate, whereby a passenger in the car has preference over an intending passenger at a floor as to the starting of the car.

17. An elevator system comprising; an elevator car; a plurality of floors; a gate for the car; a series of controls outside the car, one for each of said floors; means responsive, with the car idle at any one of said floors, to the operation of any one of said controls for the other floors

for causing the starting of the car; and means for preventing the response of said starting means to said controls for said other floors for a predetermined time interval after the closing of the car gate.

18. An elevator system comprising; an elevator car; a plurality of floors; a gate for the car; a series of controls outside the car, one for each of said floors; means responsive, with the car idle at any one of said floors, to the operation of any one of said controls for the other floors for causing the starting of the car; and means for preventing the response of said starting means to said controls for said other floors for a predetermined time interval after the closing of the car gate but for rendering said starting means responsive to such controls, upon the expiration of said predetermined time interval.

19. A control system for an elevator car comprising; a gate for the car; a series of switches within the car, one for each of a plurality of floors, operable to control the starting of the car; a series of switches outside the car, one for each of said floors, operable to control the starting of the car; and means rendered effective upon a passenger entering the car for limiting the control of the starting of the car to the switches within the car for a predetermined time interval after the closing of the gate, said means, in the event that one of said switches within the car is not operated before the expiration of said time interval, rendering said controls without the car effective to control the starting of the car.

20. An elevator system comprising; an elevator car; a plurality of floors; a gate for the car; a series of manually operable control switches within the car, one for each of said floors; a second series of manually operable control switches, one at each of said floors; means responsive, with the car idle at any one of said floors, to the operation of any one of said control switches for the other floors for causing the starting of the car in a direction toward the floor corresponding to the control switch operated; and means for limiting the response of said starting means to control switches within the car for said other floors for a predetermined time interval after the closing of the car gate and for rendering said starting means responsive to the control switches at the other floors, upon the expiration of said predetermined time interval, in the event that no control switch within the car for said other floors is operated before such time interval has expired.

21. A control system for an elevator car comprising; a gate for said car; a series of controls within the car, one for each of a plurality of floors, for causing the starting of the car; a series of controls outside the car, one for each of said floors, for causing the starting of the car; and means rendered effective upon a passenger entering the car for causing the controls within the car to have preference over the controls without the car, as regards starting the car, for a predetermined time interval after the closing of said gate.

22. A control system for an elevator car comprising; a gate for said car; a series of controls within the car, one for each of a plurality of floors, for causing the starting of the car; a series of controls outside the car, one for each of said floors, for causing the starting of the car; and means controlled by said gate and rendered effective upon a passenger entering the car for causing the controls within the car to have pref-

- erence over the controls without the car, as regards starting the car, for a predetermined time interval after the closing of said gate.
23. A control system for an elevator car comprising; a gate for said car; a series of controls within the car, one for each of a plurality of floors, operable to cause the starting of the car; a series of controls outside the car, one for each of said floors, operable to cause the starting of the car; and means rendered effective upon a passenger entering the car for causing the controls within the car to have preference over the controls without the car, as regards starting the car for a predetermined time interval after the closing of said gate, said means, in the event that one of said controls within the car is not operated before the expiration of said time interval, rendering said controls without the car effective to cause the starting of the car.
24. An elevator system comprising; an elevator car; a plurality of floors; a gate for the car; a series of manually operable control switches within the car, one for each of said floors; a second series of manually operable control switches, one at each of said floors; means responsive, with the car idle at any one of said floors, to the operation of any one of said control switches for the other floors for causing the starting of the car in a direction toward the floor corresponding to the control switch operated; and means controlled by the car gate for causing said means to respond to control switches within the car in preference to control switches at the floors.
25. An elevator system comprising; an elevator car; a plurality of floors; a well door for each floor; a series of manually operable control switches within the car, one for each of said floors; a second series of manually operable control switches, one at each of said floors; means responsive, with the car idle at any one of said floors, to the operation of any one of said control switches for the other floors for causing the starting of the car in a direction toward the floor corresponding to the control switch operated; and means controlled by the well door for the floor at which the car is positioned for causing said means to respond to control switches within the car in preference to control switches at the floors.
26. An elevator system comprising; an elevator car; a plurality of floors; a well door for each floor; a gate for the car; a series of manually operable control switches within the car, one for each of said floors; a second series of manually operable control switches, one at each of said floors; means responsive, with the car idle at any one of said floors, to the operation of any one of said control switches for the other floors for causing the starting of the car in a direction toward the floor corresponding to the control switch operated; and means controlled by the car gate and by the well door for the floor at which the car is positioned for causing said means to respond to control switches within the car in preference to control switches at the floors.
27. An elevator system comprising; an elevator car; a plurality of floors; a well door for each floor; a gate for the car; a series of manually operable control switches within the car, one for each of said floors; a series of manually operable control switches, one at each of said floors; means responsive, with the car idle at any one of said floors, to the operation of any one of said control switches for the other floors for causing

the starting of the car in a direction toward the floor corresponding to the control switch operated; and means controlled by the car gate and by the well door for the floor at which the car is positioned and rendered effective when there is a passenger in the car for causing said means to respond to control switches within the car in preference to control switches at the floors.

28. An elevator system comprising; an elevator car; a plurality of floors; a well door for each of said floors; a car gate; a plurality of control switches within the car, one for each of said floors; a plurality of control switches without the car, one for each of said floors; car actuating and stopping mechanism responsive, with the car at rest at a floor, to the operation of any one of said control switches for the other floors for causing the starting of the car, said mechanism, when the car is traveling in a certain direction, being responsive to said control switches for causing the stopping of the car at the floors corresponding to the control switches operated; and means for limiting the response of said mechanism to cause the starting of the car, after the last stop at a floor in said certain direction, to control switches within the car for the other floors for a predetermined time interval after the closing of the car gate and of the well door for the floor at which the last stop is made, in the event that a passenger is in the car.

29. An elevator system comprising; an elevator car; a plurality of floors; a well door for each of said floors; a car gate; a plurality of control switches within the car, one for each of said floors; a plurality of control switches without the car, one for each of said floors; car actuating and stopping mechanism responsive, with the car at rest at a floor, to the operation of any one of said control switches for the other floors for causing the starting of the car, said mechanism, when the car is traveling in a certain direction, being responsive to said control switches for causing the car to stop successively at the floors corresponding to the control switches operated; and means for limiting the response of said mechanism to cause the starting of the car, after the last stop at a floor in said certain direction, to control switches within the car for the other floors for a predetermined time interval after the closing of the car gate and of the well door for the floor at which the last stop is made, in the event that a passenger is in the car, and for rendering said mechanism responsive to control switches without the car for the other floors upon the expiration of said time interval, in the event that no control switch within the car for the other floors is operated before said time interval has expired.

30. An elevator system comprising; an elevator car; a plurality of floors; a well door for each floor; a gate for the car; a series of control switches, one for each of said floors, arranged within the car to be operated by the passengers therein; a series of up control switches, one at each of said floors, arranged to be operated by the intending passengers at the floors; a series of down control switches, one at each of said floors, arranged to be operated by the intending passengers at the floors; means responsive, with the car idle at a floor, to the operation of any one of said control switches for the other floors, for causing the starting of the car in a direction toward the floor corresponding to the control switch operated; and means, rendered effective upon a passenger entering the car, for limiting

the response of said first named means to cause the starting of the car to control switches within the car for the other floors for a predetermined time interval after the closing of the car gate and the well door for the floor at which the car is positioned and for rendering said first named means responsive to the up and down control switches for said other floors to cause the starting of the car, upon the expiration of said time interval, in the event that no control switch within the car is operated before such time interval has expired.

31. An elevator system comprising; an elevator car; a plurality of floors; a well door for each floor; a gate for the car; a series of control switches, one for each of said floors, arranged within the car to be operated by the passengers therein; a series of up control switches, one at each of said floors, arranged to be operated by the intending passengers at the floors; a series of down control switches, one at each of said floors, arranged to be operated by the intending passengers at the floors; means responsive, with the car idle at a floor, to the operation of any one of said control switches for the other floors, for causing the starting of the car in a direction toward the floor corresponding to the control switch operated; means controlled by the well door, for the floor at which the car is positioned, for preventing said first named means causing the starting of the car in response to such control switch when said well door is open; means controlled by the car gate, when a passenger has entered the car, for preventing said first named means causing the starting of the car in response to such control switch when the car gate is open; and means, rendered effective upon a passenger entering the car, for limiting the response of said first named means to cause the starting of the car to control switches within the car for the other floors for a predetermined time interval after the closing of the car gate and such well door and for rendering said first named means responsive to the up and down control switches for the other floors to cause the starting of the car, upon the expiration of said time interval, in the event that no control switch within the car is operated before such time interval has expired.

32. An elevator system comprising; an elevator car; a plurality of floors; a well door for each of said floors; a car gate; a series of control switches within the car, one for each of said floors; a series of control switches without the car, one for each of said floors; car actuating and stopping mechanism; means responsive, with the car idle at a floor, to the operation of any one of said control switches for the other floors for causing said mechanism to start the car; means responsive to said control switches for causing said mechanism to stop the car, when traveling in a certain direction, at the floors corresponding to the control switches operated, in the natural order of floors, regardless of the order in which the control switches are operated; and means for limiting the response of said first named means to cause said mechanism to start the car, after the last stop at a floor in said certain direction, to control switches within the car for the other floors for a predetermined time interval after the closing of the car gate and of the well door for the floor at which the last stop is made, in the event that a passenger is in the car, and for rendering said first named means responsive to operated control switches without the car, for floors in the opposite direction from

the floor at which the last stop is made, to cause said mechanism to start the car in the opposite direction immediately upon the closing of the well door for the floor at which the last stop is made, in the event that the car is empty.

33. An elevator system comprising; an elevator car; a plurality of floors; a well door for each of said floors; a car gate; a series of control switches within the car, one for each of said floors; a series of control switches without the car, one for each of said floors; car actuating and stopping mechanism; means responsive, with the car idle at a floor, to the operation of any one of said control switches without the car for the other floors, with the well door for the floor at which the car is at rest closed, and to the operation of any one of said control switches within the car for the other floors, with both the well door for the floor at which the car is at rest and car gate closed, for causing said mechanism to start the car; means responsive to said control switches for causing said mechanism to stop the car, when traveling in a certain direction, at the floors corresponding to the control switches operated, in the natural order of floors, regardless of the order in which the control switches are operated; and means for limiting the response of said first named means to cause said mechanism to start the car, after the last stop in said certain direction, to control switches within the car for a predetermined time interval after the closing of the car gate and of the well door for the floor at which the last stop is made, in the event that a passenger has entered the car at such floor, and for rendering said first named means responsive to control switches without the car, for floors in the opposite direction from the floor at which the last stop is made, operated prior to the closing of the well door for the floor at which the last stop is made, to cause said mechanism to start the car in the opposite direction immediately such well door is closed, in the event that the car is empty.

34. An elevator system comprising; an elevator car; a plurality of floors; a well door for each of said floors; a car gate; a series of control switches within the car, one for each of said floors; a series of control switches without the car, one for each of said floors; car actuating and stopping mechanism; means responsive, with the car idle at a floor, to the operation of any one of said control switches without the car for the other floors, with the well door for the floor at which the car is at rest closed, and to the operation of any one of said control switches within the car for the other floors, with both the well door for the floor at which the car is at rest and car gate closed, for causing the starting of the car; means responsive to said control switches for causing said mechanism to stop the car, when traveling in a certain direction, at the floors corresponding to the control switches operated, in the natural order of floors, regardless of the order in which the control switches are operated; and means for limiting the response of said first named means to cause said mechanism to start the car, after the last stop in said certain direction to control switches within the car for a predetermined time interval after the closing of the car gate and of the well door for the floor at which the last stop is made, in the event that a passenger has entered the car at such floor, and for rendering said first named means responsive to operated control switches without the car, for floors in the oppo-

site direction from the floor at which the last stop is made, to cause said mechanism to start the car in the opposite direction immediately upon the closing of the well door for the floor at which the last stop is made, in the event that the car is empty.

35. A control system for an elevator car comprising; a plurality of controls, one for each of a plurality of floors, operable to cause the stopping of the car at their respective floors; means for alternatively establishing different types of service whereby the direction of travel of the car may be reversed at any floor or whereby the car is caused to proceed in either direction to a terminal floor before reversing.

36. A control system for an elevator car comprising; a plurality of controls, one for each of a plurality of floors, operable to cause the stopping of the car at their respective floors; means for reversing the direction of car travel at any floor; and means for changing the type of service to prevent said first named means reversing the direction of car travel except at terminal floors.

37. A control system for an elevator car comprising; a plurality of controls, one for each of a plurality of floors, operable to cause the stopping of the car at their respective floors; a service switch having two operative positions; means controlled by said service switch for causing, when said switch is in one operative position, the reversal of the direction of car travel at any floor and, when said switch is in its other operative position, the reversal of the direction of car travel only at the terminal floors.

38. A control system for an elevator car comprising; a plurality of switches, one for each of a plurality of floors; car actuating and stopping mechanism responsive to said controls for causing the stopping of the car at the floors corresponding to the switches operated, in the natural order of floors, regardless of the order in which the switches are operated; means for reversing the direction of car travel at any floor; and means for preventing the operation of the first named means to reverse the direction of car travel except at terminal floors.

39. A control system for an elevator car comprising; a plurality of switches, one for each of a plurality of floors; car actuating and stopping mechanism responsive to said controls for causing the car, when traveling in a certain direction, to stop at the floors corresponding to the switches operated, in the natural order of floors, regardless of the order in which the controls are operated; direction control means responsive to switches for floors in the opposite direction from the car for reversing the direction of car travel after its last stop in said certain direction in response to a control switch, regardless of the floor at which such last stop is made; and means for preventing the operation of the direction control means to reverse the direction of car travel except at terminal floors.

40. An elevator system comprising; an elevator car; a plurality of floors; a circuit for causing up car travel; a circuit for causing down car travel; a series of switches, one for each of said floors, said switches being connected in series relation with the switches for floors above the car connected to the up car travel circuit and the switches for floors below the car connected to the down car travel circuit; and means for opening each of said switches when the car is positioned at the floor for which the switch is provided.

41. An elevator system comprising; an elevator car; a plurality of floors; a circuit for causing up car travel; a circuit for causing down car travel; a series of switches, one for each of said floors, said switches being connected in series relation with the switches for floors above the car connected to the up car travel circuit and the switches for floors below the car connected to the down car travel circuit, regardless of the position of the car; and a member for opening each of said switches as the car arrives at the floor for which the switch is provided.

42. An elevator system comprising; an elevator car; a plurality of floors; a circuit for causing up car travel; a circuit for causing down car travel; a series of switches, one for each of said floors, said switches being connected in series relation with the switches for floors above the car connected to the up car travel circuit and the switches for floors below the car connected to the down car travel circuit, regardless of the position of the car; and mechanism for transferring each switch, as the car passes the floor for which it is provided, from said up circuit to said down circuit during up car travel and from said down circuit to said up circuit during down car travel.

43. An elevator system comprising; an elevator car; an up switch for causing up car travel, said up switch having an actuating coil; a down switch for causing down car travel, said down switch having an actuating coil; a plurality of floors; a direction switch for each floor, said direction switches being connected in series relation with the direction switches for floors above the car connected to the actuating coil of the up switch and the direction switches for floors below the car connected to the actuating coil of the down switch, regardless of the position of the car, and said direction switches being spaced to correspond to the distances between their respective floors; and a traveling direction cam for successively disconnecting each direction switch from the actuating coil of the up switch and connecting it to the actuating coil of the down switch, as the car passes the floor for which it is provided during up car travel, and for successively disconnecting each direction switch from the actuating coil of the down switch and connecting it to the actuating coil of the up switch, as the car passes the floor for which it is provided during down car travel.

44. An elevator system comprising; an elevator car; an up switch for causing up car travel, said up switch having an actuating coil; a down switch for causing down car travel, said down switch having an actuating coil; a plurality of floors; a direction switch for each floor, said direction switches being connected in series relation with the direction switch for the upper terminal floor connected to the actuating coil of the up switch and being spaced to correspond to the distances between their respective floors and each direction switch being provided with a contacting operating member; a traveling direction cam for successively engaging said contacting operating members to open their respective switches, said direction cam having an up contacting section connected to the actuating coil of the up switch and a down contacting section connected to the actuating coil of the down switch, said sections being insulated from each other; and mechanism for causing movement of said cam during car travel in accordance with the movement of the car, said cam being of such length as to engage

at least two of the direction switch operating members, regardless of the position of the car.

45. An elevator system comprising; an elevator car; an up switch for causing up car travel, said up switch having an actuating coil; a down switch for causing down car travel, said down switch having an actuating coil; a plurality of floors; a direction switch for each floor, said direction switches being connected in series relation with the direction switch for the upper terminal floor connected to the actuating coil of the up switch and being spaced to correspond to the distances between their respective floors and each direction switch being provided with a contacting operating member; a traveling direction cam for successively engaging said contacting operating members to open their respective switches, said direction cam having an up contacting section connected to the actuating coil of the up switch, a down contacting section connected to the actuating coil of the down switch and an insulated section intermediate said up and down sections, said cam being of a length and arranged so that with the car at rest at an intermediate floor the insulated section engages the contacting operating member of the switch for that floor, causing that switch to be open and isolated from the others, the up contacting section engages the contacting operating member of the switch for the floor next above, causing that switch to be open but connecting its contacting operating member to the actuating coil of the up switch, and the down contacting section engages the contacting operating member of the switch for the floor next below, causing that switch to be open but connecting its contacting operating member to the actuating coil of the down switch; and mechanism for causing movement of said cam during car travel in accordance with the movement of the car.
46. An elevator system comprising; an elevator car; an up switch for causing up car travel, said up switch having an actuating coil; a down switch for causing down car travel, said down switch having an actuating coil; a plurality of floors; a direction switch for each floor, each comprising a stationary contact and a pivoted contacting operating member for engaging the stationary contact, said direction switches being connected in series relation with the direction switch for the upper terminal floor connected to the actuating coil of the up switch and being spaced to correspond to the distances between their respective floors; a traveling direction cam for successively engaging said contacting operating members to cause their separation from their respective stationary contacts, said direction cam having an up contacting section connected to the actuating coil of the up switch, a down contacting section connected to the actuating coil of the down switch and an insulated section intermediate said up and down sections, said cam being of a length and arranged so that with the car at rest at an intermediate floor the insulated section engages the contacting operating member of the switch for that floor, causing that switch to be open and isolated from the others, the up contacting section engages the contacting operating member of the switch for the floor next above, causing that switch to be open but connecting its contacting operating member to the actuating coil of the up switch, and the down contacting section engages the contacting operating member of the switch for the floor next below, causing that switch to be open but connecting its contacting operating member to the actuating coil of the down switch; mechanism for causing movement of said cam during car travel in accordance with the movement of the car to cause, during up car travel, the engagement of each direction switch contacting operating member by the direction cam up contacting section as the car approaches the floor for which the direction switch is provided, the engagement of each direction switch contacting operating member by the direction cam insulated section as the car is opposite the floor for which the direction switch is provided, and the engagement of each direction switch contacting operating member by the direction cam down contacting section after the car leaves the floor for which the direction switch is provided, and, during down car travel, the engagement of each direction switch contacting operating member by the direction cam down contacting section as the car approaches the floor for which the direction switch is provided, the engagement of each direction switch contacting operating member by the direction cam insulated section as the car is opposite the floor for which the direction switch is provided, and the engagement of each direction switch contacting operating member by the direction cam up contacting section after the car leaves the floor for which the direction switch is provided.
47. An elevator system comprising; an elevator car; an up switch for causing up car travel, said up switch having an actuating coil; a down switch for causing down car travel, said down switch having an actuating coil; a plurality of floors; a direction switch for each floor, each comprising a stationary contact and a pivoted contacting operating member for engaging the stationary contact, said direction switches being connected in series relation with the direction switch for the upper terminal floor connected to the actuating coil of the up switch and being spaced to correspond to the distances between their respective floors; a traveling direction cam for successively engaging said contacting operating members to cause their separation from their respective stationary contacts, said direction cam having an up contacting section connected to the actuating coil of the up switch, a down contacting section connected to the actuating coil of the down switch and an insulated section intermediate said up and down sections, said cam being of a length and arranged so that with the car at rest at an intermediate floor the insulated section engages the contacting operating member of the switch for that floor, causing that switch to be open and isolated from the others, the up contacting section engages the contacting operating member of the switch for the floor next above, causing that switch to be open but connecting its contacting operating member to the actuating coil of the up switch, and the down contacting section engages the contacting operating member of the switch for the floor next below, causing that switch to be open but connecting its contacting operating member to the actuating coil of the down switch; mechanism for causing movement of said cam during car travel in accordance with the movement of the car to cause, during up car travel, the engagement of each direction switch contacting operating member by the direction cam up contacting section as the car approaches the floor for which the direction switch is provided, the engagement of each direction switch contacting operating member by the direction cam insulated section as the car is opposite the floor for which the direction switch is provided, and the engagement of each direction switch contacting operating member by the direction cam down contacting section after the car leaves the floor for which the direction switch is provided.

for which the direction switch is provided, and the engagement of each direction switch contacting operating member by the direction cam down contacting section after the car leaves the floor for which the direction switch is provided, and, during down car travel, the engagement of each direction switch contacting operating member by the direction cam down contacting section as the car approaches the floor for which the direction switch is provided, the engagement of each direction switch contacting operating member by the direction cam insulated section as the car is opposite the floor for which the direction switch is provided, and the engagement of each direction switch contacting operating member by the direction cam up contacting section after the car leaves the floor for which the direction switch is provided; an insulated member for lifting the contacting operating members of the direction switches off the direction cam up contacting section during up car travel upon the arrival of the car within a predetermined distance of their respective floors; and an insulated member for lifting the contacting operating members of the switches off the direction cam down contacting section during down car travel upon the arrival of the car within a predetermined distance of their respective floors.

48. An elevator system comprising; an elevator car; an up switch for causing up car travel, said up switch having an actuating coil; a down switch for causing down car travel, said down switch having an actuating coil; a plurality of floors; a direction switch for each floor, each comprising a stationary contact and a pivoted contacting operating member for engaging the stationary contact, said direction switches being connected in series relation with the direction switch for the upper terminal floor connected to the actuating coil of the up switch and being spaced to correspond to the distances between their respective floors; a traveling direction cam for successively engaging said contacting operating members to cause their separation from their respective stationary contacts, said direction cam having an up contacting section connected to the actuating coil of the up switch, a down contacting section connected to the actuating coil of the down switch and an insulated section intermediate said up and down sections, said cam being of a length and arranged so that with the car at rest at an intermediate floor the insulated section engages the contacting operating member of the switch for that floor, causing that switch to be open and isolated from the others, the up contacting section engages the contacting operating member of the switch for the floor next above, causing that switch to be open but connecting its contacting operating member to the actuating coil of the up switch, and the down contacting section engages the contacting operating member of the switch for the floor next below, causing that switch to be open but connecting its contacting operating member to the actuating coil of the down switch; a control circuit for each direction switch connected to the operating member thereof, any one of the control circuits for floors above the floor at which the car is positioned upon being completed causing the energization of the actuating coil of the up switch, the circuit for this actuating coil, in the event that the control circuit completed is for the floor next above, being by way of the contacting operating member

of the direction switch for that floor and the up contacting section of the direction cam and, in the event that the control circuit completed is for a floor above such next floor above, being by way of the direction switch for that floor and those for the floors above that floor in series relation, and any one of the control circuits for floors below the floor at which the car is positioned upon being completed causing the energization of the actuating coil of the down switch, the circuit for this actuating coil, in the event that the control circuit completed is for the floor next below, being by way of the contacting operating member of the direction switch for that floor and the down contacting section of the direction cam, and in the event that the control circuit completed is for a floor below such next floor below, being by way of the direction switch for that floor to the operating member of the direction switch for the floor next below the floor at which the car is positioned through the direction switches intervening in series relation; and mechanism for causing movement of said cam during car travel in accordance with the movement of the car to cause, during up car travel, the transfer of each control circuit, upon the direction switch contacting operating member to which it is connected being engaged by the direction cam up contacting section, to said up cam section, the isolation of each control circuit, upon the direction switch contacting operating member to which it is connected being engaged by the direction cam insulated section, and the transfer of each control circuit, upon the direction switch contacting operating member to which it is connected being engaged by the direction cam down contacting section, to said down cam section, and, during down car travel, the connection of each control circuit, upon the direction switch contacting operating member to which it is connected being engaged by the direction cam down contacting section, directly to said down cam section, the isolation of each control circuit, upon the direction switch contacting operating member to which it is connected being engaged by the direction cam up contacting section, to said up cam section.

49. An elevator system comprising; an elevator car; an up switch for causing up car travel, said up switch having an actuating coil; a down switch for causing down car travel, said down switch having an actuating coil; a plurality of floors; a direction switch for each floor, each comprising a stationary contact and a pivoted contacting operating member for engaging the stationary contact, said direction switches being connected in series relation with the direction switch for the upper terminal floor connected to the actuating coil of the up switch and being spaced to correspond to the distances between their respective floors; a traveling direction cam having an up contacting section connected to the actuating coil of the up switch, a down contacting section, longer than said up section, connected to the actuating coil of the down switch and an insulated section intermediate said up and down sections, said cam being of a length and arranged so that with the car at rest at an intermediate floor the insulated section engages the contacting operating member of the switch for that floor, causing that switch to be open and isolated from the others, the up contacting section engages the contacting operating member of the switch for the floor next above, causing that switch to be open but connecting its contacting operating member to the actuating coil of the up switch, and the down contacting section, longer than said up section, engages the contacting operating member of the switch for the floor next below, causing that switch to be open but connecting its contacting operating member to the actuating coil of the down switch; a control circuit for each direction switch connected to the operating member thereof, any one of the control circuits for floors above the floor at which the car is positioned upon being completed causing the energization of the actuating coil of the up switch, the circuit for this actuating coil, in the event that the control circuit completed is for the floor next above, being by way of the contacting operating member

rest at an intermediate floor the insulated section engages the contacting operating member of the switch for that floor, causing that switch to be open and isolated from the others, the up contacting section engages the contacting operating member of the switch for the floor next above, causing that switch to be open but connecting its contacting operating member to do the actuating coil of the up switch, and the down contacting section engages the contacting operating member of the switch for the floor next below, causing that switch to be open but connecting its contacting operating member to the actuating coil of the down switch, a control circuit for each direction switch connected to the operating member thereof, any one of the control circuits for floors above the floor at which the car is positioned upon being completed causing the energization of the actuating coil of the up switch, the circuit for this actuating coil in the event that the control circuit completed is for the floor next above, being by way of the contacting operating member of the direction switch for that floor and the up contacting section of the direction cam, and, in the event that the control circuit completed is for a floor above such next floor above, being by way of the direction switch for that floor and those for the floors above that floor in series relation, and any one of the control circuits for floors below the floor at which the car is positioned upon being completed causing the energization of the actuating coil of the down switch, the circuit for this actuating coil, in the event that the control circuit completed is for the floor next below, being by way of the contacting operating member of the direction switch for that floor and the down contacting section of the direction cam, and, in the event that the control circuit completed is for a floor below such next floor below, being by way of the direction switch for that floor to the operating member of the direction switch for the floor next below the floor at which the car is positioned through the direction switches intervening in series relation; mechanism for causing movement of said cam during car travel in accordance with the movement of the car to cause, during up car travel, the transfer of each control circuit, upon the direction switch contacting operating member to which it is connected being engaged by the direction cam up contacting section, to said up cam section, the isolation of each control circuit, upon the direction switch contacting operating member to which it is connected being engaged by the direction cam down contacting section, to said down cam section, and, during down car travel, the connection of each control circuit, upon the direction switch contacting operating member to which it is connected being engaged by the direction cam down contacting section, directly to said down cam section, the isolation of each control circuit, upon the direction switch contacting operating member to which it is connected being engaged by the direction cam insulated section, and the transfer of each control circuit, upon the direction switch contacting operating member to which it is connected being engaged by the direction cam up contacting section, to said up cam section; an insulated member for momentarily lifting the 75 contacting operating members of the direction

switches off the direction cam up contacting section during up car travel upon the arrival of the car within a predetermined distance of their respective floors; and an insulated member for momentarily lifting the contacting operating members of the switches off the direction cam down contacting section during down car travel upon the arrival of the car within a predetermined distance of their respective floors.

50. Switching mechanism comprising; a series of spaced switches, each switch comprising a movable contact member; a traveling cam for successively engaging said movable contact members to make electrical contact therewith and to cause the opening of their respective switches, 15 said cam comprising two contacting sections separated by an insulated section and being of a length to span at least two of said movable contact members; and mechanism for moving said cam.

51. Switching mechanism comprising; a series of vertically spaced switches, each switch comprising a stationary contact, a movable contact and a contacting operating member electrically connected to said movable contact; a vertical 25 traveling cam for successively engaging said contacting operating members to cause the separation of the movable and stationary contacts of the switches for which they are provided, said cam comprising an upper contacting section, a 30 lower contacting section and an insulated section intermediate said upper and lower sections, and said cam being of a height and arranged so that, with the insulated section in engagement with the contacting operating member of an intermediate one of said switches, the upper contacting section is in engagement with the contacting operating member of the switch next above and the lower contacting section is in engagement with the contacting operating member 40 of the switch next below; and mechanism for moving said cam.

52. Switching mechanism comprising; a series of vertically spaced switches, each switch comprising a stationary contact, a movable contact 45 and a contacting operating member electrically connected to said movable contact; a vertically traveling cam for successively engaging said contacting operating members to cause the separation of the movable and stationary contacts 50 of the switches for which they are provided, said cam comprising an upper contacting section, a lower contacting section longer than said upper section and an insulated section intermediate said upper and lower sections, and said cam being of a height and arranged so that, with the insulated section in engagement with the contacting operating member of an intermediate one of said switches, the upper contacting section is in engagement with the contacting operating 60 member of the switch next above and the lower contacting section is in engagement with the contacting operating member of the switch next below; and mechanism for moving said cam to cause, during up cam movement, after the engagement of the contacting operating member of any one of said switches by the up contacting cam section, the transfer of such operating member to the insulated cam section and thereafter the transfer of such operating member to 70 the down cam section, and, during down cam movement, after the engagement of the contacting operating member of any one of the switches by the down contacting cam section, the transfer of such operating member to the insulated 75

cam section and thereafter the transfer of such operating member to the up contacting cam section.

53. A switch comprising; a stationary contact; a pivoted contact member normally in engagement with said stationary contact; a movable operating member upon which said contact member is pivotally mounted; and means for causing, during the initial movement of said operating member about its pivot, movement of said contact member about its pivot to slidably maintain it in engagement with said stationary contact, said operating member, during its movement, engaging said contact member to cause its disengagement from the stationary contact.

54. A switch comprising; a stationary contact; a pivoted movable contact member for engaging said stationary contact; a pivotally movable operating member upon which said contact member is pivotally mounted; and means for yieldingly maintaining said movable contact member in engagement with said stationary contact, said means, during the initial movement of said operating member about its pivot, causing movement of said contact member about its pivot to slidably maintain it in engagement with said stationary contact, said operating member, during its movement, engaging said contact member to cause its disengagement from the stationary contact.

55. A switch comprising; a stationary contact; a pivoted lever, one end of the lever forming a contact for engaging said stationary contact; a pivotally movable member upon which said lever is pivotally mounted; and means for yieldingly maintaining said contact end of the lever in engagement with said stationary contact, said means, during the initial movement of said member about its pivot in a certain direction, causing movement of said lever about its pivot to slidably maintain said contact end of the lever in engagement with said stationary contact, said member, during the latter part of its movement, engaging said lever to cause the disengagement of the contact end of the lever from the stationary contact against the force of said yielding means.

56. A switch comprising; a stationary contact; a pivoted lever, one end of the lever forming a contact for engaging said stationary contact; a pivotally movable member upon which said lever is pivotally mounted, said movable member having a portion for engaging the other end of the lever, said portion being disengaged from said other end of the lever when said contact end of the lever is in its engaged position; and resilient means for yieldingly maintaining said contact end of the lever in engagement with said stationary contact, said resilient means, during the initial movement of said member about its pivot in a certain direction, causing movement of said lever about its pivot to slidably maintain said contact end of the lever in engagement with said stationary contact until the engagement of said portion of said member and the other end of said lever occurs, said member, upon its continued movement after the engagement of its portion and the other end of the lever, causing the disengagement of the contact end of the lever from the stationary contact against the force of said yielding means.

57. Switching mechanism comprising; a pivoted operating member, said member having an extended position; a movable contact member pivotally mounted on said operating member and

electrically connected thereto; a stationary contact for said movable contact and disposed in the path of movement thereof; resilient means for maintaining said movable contact in engagement with said stationary contact and for biasing said operating member into its extended position; and means for engaging said operating member to cause its inward pivotal movement, said operating member, during the first part of said movement, causing inward movement of said movable contact member, said resilient means maintaining said movable contact member in slidable engagement with said stationary contact during such movement, and said operating member thereafter engaging said movable contact member to cause its separation from said stationary contact against the force of said resilient means.

58. Switching mechanism comprising; a bracket; an operating member pivotally mounted on said bracket, said member being formed with a stop for engaging said bracket to limit its movement in one direction; a movable contact member pivotally mounted on said operating member and electrically connected thereto; a stationary contact for said movable contact and disposed in the path of movement thereof; a spring for maintaining said movable contact member in engagement with said stationary contact and for biasing said operating member into its position with its stop in engagement with said bracket; and means for engaging said operating member to cause its pivotal movement in the other direction, said operating member, during the first part of said movement, causing movement of said movable contact member, said spring maintaining said movable contact member in slidable engagement with said stationary contact, and said operating member thereafter engaging said movable contact member to cause its separation from said stationary contact against the force of said spring.

59. In a floor controller; switching mechanism comprising; a traveling member; a series of spaced collars; a pawl carried by said member, said pawl having an extended and a retracted position and being adapted, when extended, to successively engage said collars during movement of said member; a magnet for moving said pawl to retracted position; and a switch carried by said member and arranged to be operated by said pawl upon its engagement with any one of said collars.

60. In a floor controller; switching mechanism comprising; a traveling member; means for causing movement of said member; a series of spaced collars; a pawl carried by said member, said pawl having an extended and a retracted position and being adapted, when extended, to successively engage said collars during movement of said member; an electromagnet adapted, when energized, to move said pawl to retracted position so as to cause it to clear said collars during travel of the member; and a switch carried by said member and connected to be operated by said pawl upon its engagement with any one of said collars.

61. In a floor controller; switching mechanism comprising; a traveling nut; means for causing movement of said nut in opposite directions; a group of spaced stationary collars; a second group of spaced stationary collars; a pair of pivoted pawls carried by said nut, one of said pawls being adapted, when the nut is moving in one direction, to successively engage the collars of

- the first group and the other being adapted, when the nut is moving in the opposite direction, to successively engage the collars of the second group; means for biasing each pawl into position 5 to engage its collars; a magnet for retracting said pawls so as to cause them to clear said collars during travel of the nut; and a plurality of switches connected to be successively operated by either of said pawls upon its engagement 10 with any one of its collars.
62. In a floor controller; switching mechanism comprising; a screw; a traveling nut mounted on said screw; means for turning said screw in opposite directions to cause opposite travel of said nut; a group of spaced stationary collars; a second group of spaced stationary collars; a pair of pivoted pawls carried by said nut, one of said pawls being adapted, when the nut is moving in one direction, to successively engage the collars 15 of the first group and the other being adapted, when the nut is moving in the opposite direction, to successively engage the collars of the second group; means for biasing each pawl into position to engage its collars; an electromagnet adapted, 20 when energized, to retract said pawls so as to cause them to clear said collars during travel of the nut; and a plurality of switches carried by said nut and connected to be successively operated by either of said pawls upon its engagement with 25 any one of its collars.
63. In a floor controller; switching mechanism comprising; a traveling nut; means for causing movement of said nut in opposite directions; a group of spaced collars; a second group of spaced collars; a plurality of switches carried by said nut, each switch having a pivoted operating member; a pair of pivoted pawls carried by said nut and connected to said operating members, each of said pawls having an extended and a retracted 30 position, one of said pawls being adapted when extended to successively engage the collars of the first group during travel of the nut in one direction and the other of said pawls being adapted when extended to successively engage the 35 collars of the second group during travel of the nut in the opposite direction, each of said pawls, upon continued movement of said nut after the engagement of the pawl with a collar, causing the successive movement of said operating members about their pivots to cause the opening of their respective switches and both of said pawls when retracted clearing said collars during travel 40 of the nut in both directions.
64. In a floor controller; switching mechanism comprising; a traveling nut; means for causing movement of said nut in opposite directions; a group of spaced stationary collars; a second group of spaced stationary collars; a plurality of switches carried by said nut, each switch having 45 a pivoted operating member biased to switch closed position; a pair of pawls pivotally mounted on the operating member for one of said switches, each of said pawls having an extended and a retracted position, one of said pawls being adapted when extended to successively engage the collars of the first group during travel of the nut in one direction and the other of said pawls being adapted when extended to successively engage the 50 collars of the second group during travel of the nut in the opposite direction, each of said pawls, upon continued movement of said nut after the engagement of the pawl with a collar, causing the successive movement of said operating members about their pivots to cause the opening of their respective switches; means for biasing each pawl to extended position; and an electromagnet carried by said nut, said electromagnet, when energized, causing movement of said pawls to retracted position against the force of said biasing means to cause the pawls to clear the collars during travel 55 of the nut.
65. In a floor controller; switching mechanism comprising; a vertical screw; a traveling nut mounted on said screw; means for turning said screw in opposite directions to cause up and down movement of said nut; a pair of stationary vertical members; a group of spaced collars mounted on one of said vertical members; a second group of spaced collars mounted on the other vertical member; a plurality of switches carried by said nut, each switch having a pivoted operating member biased to switch closed position; a pair of 60 pawls pivotally mounted on the operating member for one of said switches, each of said pawls having an extended and a retracted position, one of said pawls being adapted when extended to successively engage the collars of the first group during travel of the nut in one direction and the other of said pawls being adapted when extended to successively engage the collars of the second group during travel of the nut in the opposite direction, each of said pawls, upon continued movement of said nut after the engagement of the pawl with a collar, causing the successive movement of said operating members about their pivots to cause the opening of their respective switches; means for biasing each pawl to extended position; and an electromagnet carried by said nut, said electromagnet, when energized, causing movement of said pawls to retracted position against the force of said biasing means to cause the pawls to clear the collars during travel 65 of the nut.
66. In a floor controller; switching mechanism comprising; a vertical screw; a traveling nut mounted on said screw; means for turning said screw in opposite directions to cause up and down movement of said nut; a pair of stationary vertical members; a group of spaced collars mounted on one of said vertical members; a second group of spaced collars mounted on the other vertical member; a plurality of switches carried by said nut, each switch having a pivoted operating member; a pair of pawls pivotally mounted on the operating member for one of said switches, each of said pawls having an extended and a retracted position, one of said pawls being adapted when extended to successively engage the collars of the first group during travel of the nut in one direction and the other of said pawls being adapted when extended to successively engage the collars of the second group during travel of the nut in the opposite direction, each of said pawls, upon continued movement of said nut after the engagement of the pawl with a collar, causing the successive movement of said operating members about their pivots to cause the opening of their respective switches; means for biasing each pawl to extended position; and an electromagnet carried by said nut, said electromagnet, upon being energized, causing movement of said pawls to retracted position against the force of said biasing means, thus causing the release of the pawl in engagement with a collar; and biasing means for said switches for causing them to be returned to closed position upon the release of the pawl from said collar.
67. In combination, an elevator car, a hoisting motor therefor having multi-speed regulation, control means at each of a plurality of landings having combined dispatch and intercepting functions and affording selectivity to effect automatic 70
- 75

slow-down and stop of the car in accordance with its direction of movement, the farthest-up and farthest-down car movement being effected in accordance with a farthest-up and farthest-down actuated control means regardless as to which of the two for each of the two different landings is actuated, and either of said control means at each of said two landings being effective to cause automatic slow-down and stop of the car thereat, 10 any of said control means being actuatable at any time regardless of the position of the car and the direction of car movement.

68. A control system for an elevator car comprising plural control means at each of a plurality of landings, any control means at each landing effective to initiate movement of the car directly to its landing from either direction and to stop the car thereat, any of said control means requiring actuation only once to effect response thereto regardless of the position of the car and the direction of car movement when actuated.

69. A control system for an elevator car comprising two control means at each of a plurality of landings, effective to initiate start of the car toward their respective landings, one at each landing effective to intercept the car when moving upwardly, and the other one at each landing effective to intercept the car when moving downwardly, any of said control means requiring actuation only once to effect response thereto, regardless of the position of the car and the direction of car movement when actuated.

70. A control system for an elevator car comprising two control means at each of a plurality of landings, either one at each landing effective to initiate start of the car directly to its landing from a position above or below same and to stop the car thereat, one at each landing effective to intercept the car when moving upwardly and the other one at each of said landings effective to intercept the car when moving downwardly, any of said control means requiring actuation only once to effect response thereto regardless of the position of the car and the direction of car movement when actuated.

71. A control system for an elevator car comprising two control means at each of a plurality of landings effective to cause start of the car, farthest movement of the car in one direction being in accordance with the farthest actuated of either control means at a landing, said control means at each landing operable selectively to intercept the car in accordance with "up" and "down" directions of car movement, any of said control means requiring actuation only once to effect response thereto regardless of the position of the car and the direction of car movement, and time-controlled means to start the car in a direction predetermined by said control means.

72. In a control system for an electric elevator the combination of the elevator car, a plurality of floors, push buttons at the floors, a machine on the car for weighing the car load, means operable in response to pressure of a floor button for causing the car to stop at said floor, and means controlled by the weighing machine to prevent the car from stopping at that floor if fully loaded.

73. In a control system for an electric elevator, the combination of the elevator car, a plurality of floors, push buttons at the floors, means operable in response to pressure of a floor button for causing the car to stop at said floor, and means automatically to prevent the car from stopping at that floor if fully loaded.

74. A control system for an elevator car comprising a circuit controller controllable manually to control the car, and means responsive to load on the car to render said circuit controller ineffective to control the car without rendering it nonactuable.

75. A control system for an elevator car comprising control means for each of a plurality of landings and means responsive to load on the car to render said control means ineffective to control the car without rendering them non-actuable to register calls.

76. A control system for an elevator car comprising control means at each of a plurality of landings, control means on the car for each of said landings, circuits responsive to said control means at the landings to control the car, additional circuits responsive only to said control means on the car to control the car, and means responsive to load on the car to render said first named circuits inoperative.

77. A control system for an elevator car comprising control means at each of a plurality of landings, control means on the car for each of said landings, circuits effective to cause stop of the car, responsive to said control means at the landings, additional circuits effective to cause stop of the car, controllable only by said control means on the car, and means responsive to load on the car to render said first named circuits inoperative whereby stop of the car is responsive only to said control means on the car.

78. A control system for an elevator car comprising selective means to register calls from each of a plurality of landings and from the car, means responsive thereto to stop the car, and load controlled means to render second named means ineffective to stop the car so that the car operates as express without stopping at landings for which calls are registered from the landings while at the same time said second named means operates to stop the car only at landings for which calls are registered from within the car.

79. In an elevator control system, a car operable in a hatchway past a plurality of floors, passenger-operated means disposed at each floor for registering calls for stopping the car at the corresponding floor, and means responsive to the load on the car for causing the car to by-pass the calls registered on the passenger-operated means at the floors.

80. In an elevator control system, a car operable in a hatchway past a plurality of floors, passenger-operated means disposed at each floor for registering calls for causing said car to move to the corresponding floor, and means responsive to the load on the car for causing the car to by-pass the calls registered on the passenger-operated means at the floors.

81. In an elevator control system, a car operable in a hatchway past a plurality of floors, passenger-operated means disposed at each floor for registering calls for stopping the car at the corresponding floor, means disposed on the car for registering calls for stops to be made at the floors and load responsive means for causing the car to by-pass only the calls registered on the passenger-operated means at the floors in responding to registered calls.

82. In an elevator control system, a car operable in a hatchway past a plurality of floors, passenger-operated means disposed at each floor for registering calls for stopping the car at the corresponding floor, means disposed on the car for registering calls for stops to be made at the floors,

- means responsive to action of the car in answering registered calls for cancelling said calls and load responsive means for causing the car to bypass only the calls registered on the passenger-operated means at the floors in responding to registered calls and for rendering said cancelling means ineffective to cancel by-passed calls.
83. A control system for an elevator car comprising a circuit controller controllable manually and effective to cause slow-down of the car, and means responsive to load on the car to render said circuit controller ineffective to cause slow-down of the car without rendering the latter non-actuable.
84. A control system for an elevator car comprising control means for each of a plurality of landings, means responsive thereto automatically to cause slow-down of the car at landings, and load controlled means to cause movement of the car uninterruptedly regardless of said control means which are actuated.
85. A control system for an elevator car comprising the car control means for each of a plurality of landings, a switch to effect stop of the car, an electro-responsive means operatively associated therewith, circuits for said electro-responsive means controllable manually from said landings, each circuit partially closed by its associated control means, a contactor in each of said circuits, a contactor common to all of said first named contactors actuable by movement of the car successively to engage same to complete their associated circuits, and means to energize said electro-responsive means independently of said circuits.
86. A control system for an elevator car comprising call registering means, means responsive thereto to cause stop of the car, and load con-
- trolled means to cause non-stop operation of the car regardless of calls which are registered.
87. A control system for an elevator car comprising, car start contacts controllable from within the car, selectively controlled stop circuits controllable from each of a plurality of landings, additional selectively controlled stop circuits controllable only from within the car, and load controlled means to render said first named stop circuits ineffective to stop the car while at the same time said additional stop circuits are effective to stop the car.
88. A control system for an elevator car comprising a car running circuit controllable from within the car to cause the car to run, a stop circuit, and load controlled means to render said stop circuit ineffective to cause stop of the car.
89. An electric elevator system comprising; an elevator car; a plurality of landings served by the car; a plurality of controls, one for each of said landings; means responsive to the operation of said controls for causing the car, during travel in a certain direction, to slow down and stop at each of the landings for which controls are operated; means for starting the car after each stop; and means for causing the car in its travel in said certain direction toward a predetermined one of said landings to continue to and stop at said predetermined landing after a stop has been made at the farthest landing for which a control has been operated, provided said predetermined landing is beyond said farthest landing, and in the event said farthest landing is beyond said predetermined landing, for causing the car to run past said predetermined landing without stopping thereat unless said control for said predetermined landing has been operated.

EDWARD L. DUNN.
